UNITED STATES PATENT OFFICE.

SAMUEL B. WILLIAMS, OF BROOKLYN, NEW YORK, AND EARL S. GIBSON, OF RIDGEWOOD, NEW JERSEY, ASSIGNORS TO WESTERN ELECTRIC COMPANY, INCORPORATED, OF NEW YORK, N. Y., A CORPORATION OF NEW YORK.

TELEPHONE-EXCHANGE SYSTEM.

Application filed June 13, 1923. Serial No. 645,011.

To all whom it may concern:

Be it known that we, SAMUEL B. WILLIAMS and EARL S. GIBSON, citizens of the United States of America, residing at Brooklyn, in the county of Kings and State of New York, and Ridgewood, in the county of Bergen and State of New Jersey, respectively, have invented certain new and useful Improvements in Telephone-Exchange Systems, of which the following is a full, clear, concise, and exact description:

This invention relates to telephone exchange systems, and more particularly, it has to do with telephone systems of the class wherein automatic switching apparatus is employed in the establishment of conversational connections.

Heretofore multi-office telephone systems have been devised wherein so-called tandem offices are employed. In such systems when a subscriber's line in a calling office requires extension to a called line in a distant office and there exists no interconnecting trunk between the calling and called offices, the call is necessarily routed through a tandem office. Furthermore, in such systems wherein in a call requires the employment of line extending apparatus in a tandem office, it has been the usual practice to transfer from the calling office to the tandem office the designation of a wanted line by means of codes of impulses. Thereupon the transferred record causes the switching apparatus at the tandem office to select a trunk outgoing to the called office. When this trunk is seized, the called line designation record is again repeated by means of current impulses from the tandem office to registering apparatus in the called office for the purpose of completing the connection thereat. That is to say, in telephone systems wherein tandem offices are employed, it has been customary to repeat from one office to a succeeding office a record of the called line designation as dialed by a calling subscriber. Under certain conditions, however, it conduces to greater efficiency if instead of repeating a called line designation from office to office, this same record is transferred directly from an originating office to a terminating office

by means of a tandem office without the necessity of repetition at said intervening tandem office.

The object of the invention is to increase the efficiency and serviceability of telephone exchange systems involving a number of central offices distributed throughout the exchange area, by improving the method of establishing and controlling connections where such connections involve a plurality of said central offices.

A feature of the invention relates to the provision, in a system where connections are extended through a number of offices, of means for sending designation records from one office through a succeeding office to a distant office beyond, there to control the further extension of the connection.

A further feature of the invention relates to the provision of means in a given office for sending a portion of a designation record to a succeeding office to determine the extension of the connection to a still further office beyond, and for sending another portion of such record through the succeeding office to the office beyond in order to control selection at said latter office.

Another feature relates to a system involving connections established from an originating office through a tandem office to a distant office beyond wherein the character of the line between the originating and tandem offices together with the designation record of the call determine in some cases that the record is sent from the originating office to the tandem and then to the office beyond whereas in other cases, it is sent directly from the originating office to the office beyond.

A still further feature relates to a system arranged to build connections from an originating office through a plurality of tandem offices to a terminating office wherein the record of a called line designation may be repeated from the originating office through each succeeding tandem office to the final office to control the extension of the connection in said final office or it may be sent directly from the originating office through all intermediate tandem points to the final office.

2
fice or directly from any tandem point through succeeding tandem points to the final office.

A still further feature relates to a system 5 having a calling office equipped with a number of registers and a common switch controlling marker, wherein a portion of such record is transferred from one of the senders to the marker to establish a connection to a tandem 10 office while another portion is transferred from the sender through the tandem office to an office beyond for controlling therein the further extension of the connection.

These and other features and advantages 15 contemplated by the present invention will become more thoroughly understood after a detailed consideration of the drawing and a study of the appended claims.

The drawing, which constitutes a part of 20 the disclosure illustrates, partly in diagrammatic manner and partly in detail, the circuits and apparatus constituting a telephone system incorporating the principles and features of invention. While telephone exchange systems of the character herein disclosed are capable of handling the various classes of calls giving the different types of service and are arranged to meet the usual requirements found in telephone practice, 25 the drawing in the present case has been devoted more especially to a showing of interoffice working. It will be understood, of course, that the various offices illustrated in the drawing may each be equipped with local switching apparatus for the purpose of 30 building connections to lines terminating in these offices. Considering the system as capable of establishing connections through one or more tandem points intermediate the originating and terminating offices, the drawing may be divided into two main sections as illustrated in Figs. 57 and 58. Fig. 35 57 is a diagram of the manner in which the several sheets of drawing could be arranged to show the equipment necessary for setting up a connection involving an originating office, an intermediate office and a final or terminating office. Fig. 58 is a diagram showing the manner in which the several sheets of 40 the drawing should be arranged to illustrate the circuits and apparatus for the establishment of a connection involving an originating office, two intermediate tandem offices and a final or terminating office. Comparing these two diagrams it will be observed that in order to attain the layout shown in Fig. 58 it is only necessary to introduce at the proper place in the diagram of Fig. 57, the additional Figures 34 to 44, 45 inclusive.

Referring to the drawing Fig. 1 is a partial showing of one of the coordinate line switches illustrating the manner in which calling subscribers' lines are connected 50 through link circuits to idle outgoing trunks.

This figure also discloses a step-by-step allotter switch for allotting the outgoing trunks for use in succession.

Fig. 2 shows in detail one of the trunks leading from the line switch to a first group selector or district selector switch as it will be called hereinafter. This figure also shows diagrammatically a second one of the trunks outgoing from the line switch. 70

Fig. 3 shows a sender selector switch of 75 the coordinate type for attaching an idle recording mechanism or sender with the trunks, such as the one leading from the line switch to the district selector. This figure also illustrates a step-by-step allotter switch for allotting the recording mechanisms in succession for use. 80

Figs. 4, 5, 6, 7, 8 and 9 represent one of the several senders.

Fig. 4 shows the recording circuit where 85 the incoming impulses from the subscriber's dial are received on counting relays to be recorded on the registers.

Fig. 5 illustrates the circuits for controlling 90 the operations of the sender in their proper sequence and also for determining the character of these operations in accordance with the class of the call undergoing extension.

Fig. 6 shows the equipment used for transmitting 95 code impulses to distant offices in the case of interoffice connections and also shows other controlling mechanism.

Fig. 7 illustrates the code registers for recording 100 the office designations which are represented by the first three letters or characters.

Fig. 8 shows the registers of the recording mechanism which receive the thousands and hundreds numerical designations. 105

Fig. 9 illustrates the tens units and stations registers.

Fig. 10 shows a portion of the district selector switch which is also of the coordinate type and in which the trunks incoming 110 from the line switches terminate on vertical rows of contacts. Several outgoing trunks leading to succeeding switches are also illustrated.

Figs. 11, 12 and 13 illustrate a selection 115 controlling device or district marker as it will be called hereinafter common to a plurality of district switches such as the one shown in Fig. 10.

Fig. 11 shows the circuits for controlling 120 the sequential operations of the marker.

Fig. 12 shows the marker registers which are operated in accordance with the settings of sender registers to determine selection at the district switches, and also to determine the class of the call undergoing extension in order that this latter information may be transferred back to the sender. 125

Fig. 13 shows the testing equipment which is common to several district selector 130

switches and also connecting devices for connecting the testing equipment with the desired selecting switch.

Fig. 14 shows a connector for attaching the district marker to any one of the several recording senders, such as the one shown in Figs. 4 to 9, inclusive.

Figs. 15 and 16 illustrate circuit connections leading from the recording sender to the district marker and also to the office marker.

Fig. 17 illustrates one of the trunks outgoing from the district switches and leading to an office selector.

Fig. 18 shows a portion of a second coordinate selector switch hereinafter referred to as the office selector in which terminate on vertical rows of contacts, the trunks incoming from the district selector switches such as the one shown in Fig. 10. This figure also illustrates outgoing trunks leading to distant offices.

Figs. 19, 20 and 21 illustrate a selection controlling device or office marker which is common to a number of office selector switches and is similar in many respects to the district marker.

Fig. 22 shows an office marker sender connector whereby the office marker device may be connected to any one of the recording sender mechanisms.

Fig. 23 shows an interoffice trunk incoming to the first tandem office from the office selector in the originating office.

Fig. 24 illustrates a coordinate selector switch in the tandem office in which terminates the incoming trunk. This figure also shows outgoing trunks which lead to distant offices.

Fig. 25 shows a coordinate sender selector switch for attaching any one of a number of senders to the incoming trunks.

Figs. 26, 27, 28 and 29 illustrate one of these register senders in the tandem office.

Figs. 30, 31 and 32 illustrate the tandem marker which is similar in many respects to district and office markers and which is common to a number of the selector switches in the tandem office.

Fig. 33 shows a sender connector device for connecting the tandem marker to any of the register senders.

Fig. 34 illustrates a trunk circuit incoming to the second tandem office from a selector switch in the first tandem office.

Fig. 44 is a sender connector device for connecting the register senders to the tandem marker.

Fig. 45 illustrates a trunk in a final or terminating office incoming from either a first or second tandem point as the case may be.

Fig. 46 illustrates a coordinate incoming selector switch in which terminate the incoming trunks.

Fig. 47 shows a coordinate sender selector switch for attaching the register senders at the terminating office with the incoming trunks.

Figs. 48, 49 and 50 illustrate one of these register senders.

Fig. 51 and a portion of Fig. 52 illustrate one of the incoming marker mechanisms arranged in common to the incoming selector switches.

Fig. 52 also shows a connector device for associating the register senders with the incoming marker.

Fig. 53 illustrates a group selector switch located in the terminating office which receives the trunk from the incoming selector switches.

Fig. 54 shows a final or connector switch also of the character described, receiving trunks from the group selector switches and in which terminate the called subscribers' lines.

Fig. 55 together with Fig. 56 disclose a line marker mechanism which is common to a plurality of group selector and connector switches. Fig. 55 also illustrates a sender connector device for attaching the incoming senders with the line marker.

Figs. 57 and 58 shows the manner in which the various sheets of the drawing should be arranged to illustrate the different classes of connections.

Fig. 59 is a diagram illustrating the relation of the central offices and tandem points in the exchange area.

Fig. 60 is a diagram illustrating the switches and controlling equipment employed in the establishment of a call involving an originating office, a tandem point and a terminating office.

Fig. 61 shows structural details of a coordinate switch of the type employed in this system.

Figs. 62 and 63 are details of the switch structure.

General description of the system and its organization.

In districts embracing thickly populated areas such as the territory of the larger cities, in order to supply adequate telephone

communication to all parts of the area it must be provided with an exchange system comprising a large number of central offices properly distributed throughout the area. 5 To furnish a universal service on the basis that interoffice trunk groups are provided between each office and every other office in the district is highly objectionable. The cost of installing and maintaining so complex a trunk network in congested city districts is prohibitive. To obviate the expense incident to the installation of inter-office trunk groups for all offices in the system and at the same time to give every office, facilities for connecting with every other office the tandem switching principle is adopted, as a satisfactory solution of the problem.

According to the tandem plan, central 20 switching offices are located at convenient positions in the area and from these tandem points, groups of trunks radiate to the out-lying offices. Each tandem switching point serves a given portion of the entire district 25 and is interconnected by trunk groups with all of the central switching offices lying in that particular district. The various offices are in the nature of satellites in respect to the tandem switching point about which they 30 are distributed and to which they are connected by the different trunk groups. Of course it follows that where any two central offices are geographically located in proximity to each other or where the traffic between 35 them is heavy, or where for any other reason the same may be desirable, they may be interconnected by trunk groups extending directly from one office to the other independently of any other tandem switching office.

40 A central office may obtain connection with another central office both of which are served by the same tandem point provided they are not interconnected by direct trunks by routing the call from the originating office through the tandem point and thence to the called office. Where a calling office which is satellite to a particular tandem point wishes to obtain connection with a called office which is a satellite to a second 45 tandem point, the two tandem points being interconnected by direct trunks, the connection is established by routing the call from the originating office through the first tandem point, thence through the second tandem point and thence to the called office. In like manner, connections may be established from the calling office to a called office involving any number of intermediate tandem switching points dependent upon the relative location of the office and the trunking facilities therebetween.

With reference to Fig. 59, the diagram there shown is illustrative of the exchange area involving central offices and tandem office switching centers. Two tandem

switching points 5900 and 5901 are shown together with the various satellite offices. There may be as many of these tandem points as are necessary to serve the area involved. The offices 5902, 5903, 5904, etc. are 70 illustrated as satellites to the tandem point 5900 with provisions for extending calls into the tandem point. The offices 5905 and 5906 are also shown as satellites to the tandem point 5900 with provision for extending calls 75 from the tandem point to these offices.

Similarly, offices 5907 and 5908 are shown as calling offices and satellites of the second tandem point 5901, while offices 5909, 5910 and 5911 are shown as called offices, 80 satellite to the second tandem point. It will be understood, of course, that each of the central offices which are satellite to a given tandem switching center may be calling or called offices with respect thereto. That is to say, each office may extend calls into the tandem switching point or be called through the tandem switching point. It has not been considered necessary to illustrate this facility in the drawing.

Considering the particular portion of the exchange area served by a given tandem switching center and its satellite offices, as for instance, the tandem point 5900 and its associated central offices, there may arise within this fractional part of the entire exchange a number of distinctly different types of connections, each of which may be most efficiently handled when treated in a manner 95 different from the method of handling other types of connections. To be specific, the distance between a calling office and tandem point together with the distance between the tandem point and the called office varies with 100 different connections. If this total distance is less than a given value, the connection may be established and controlled in one manner, whereas if the distance exceeds the given value, it will be found advantageous to employ a different method in the establishment 105 and control of the connection. The central offices 5903 and 5905 are seen to lie at a relatively short distance from the tandem point 5900. The central offices 5902 and 5906, on the other hand, are situated at remote points from the tandem switching center 5900. In the event that a connection is desired from the office 5903 to the office 5905, it may be established by first extending the 110 call over a trunk leading from the office 5903 to the tandem point 5900. Following this, a portion of the entire designation record, representing the office code, is transmitted to the tandem point and influences 115 the equipment thereat to select a trunk leading to the called office 5905. Thereafter the remainder of the designation record which is first set up in the calling office 5903 is transferred over the established connection 120 directly through the tandem point 5900 to 125 130

the called office 5905, where it controls switching equipment to complete the connection to the called subscriber's line 5912. It will be noted that a portion of the designation record is transmitted directly from the calling office through the tandem point to the called office and this may be done in every case where the total distance is less than the given value.

- 10 Should the office 5903 desire connection with the called office 5906, the same method would be employed providing the length of the connection from the office 5903 to the tandem point 5900 and thence to the called office 5906 does not exceed the predetermined distance. On the other hand, however, if the office 5902 desires connection with the office 5906, the total distance being relatively great and in excess of a given value, a different plan of controlling the switch is used. The connection is first built up from the calling office 5902 to the tandem office 5900. Following this, the entire designation record including both the office code and the numerical part is sent from the calling office 5902 to the tandem point 5900 where it is recorded on controlling equipment. After this, the connection is further established from the tandem point over a trunk leading to the distant office 5906. Next the numerical portion of the designation is transferred from the equipment in the tandem office over the extended connection to the called office 5906 where it directs the completion of the connection to the called subscriber's line 5913. What has been said with respect to the tandem point 5900 and its satellite office also applies to the tandem office 5901 and to all of the other tandem offices in the area. In order to further illustrate the different types of connections involved in a system of this kind, it will be considered that the calling and called offices are satellites of different tandem points. In this case, the conditions may be such that the same general plan may be advantageously employed as regards the extension and control of the connections. If the calling office 5902 wishes connection with called office 5909 and the total trunking distance exceeds a given value as it usually would where two tandem offices are involved, the call is first extended from the calling office 5902 to the tandem point 5900 and the entire designation record is also transferred to the tandem point 5900. Following this, the call is extended by means of a trunk from the tandem point 5900 to the second tandem point 5901, whereupon the entire designation record is retransferred from the first tandem point to the second tandem point. Next the call is further extended from the second tandem point, over a trunk leading to the called office 5909 and the numerical part of the

designation is then shifted from the second tandem point to the called office 5909. Although, as a general rule, the tandem points are situated at a considerable distance from each other, it may so occur due to the various conditions encountered in the distribution of the offices and tandem senders, that one terminal point may be located relatively near to another terminal point. Another class of call that may possibly arise due to this situation is one where a calling office 5902 wishes connection with a called office 5910 satellite to a second tandem office where the trunking distance from the tandem office 5900 to the called office 5910 is sufficiently short to make it advantageous to transmit records directly from the first tandem point to the called office. In such case, a connection is first extended from the calling office 5902 to the tandem point 5900 and the entire designation record is then shifted from the calling office to the tandem point. Following this, the connection is further extended over a trunk leading to the second tandem office 5901 and the office portion only of the designation is then sent from the first tandem point to the second tandem point, thereupon a connection is further extended to the called office 5910 and next the numerical part of the record is transferred from the tandem point 5900 directly through the second tandem point 5901 to the called office 5910.

Still another type of connection that may arise is one where an office 5903 satellite to the first tandem point wishes connection to an office 5911, the total trunking distance between the offices being less than a given value. In this case the connection is first extended from the calling office 5903 to the tandem point 5900, whereupon the office portion of the record only is sent to the tandem point. Next the connection is extended to the second tandem office 5901 and again the office portion of the record is sent from the first tandem point to the second tandem point. Thereupon, the connection is extended from the second tandem office to the called office 5911. Following this the numerical part of the designation record is transmitted directly from the originating office 5903 through both tandem points to the terminating office 5911 for determining the completion of the connection to the called line 5914.

In smaller exchange systems where only a single tandem point is necessary in the establishment of a connection, two different types of calls which are incident thereto may be distinguished from each other by the joint effect of two factors. One of these factors is the length of the trunk interconnecting the calling office and the tandem point and by an individual test of the incoming trunks in the tandem point an iden-

tification may be had as to whether a particular trunk over which a connection has been extended is less than or is in excess of a given length. The other factor is the 5 length of the trunk extending from the tandem point to the called office and this may be ascertained as a class function from the office record which is always received at the tandem point. By means of these two factors 10 the tandem office controlling equipment is advised as to whether the connection involves the transmission of a part or all of the designation record from the first office to the tandem point and governs itself accordingly. 15

In the larger exchange systems, however, involving two or more tandem switching centers as above described, the controlling equipment at the tandem points may be arranged 20 to expect all of the designation record including the office and numerical portions in every case. Where it receives all of the record, it will transfer either all or a portion to the next tandem office according 25 to the class requirements and where it receives only the office portion it will transfer only this portion or none at all to the succeeding tandem point or office according to the class of the connection. These 30 features will be more fully understood in connection with the following detailed description.

The telephone exchange system herein disclosed employs an improved switching 35 medium in the form of a selective switch of the coordinate type. Primarily, the switch comprises a plurality of link circuits which are interposed between a number of incoming lines or trunks and a number of 40 outgoing lines or trunks in such a manner that a comparatively large number of connections may be established between incoming circuits and outgoing circuits in a speedy manner and with the use of comparatively little apparatus. As will be explained more fully hereinafter the connections through the switch are effected by 45 means of coordinate bars jointly operated under the control of operating magnets. Due to the arrangement of the controlling 50 circuits of the switch, whether employed as a non-numerical selector switch or a numerical selector switch, it is possible to obtain a plurality of coexisting connections 55 through any switch unit by the repeated use of the same switch bars, while the amount of apparatus necessary to maintain the established connections is only a fraction of a part of that used in building up the 60 connection.

Another important characteristic of the present system, and one which is in part made possible by the type of switch employed, is the selection controlling mechanism or marker which is arranged in com-

mon to a large number of switches and to a large number of register senders. Owing to the fact that the selective operation of the switch is practically instantaneous, the controlling equipment which is associated with the switch only during the interval that the connection is being established is held for a very short time in connection with any one call and is then immediately released to the common use of other switches. 75

With particular attention to Fig. 60, a description will now be given of the general organization of the system. The total number of subscribers' lines in an originating office, of which two lines 6000 and 6001 80 are illustrated, appear as calling lines in a number of line switches 6002 and 6003. The trunks outgoing from the several line switches have an appearance each in sender selector switches. Two trunks 6004 and 85 6005 are shown, one leading from each of the line switches 6002 and 6003 and these trunks appear in the sender selector switch 6006 which is also a switch of the coordinate type. It is obvious, of course, that as 90 many line switches may be provided as necessary and the same is true of the sender selectors. The circuits 6007 and 6008 outgoing from the sender selector switch lead to different senders or recording mechanisms, two of these senders 6009 and 6010 are diagrammatically illustrated.

Also the trunks outgoing from the line switches appear as incoming trunks in the coordinate district selector switches. There 100 will be a number of these district selectors in the originating office and each will accommodate a plurality of trunks. The trunks may be distributed among the district selectors in any suitable manner. In 105 the diagram two district switches 6011 and 6012 are shown and the trunks 6004 and 6005 appear, respectively, in these switches. The outgoing trunks of the district selectors are divided into numerical groups and lead 110 to succeeding switches. Since each of the trunks incoming to any one of the district selectors must have access to any of the outgoing groups of trunks, the outgoing trunks, 115 are multiplied to appear in all of the district switches. For example, trunk 6015 has an appearance in district selector 6011 and a similar numerical appearance in the district selector 6012 and would also have an appearance in the remaining 120 district switches. Likewise the outgoing trunk 6032 which belongs to another numerical group appears correspondingly in all of the district selector switches.

There is a selection controlling device or 125 marker 6013 assigned in common to all of the district selectors. This device is known as the district marker and may be temporarily associated with any one of the district switches over which a connection is 130

being extended. The marker 6013 is connectible by means of a sender connector 6014 with any one of the senders 6009, 6010, etc. The record of the wanted designation is received from the calling subscriber's dial and established on one of the recording senders. Thereafter the sender containing the record is associative with the district marker 6013 and the district marker 10 is at the same time associated with the particular district switch into which leads the trunk involved. The marker cooperates with the recording sender to determine the selection at the district switch.

15 The diagram in Fig. 60 shows the equipment used in setting up a connection involving an originating office, a tandem office and a terminating office. The originating office is illustrated at the left of the figure, 20 the tandem office within the broken rectangle and the terminating office is shown at the right of the figure.

The trunk groups outgoing from the district selectors may lead in various directions and serve for the different classes of calls required in actual practice. For handling local calls, that is, a call made to a subscriber's line in the same office, some of the trunks outgoing from the district selectors such as the trunk 6032 may lead directly to switches which are only used for completing local calls. In the present illustration, however, where the connection is one leading to a tandem point, office selector switches are employed in the originating office, two of which 6016 and 6037 are shown. The office selector switches are interconnected with the district switches by means of trunks such as the trunk 6015, 40 while the office switches have numerical groups of trunks outgoing therefrom to distant points. Some of these groups may lead to tandem offices, while others may lead to final completing mechanical offices. In 45 the diagram one trunk 6019 is shown which leads to the tandem office and appears in the tandem district selector 6033.

Like the district selectors the office selector switches are provided with a common office marker 6017 which is connectible to any one of the office selectors and is also connectible through the connector device 6018 to any one of the several recording senders 6009, 6010, etc. Considering the 55 tandem point, the equipment here is substantially similar to that above described. The trunks incoming to the tandem district switches 6033 also appear in sender selectors 6034 which have access to register senders 6035. A tandem district marker 6036 is 60 associative with any of the district switches and also with any of the senders. Outgoing from the district switches 6033 at the tandem office are groups of trunks which may

lead either to other tandem points or to final 65 completing offices. The particular trunk 6039 shown leads to the terminating office and appears in the incoming selector switch 6020 and also in the sender selector switch 6025. The incoming selector 6020 has 70 groups of trunks leading to group selector switches 6022 in the same office. One of these trunks 6021 is illustrated. Furthermore, the group selector switches 6022 have groups of trunks, one of which 6023 is 75 shown leading to the final or connector switches 6024. These connector switches, in turn have access to the called subscriber's lines in the terminating office.

The trunks incoming to the terminating office are connectible through the sender selectors 6025 to the incoming register senders 6026, 6027, etc. These senders are, in turn, associative with the incoming marker 6028 for controlling any of the incoming switches 6020 and also associative with the different line markers such as the line marker 6029 for controlling the group selector and connector switches.

Having given a general outline of the system a more specific description will now be made of the circuit arrangements together with an explanation of the structure and operation of the various parts of the apparatus. The line switches, sender selector switches, district and office selector switches, incoming switches, group selector switches and the connector switches shown in the drawing, the structure of which will be described in detail hereinafter are in their 90 general mechanical operation the same as the switch disclosed in the British Patent No. 183,438, issued to Western Electric Company, Limited, accepted September 6, 95 100 1923.

The subscribers' lines appear in the line switches as seen in Fig. 1, there being a plurality of lines assigned to each vertical row. For example, two lines 101 and 102 occupy the vertical row 110 in the line switch 100. The line 101 has contacts for connection with each of a plurality of horizontal link circuits; two of these links 106 and 107 are shown and there may be any suitable number of similar links to which the line 101 has access. The line 102 in the same vertical row of the group has access to the horizontal links 108, 109, etc. of a different horizontal group. In like manner other lines of the same vertical group 110 have access to other horizontal groups (not shown) in the drawing. There may also be any desired number of vertical rows of groups of lines, one other of which, group 111 is illustrated. The outgoing trunks two of which, trunks 114 and 115, are illustrated, occupy each a complete vertical row intersecting all horizontal links in the line switch. The trunk

114 occupies the vertical row 112 while the trunk 115 occupies the row 113.

The contact controlling bars assigned to the vertical rows 110, 111, 112 and 113 are 5 operated by the respective magnets 116, 117, 118 and 119, while the contact controlling bars of the horizontal links 106, 107, 108 and 109, are operated by their respective magnets 124, 125, etc.

10 For determining the selection of an idle outgoing trunk an allotter switch 143 is employed. The allotter 143 is an ordinary step-by-step switch which is automatically advanced from position to position to find 15 and allot an idle trunk for use.

The trunks outgoing from the line switches lead to the district selector switches and appear therein as incoming trunks, each occupying a full vertical row of terminals. 20 There may be any suitable number of these trunks depending upon the number and capacity of the line switches and they may be distributed in any convenient manner among a plurality of district selectors. The 25 two trunks 114 and 115, shown, extend from the line switch and appear as incoming trunks in the district selector switch 1000. The trunk 114 is shown in detail with its controlling equipment in Fig. 2, while the 30 trunk 115 has its controlling equipment in Fig. 2, illustrated schematically by the broken rectangle 200. It will be understood that other trunks leading from the line switch 100 may appear in the district switch 35 1000 or in any suitable number of similar district selector switches and also that similar trunks coming from other line switches may be likewise distributed.

The trunks extending between the line 40 switches and district selectors also have appearances in the sender selector switch 300. These trunks appear in the sender selector switch in substantially the same fashion as the subscribers' lines appear in the line 45 switches. A plurality of trunks occupy each vertical row, each trunk being accessible to a group of horizontal link circuits. For instance, the trunks 114 and 115 appear in the vertical row 301 of the sender selector, the 50 trunk 114 having access to the group of links 307 and 308 and the trunk 115 having access to the group containing the links 305 and 306. In like manner other trunks occupy other incoming vertical rows. The outgoing 55 circuits from the sender selector switch lead to separate recording sender mechanisms and each such circuit occupies a full vertical row of contacts. The circuit 332 occupies the vertical row 304, while the circuit 333 relating to another sender occupies 60 the vertical row 303. There will be as many of these circuits and as many sender selector switches as the system may require. A step-by-step allotter switch 326 is associated with 65 the sender selector switch 300 and serves to

keep an idle sender continually allotted for use.

The purpose of the recording sender mechanisms, such as the one shown in Figs. 4 to 9 inclusive, is to receive and record the designation of a wanted line. To this end the sender is associated with the calling line through the sender selector switch and responds to a series of impulses transmitted by the calling subscriber and sets up the 75 record thus received on a series of registers. The receiving portion of the sender is shown in Fig. 4 and consists of a series of counting relays 413, 414, 415, etc. which respond to impulses transmitted over the calling subscriber's line. 80

The first three registers 700, 701 and 702 consist each of a plurality of relays and are set by the counting relays in Fig. 4 in response to the first three series of impulses to establish a record of the office designation. The next four registers 800, 801, 900 and 901 are set similarly by the counting relays to establish the thousands, hundreds, tens and units designations. These registers likewise consist of a plurality of relays. The last register 906 is also positioned by the counting relays in the event it is necessary to transmit an extra series of impulses for controlling stations selection in case of party 95 lines.

The circuit shown in Fig. 5 consists for the most part of relays and its function is to cooperate with other parts of the system for determining the various kinds of information necessary for the sender to have, such, for example, as class indications, and to govern the sequential operations of the sender accordingly.

The circuit arrangement illustrated in 105 Fig. 6 is for controlling the operation of the sender under given conditions and serves particularly for transmitting codes of impulses for transferring designations to distant offices in case of interoffice calls. 110

The district selector switches as above observed receive trunks incoming from the line switches and it is their function to connect these trunks in a group selecting action to outgoing trunks. The arrangement of the 115 outgoing trunks on the district selector switches, the grouping of these trunks and the number of the trunks per group depend upon the character of the system and the kind of service to be rendered. These selector switches must have access to various types of outgoing trunks such as those leading to succeeding switches for making local connections, trunks leading to office switches which in turn have access to interoffice 125 trunks and also to trunks leading to the different supervisory and special operators' positions. In order to secure a better understanding of the appearance of the groups of trunks in the district switches, a brief 130

explanation will be given of the numerical grouping of the subscribers' lines as regards the establishment of local connections.

Assuming for the purpose of illustration 5 only that the local exchange has a capacity of 10,000 subscribers' lines, these lines may be divided into five terminal groups of 2000 lines. Each terminal group of 2000 lines is served by a number of group selector 10 switches and connector switches such as those shown in the terminating office in Fig. 60. The district selector switches have access to trunk groups which lead directly to the switches of the terminal line groups. 15 Hence, the several district selector switches, such as switch 1000, are provided each with five groups of trunks leading to the five different terminal line groups.

Furthermore, for the sake of illustration, 20 it may be considered that the district selector switches are equipped with 70 horizontal link circuits for interconnecting the incoming trunks to the outgoing trunks which are divided into two groups of 35 each. In the 25 district selector switch 1,000, three horizontal links 1003, 1004 and 1005 in the lower group 1001, and two horizontal links 1006 and 1007 in the upper group 1002 are illustrated. All incoming trunks such as the 30 trunks 114 and 115 have access to all the horizontal links in both groups.

With this arrangement each of the several 35 vertical rows 1011, 1012, 1013, 1014, etc., may serve a maximum of 70 outgoing trunks, 40 35 in the lower group and 35 in the upper group. Depending upon the character of a particular trunk group outgoing from the district selector, it may occupy all or a portion of either one of the lower or upper 45 groups in a vertical row, or it may occupy both groups. If a small trunk group is sufficient, either the lower or the upper portion of a given vertical row is sufficient, whereas for larger trunk groups a full vertical row 50 may be utilized. While the assumption was made that the district selector switch is provided with 70 horizontal links divided into two groups of 35 each, it is obvious that any required total may be employed and the 55 division may be such as to give two or three or any required number of groups.

Consider as an example that each of the 60 five terminal line groups requires a group of 35 trunks outgoing from the district selector switch banks. The group of trunks leading to the first line terminal group of 2000 lines may occupy the lower half of the vertical row 1014 of the district selector switch 1000. The groups of trunks leading 65 to the second and third terminal groups may occupy respectively the upper and lower halves of the vertical row 1013. The groups of trunks leading to the fourth terminal group of subscribers' lines may occupy the 70 lower half of the vertical row of terminal

1012. The group of trunks leading to the fifth terminal line group may occupy the upper half of the vertical row 1012.

The vertical row 1011 of the district selector may accommodate a group which leads 70 to the office selector switches which in turn have access to trunks outgoing to distant offices. One of these trunks 1028 is shown in detail and leads to the office selector switch 75 illustrated in Fig. 18.

Since there are a number of district selector switches similar to the switch 1000 all having access to the same groups of trunks, it is necessary that each of the several trunks have a corresponding appearance in 80 each of the several switches. The manner in which these trunks are multipled is shown in the schematic drawing of Fig. 60.

The district marker shown in Figs. 11, 12 and 13, which is provided for the common 85 use of a plurality of district selector switches, is a device made up almost entirely of relays. The function of the district marker is to take a portion of the record initially recorded on the sender mechanism 90 and to use the record thus received to determine selection at the district switch and to determine the class of the call being extended. Inasmuch as a plurality of the recording senders are available to calling subscribers for recording the designation, it is necessary to make provision for connecting any one of these senders to the district marker allotted to the district switches that serve those calling subscribers' lines. To 100 this end the district marker sender connector 1400 is provided. The sender connector 1400 comprises a plurality of multi-contact relays 1401, 1402, 1403 and 1404. Each of these relays represents a recording sender 105 and serves when actuated to connect such sender to the common district marker.

The district marker consists of, among other elements, the three relay registers 1201, 1202 and 1203. These three registers receive the three portions of the office code designation from the corresponding registers 700, 701 and 702 of the recording sender. The district marker also consists of a translator mechanism 1200 and 1220 which is 110 made up of a number of multi-contact relays 1205 to 1219, inclusive. The translator is operated in accordance with the records on the registers 1201, 1202 and 1203 to determine the class of the call involved and to 120 place the necessary conditions upon the class conductors 1236 for governing the operation of the recording sender and for properly preparing the talking circuit for conversation. 125

The portion 1220 of the translator consists of multi-contact relays 1205 to 1212, inclusive, having contacts for cooperating with a bank of horizontal conductors. This bank of horizontal conductors is divided into 130

two sections 1223 and 1222. The contacts of the relays 1205, 1206, 1207, etc., which cooperate with the horizontal conductors are arbitrarily wired to the class conductors 1236 5 in such a fashion as to give the desired number of class combinations.

The portion 1200 of the translator is made up of multi-contact relays 1213 to 1219 which operate under the control of registers 10 1202 and 1203 to select the relays 1205, 1206, 1207, etc. The register 1201 selects the relays 1208 to 1212, inclusive, whereby a potential is placed upon the corresponding horizontal conductors in the section 1223. 15 Thus, through the cooperation of registers 1201, 1202 and 1203 and the sections 1221 and 1223 of the translator, electrical potential may be placed upon a large number of combinations of class conductors 1236. 20 While only the five multi-contact relays 1208 to 1212, inclusive, controlled by the register 1201, are shown, there would in practice be more of such relays. Furthermore, only three relays 1205, 1206 and 1207 have been 25 shown cooperating with the horizontal conductors of the section 1200, but as many other similar relays may be provided as are necessary.

Another function of the translator is to 30 cooperate with the relay register 1204, which receives the thousands record from the thousands register 800 in the recording sender, to determine group selection at the district selector switch in the event of local calls. 35 For this purpose the contacts cooperating with the upper section 1222 of the translator bank are wired in a suitable fashion to the contacts of the thousands register relays 1204. Where interoffice trunks are to be selected, the translator directly determines the 40 selective operation of the switch.

In addition to the elements above described the district marker includes two sets of testing relays 1300 and 1303. The 45 set of testing relays 1303 is common to all district selector switches and also common to all vertical groups of outgoing trunks on any switch. A set of testing relays comprising three relays 1327, 1328 and 1329 is 50 used for testing the first horizontal link and the corresponding outgoing trunk in any vertical group 1011, 1012, etc. of the lowermost group 1001. It also includes relays 1330, 1331 and 1332 for testing the 55 second horizontal link in the group 1001 and also the corresponding outgoing trunk such as the trunk 1028 in any vertical row of any district selector switch. The third group of three relays 1333, 1334 and 1335 similarly 60 serve to test the horizontal link such as the link 1005 and the corresponding outgoing trunk in any vertical row. In a like fashion the set of test relays 1303 has a number of other testing relays for the remaining horizontal links in the lower group 1001 and for 65

the corresponding outgoing trunks in all vertical rows.

The upper set of testing relays 1336, 1337, 70 1338, etc., are for testing the horizontal link circuits 1006, 1007, etc., of the upper group 1002 and the corresponding outgoing trunks in all vertical rows on any district selector switch.

Since the testing relays 1300 and 1303 are 75 common to all district selector switches and common to all outgoing trunk groups, it is necessary to provide some means for associating either one or the other, or both of these sets with the proper district selector switch and with the proper outgoing trunk 80 group. For this purpose the multi-contact relays 1326, 1320, 1323, 1325, 1319 and 1322 are provided. For example, the relays 1323, 1320 and 1326 are individual to the particular district selector switch 1000 shown and 85 when operated they associate the testing relay sets 1300 and 1303 with the horizontal link circuits of that particular district selector.

In order that the testing relay sets 1300 90 and 1303 may also be associated with the proper group of outgoing trunks at the district selector switch, the relays 1312 to 1317, 95 inclusive are provided. Each of these multi-contact relays is individual to a particular group of trunks outgoing from the district selector switch. When any one of these multi-contact relays is operated, it associates the testing relays with the sleeve conductors of the trunks of the group to which it is 100 individual for the purpose of testing and selecting any one thereof.

For handling interoffice connections groups of trunks at the district selector switches 1000 are provided leading to a suitable number of office selectors 1800. It will be assumed that the group of trunks, of which one trunk 1028 is illustrated extending to the office selectors, occupies a full vertical row 1011 on the district switch 1000. The trunk 1028 appears in the office selector 1800 in the vertical row 1808 and is accessible to all horizontal links in both the lower and upper groups 1801 and 1802. Other trunks, similar to the trunk 1028, will 115 appear in other vertical rows of this particular office switch and also in vertical rows of other office selectors, not shown in the drawing.

The office marker shown in Figs. 19, 20 and 21 is similar, in many respects, to the district marker and is arranged in common to all of the office selector switches. A sender connector device 2200, comprising a number of multi-contact relays, operates to connect the office marker to any one of the several recording sender mechanisms.

The office marker comprises three relay registers 2002, 2003 and 2004 which receive the three portions of the office code designa- 130

tion from the registers 700, 701 and 702 of the recording sender. These relay registers cooperating with translator devices 2000 and 2001 determine the selection of 5 the proper group of trunks outgoing from the office switch to the distant office. Moreover, the office marker comprises the common testing relay sets 2105 and 2106 which are associable through multi-contact relay 10 devices 2102 and 2103 with the horizontal link circuits of the particular office switch taken into use. Furthermore, the multi-contact relay devices 2100 and 2101 serve to associate the common testing relay sets 2105 15 and 2106 with the several groups of outgoing trunks to the office selectors.

The grouping and distribution of the trunks outgoing from the office switches 1800 may be taken to suit the particular 20 traffic conditions concerned. These trunks may extend to terminating offices for making direct calls. Other of the trunks lead to the tandem switching center as shown in Fig. 59. Trunks extending to the tandem 25 point are assigned to the vertical row 1811 in the switch 1800 and one such trunk 1823 is shown.

Thus, the equipment shown in Figs. 1 to 22, inclusive, represents an originating 30 central office such as the office 5902 in Fig. 59. Reference will next be made to Figs. 23 to 33, inclusive, which disclose the apparatus located at a tandem point such as the tandem point 5900 to which the calling office 35 is a satellite. Thereafter, reference will be made to Figs. 34 to 44, inclusive, which illustrate the second tandem office in the exchange area such as the tandem point 5901. Lastly, reference may be made to Figs. 45 40 to 56, inclusive, which disclose the apparatus in a central office serving in the capacity of a terminating office such, for instance, as the office 5910 which is satellite to the second tandem point 5901.

45 At the first tandem point 5900 there are located a number of tandem district selector switches, one of which switch 2400 is shown. The incoming trunks from the various satellite offices and also where other tandem 50 points appear in vertical rows in the tandem district switch 2400, the trunk 1823 outgoing from the originating offices, disclosed in full, terminates in the tandem district switch 2400 in the vertical row of contacts 2403.

The purpose of the tandem senders, one of which is shown in Figs. 26 to 29, inclusive, is to receive either the entire designation record or a part thereof according 60 to the class of the call being extended. These senders are associable with the incoming trunks through the medium of coordinate sender selector switches 2500. The sender comprises three office registers 2700, 2701

and 2702, four numerical registers 2800, 65 2801, 2802 and 2900 and a station register 2901. The equipment shown in Fig. 26 is for controlling the operations of the sender both in the receiving and transmitting of 70 code impulses representing the designation. The tandem selector switches 2400 are similar in construction and arrangement to the district selectors employed in the originating offices.

The tandem district marker shown in 75 Figs. 30, 31 and 32 is common to all of the district selectors. Similar to the district marker above mentioned the tandem marker comprises three registers 3101, 3102 and 3103 and a translator mechanism 3100 and 3120. 80 The registers 3101, 3102 and 3103 receive the three portions of the office code designation from the corresponding registers of the sender and determine in conjunction with the translator mechanism the selective operation of the tandem district switch. The translator mechanism also serves to prepare 85 the proper class indication for governing the tandem sender. Similar to the translator of the district marker in the originating office, the translator at the tandem point is made up of one portion 3100 comprising multi-contact relays 3113, 3114, 3118, 3119; etc., and the portion 3120 is made up of 90 multi-contact relays 3105, 3106, 3107, 3108 95 3109, etc.

In addition to these elements, the tandem district marker has two sets of testing relays 3200 and 3203 similar to the corresponding testing relays in the marker at the originating office. The set of relays 3203 which is only partially shown is common to all tandem district selector switches and to the vertical groups of outgoing trunks on any switch. The second set of relays 3204, 100 3205, and 3206 in the group 3200, for instance, serve to test the second horizontal link 2410 in the section 2402 of the district switch and also the corresponding outgoing 105 trunk 2428. Similarly, the set of testing relays 3203 serve to test the corresponding horizontal links in the group 2401 of the tandem district selectors and the corresponding outgoing trunks in each of the vertical 110 rows.

115 Since the testing relays 3200 and 3203 are common to all tandem district switches, the multi-contact relays are provided for associating these testing relays with the proper tandem district switch and also with the proper group of trunks thereon. For instance, the relays 3207, 3208 and 3209 are individual to the tandem district switch 2400 and serve to connect the marker therewith. Likewise, relays 3240 and 3241, etc., are each individual to a particular group of trunks on any switch and operate to connect the common testing relays with the trunk of 120 125

these groups. The tandem marker is associative with any of the recording tandem senders by means of a multi-contact relay connector 3300 made up of individual relays 5 3301, 3302, etc., each individual to a different sender.

Considering the second terminating office illustrated in Figs. 34 to 44, inclusive, this 10 may be substantially the same as any of the other terminating offices in the area and while it is shown as a second tandem office in this particular disclosure, it, of course, may also serve as a first tandem office or at 15 any other relative position in an extended connection. The apparatus and switches employed are substantially the same as those illustrated in the first tandem office.

There are a number of tandem district selector switches, one of which, the switch 20 3500, is illustrated for receiving the incoming trunks and for selecting groups of outgoing trunks. The incoming trunk 2428 from the first tandem point is seen to occupy the vertical row of contacts 3503 in the tandem district switch 3500. There are also 25 provided a number of senders similar to the one shown in Figs. 37 to 40, inclusive, which are associative by means of sender selector switches 3600 with the incoming trunks. 30 Moreover, a tandem district marker shown in Figs. 41 to 43, inclusive, is common to the tandem district switches and associative by means of the multi-contact relay sender connector 4400 with any of the recording 35 senders. This marker similarly consists of registers 4201, 4202 and 4203 and a translator mechanism 4200 and 4220. Furthermore, it comprises two sets of testing relays 4300 and 4303 associative with any of 40 the district switches through individual multi-contact relays and with any of the groups of outgoing trunks for testing purposes.

At the final or terminating office disclosed 45 in Figs. 45 to 56, inclusive, there are provided a plurality of incoming selector switches 4600. Trunks incoming from central switching offices and from tandem points 50 may appear in these switches. The particular trunk 3508 incoming from the second tandem office is seen to appear in the vertical row of contacts 4601 of the incoming selector 4600, the incoming trunks also appearing 55 in sender selector switches 4700 in the manner already described, the particular trunk 2428 shown appearing in the row of contacts 4708 of the switch 4700 and being accessible to the links 4701 and 4702. The sender selectors have access to a number of 60 incoming register senders at the final office, one of which is shown in Figs. 48, 49 and 50.

The register sender comprises a number of registers for receiving the different digits of the designation. In the present disclo-

sure there are four registers 4900, 4901, 5000 65 and 5001 for recording the thousands, hundreds, tens and units digit. Associated with the incoming switches and in common thereto is an incoming marker illustrated in Figs. 51 and 52, similar in function to the 70 other markers heretofore described for controlling selection at the incoming switches. The incoming marker is associative with any 75 of the incoming senders through the connecting device 5200.

The incoming switches 4600 have groups of trunks outgoing from there and terminating in group selector switches such as the switch 5300. One of these trunks 4606 is 80 illustrated and is seen to terminate in the vertical row 5323 at the group selector switches 5300. Other trunks may appear in the group selector switch 5300 and also in other group selector switches (not shown).

Assuming for the purpose of illustration 85 only that the terminating office has a class capacity of ten thousand subscribers' lines, these lines may be divided into five terminal groups of two thousand lines each. 90 Each terminal group of two thousand lines is served by a number of group selector switches and connector switches such as those shown in Figs. 53 and 54. The incoming selector switches 4600 have access to 95 trunks as explained which lead directly to the group selectors in all of the five terminal line groups. A terminal line group of two thousand lines is served by a number of group selector switches and a number of connector switches. For the particular terminal group illustrated, one group selector 100 5300 and one connector 5400 are shown in the drawing. It may be assumed for explanation that each of the connector switches 5400 has a capacity for two hundred and 105 fifty called subscribers' lines. These two hundred and fifty lines may be divided into twenty-five groups of ten lines, each group occupying a vertical row in the connector switch. The group to which the lines 5416 110 and 5426 belong occupies the vertical row 5427. Other lines would likewise occupy the same and other rows in the switch.

Assume also that the connector switch 115 5400 has a vertical capacity for seventy horizontal links. With seventy links in the structure and ten lines per vertical group, each line may be accessible to seven different links. Of these seven links, six are used for the establishment of talking connections, while the remaining link is employed for testing purposes. Referring to the figure two of the ten groups of horizontal links are illustrated, only a portion of each group being shown. The line 5416, 120 for instance, is served by the group of horizontal links containing the links 5401, 5402 and the testing link 5403. The line 5426 is 125

served by another group containing the links 5404, 5405 and the common test link 5406. Each of these several horizontal groups serve each of the vertical groups of lines in the 5 switch.

Since each connector switch 5400 accommodates two hundred and fifty lines, there will be a total of eight of these switches for the two thousand lines. Connections are 10 extended from the group selector switch 5300 to any one of the eight different connector switches over incoming trunk circuits. One of these trunks 5322 is illustrated in the drawing. There will be a 15 suitable number of group selector switches 5300 for serving the terminal line group and the trunks incoming from the incoming selectors are distributed among the several group selectors. Where several group 20 selector switches similar to the switch 5300 all have access to all of the eight connector switches in the terminal line group, it is necessary to multiple the incoming trunk groups to appear in each of these group 25 selectors. Considering the trunk group of which the trunk 5322 is one, this group would have a similar appearance in each of the total number of group selectors. In other words, the trunk 5322 would be mul- 30 tipled to appear in the corresponding row of all other group selectors and would be accessible to the link in all of the group 35 selectors which corresponds to the link 5305 in the switch 5300. The same is true of other trunks in the group. Each of the 40 five terminal line groups of two thousand lines is further provided with a line marker. The marker shown in Figs. 55 and 56 be- 45 longs to the terminal line group represented in the drawing and may be associated with any of the group selector and connector switches of that group for governing their selective operations. The line marker is provided with a sender connector 5501 con- 50 sisting of a plurality of multi-contact relays 5508, 5509, etc., each individual to a dif- 55 ferent one of the incoming senders and serv- 60 ing to associate such senders with the line marker. The line marker includes the relay 65 register 5600, 5601 and 5602 which re- 70 ceive the hundreds, tens and units digits from the incoming sender and also the 75 translator device 5603 and 5604 consisting of the two banks of horizontal conductors and the several multi-contact relays. The 80 purpose of the section 5604 of the translator is to cooperate with the register 5602 to 85 select the group of ten subscribers' lines on the connector switches which contain the called line. The section 5603 of the translator in conjunction with the register 5601 serve to 90 control the operation of the multi-contact relay connecting device 5410 to associate the common test relays 5622, 5624 of the marker 95 with the group of horizontal links in the con-

nector switch having access to subscribers' lines of the desired units designation.

The line marker further consists of a set of testing relays illustrated in Fig. 55 which are associative through a connecting device 70 5302 with any group selector switch and are also associative through a connecting device 5301 with any group of trunks outgoing from the selector switch to connector switches for the purpose of testing the condition of the horizontal links and the outgoing trunks at the group selector switch. 75

Detailed description of the switch structure.

Before proceeding with a detailed description of the circuit operation, an explanation will be made of the mechanical construction of the switching device employed in this system. For this purpose reference is made to Figs. 61, 62 and 63 which 80 are perspective and detailed views of a portion of the switching mechanism clearly illustrating the manner in which it operates. 85

Considering the terminal portion of the switch, there are provided a plurality of intermediate or horizontal link circuits 6100, 6101, consisting each of a number of plain bare wire conductors. The horizontal link 6100 includes, as shown, four conductors 6102, 6103, 6104 and 6105, and the horizontal 90 link 6101 likewise has four conductors 6106, 6107, 6108 and 6109. As many of these horizontal links may be provided as is necessary and each may have more or less than the number of conductors actually shown. 95 These horizontal bare wire link circuits constitute the passive or stationary part, of the 100 terminal arrangement.

Regarding the switch in the capacity of a selector, as shown in Figs. 10, 18, 24, 35, 46, 105 53 and 54, the incoming trunks or circuits each constitute a full vertical row of movable terminals and have access to all the horizontal link circuits. Fig. 61 shows one 110 of these incoming trunks which is made up of four conductors 6110, 6111, 6112 and 6113. This trunk has a set of movable bare wire 115 terminal conductors 6114, 6115, 6116 and 6117 connected to the respective conductors and which extend through a window 6179 occurring in the vertical channel guide member 6163. After passing through the window 6179 the movable terminal conductors pass through respective diagonal slots 6168, 6169, 6170 and 6171 in a slidable 120 insulating card 6166. The card 6166 is retained in the guide member 6163 and adapted to slide freely up and down therein. For supporting the card 6163 in its normal position, a spring wire 6167, firmly attached to the insulating block 6198 in the rear, extends through the window 6179 and through the lower end of the card 6166. The movable terminals 6114, 6115, 6116 and 6117 are 125 also secured to the insulating block 6198, 130

and with the spring support wire 6167 in its normal position these terminal wires are out of engagement with the respective wires 6102, 6103, 6104 and 6105 of the horizontal link 6100 with which they coat.

The conductors 6110, 6111, 6112 and 6113 of the incoming trunk are provided with a second set of movable wire terminals 6118, 6119, 6120 and 6121, attached to the block 6198, and which extend through a window in the guide 6163 and thence through diagonal slots in the insulating card 6172 to a point where they cooperate with the respective wires 6106, 6107, 6108 and 6109 of the next horizontal link 6101. The insulating card 6172 is supported by the flexible spring wire 6173. In like fashion, the incoming trunk conductors have a set of these movable terminals in the vertical row for every horizontal link circuit. Obviously, there will be one of these vertical rows of contacts for each trunk incoming to the switch.

In addition to the several vertical rows of incoming circuits, each representing a single incoming trunk, there are provided a plurality of vertical rows of outgoing trunks to be fully described hereinafter. In Fig. 61, two such vertical rows of outgoing trunks are illustrated, two separate trunks in each row being shown. One of these trunks appears in the switch in the single set of movable wire terminals 6122, 6123, 6124 and 6125, secured to the insulating block 6199, and which extend through the window 6180 in the terminal guide 6164 and through diagonal slots in the sliding card 6174 to cooperate with the respective conductors of the link 6100. The other outgoing trunk in the same vertical row is represented by the movable conductors 6126, 6127, 6128 and 6129, which are also secured to the block 6199, and extend through the window 6182 and through diagonal slots in the card 6176 and cooperate with the conductors of the horizontal link 6101. One of the trunks in the second vertical row of outgoing trunks appears in the switch in the movable wire terminals 6130, 6131, 6132 and 6133, secured to the block 6301, and which extend through the window 6180 of the channel guide 6165, and thence through the slots and sliding card 6177 in cooperative relation with the conductors of the link 6100. The second outgoing trunk illustrated in this vertical row appears in conductors 6134, 6135, 6136, and 6137, extending through diagonal apertures of the card 6178 to cooperate with the conductors of the link 6101. Similarly, each vertical row of outgoing trunks has as many trunks therein as required and each trunk is provided with terminals coacting with one of the horizontal link circuits.

For operating and maintaining the terminals to establish connection through incoming trunks, links and outgoing trunks, there

are provided a plurality of operating members or bars, a bar being arranged to serve each of the several vertical and horizontal rows of trunks. The vertical bar 6140 is individual to the row represented by the incoming trunk 6110, 6111, 6112 and 6113 and controls all of the movable contacts pertaining to this trunk. The next vertical bar 6141 is individual to the row of contacts belonging to the group of outgoing trunks appearing in the terminals 6122, 6123, 6124 and 6125 and 6126, 6127, 6128 and 6129. Likewise, the vertical bar 6142 is individual to the vertical row in which appear the outgoing trunks represented by the movable terminals 6130, 6131, 6132 and 6133, and 6134, 6135, 6136 and 6137. The function of these vertical bars is to prepare the contacts for operation, and after the contacts have been operated said bars may be restored ready to be taken again for preparing another set of contacts.

The horizontal operating members or bars, two of which, bars 6138 and 6139, are shown, are each individual to a corresponding one of the horizontal links 6100 and 6101. The function of these bars is to operate the sets of prepared contacts and maintain these contacts in operated condition after the vertical bars have restored to normal.

The switching device has been outlined in its capacity as a selector. When desired to employ this switch as a line or trunk connector, as illustrated in Fig. 1, it is obvious that the incoming lines appear in the vertical rows containing the terminals 6122, 6123, 6124 and 6125 and 6126, 6127, 6128 and 6129 and 6130, 6131, 6132 and 6133, etc. The outgoing trunks would then appear as trunks, such as 6110, 6111, 6112 and 6113, each comprising a full vertical row of trunks. Dependent upon the number of horizontal links required for serving each incoming subscriber's line, said line may be provided with a variable number of movable wire terminals for cooperating with the respective corresponding links.

In the perspective view of Fig. 61, the horizontal link conductors are shown as straight bare wires in order to give clearness to the illustration. In practice, however, these horizontal conductors are woven in and out among a series of vertical insulating strips to form a grid construction for the stationary portion of the terminal bank. This construction is illustrated in the details of Figs. 62 and 63. A series of vertical insulating strips 6302, 6303, 6304 and 6305 are spaced at proper distances. The horizontal link conductors are woven in and out among these vertical strips and secured in any suitable manner to form a rigid structure which may be assembled and held in place in any convenient manner. Due to

the sinuating disposition of the wire conductors in this grid construction, the distance of each conductor from the insulating blocks 6198, 6199 and 6101 varies at different points along said conductor. This construction serves to very good advantage, as will be explained hereinafter for the purpose of maintaining clean electrical contacts for the engaging wires.

Assume that it is desired to connect incoming trunk or circuit 6110, 6111, 6112, and 6113 to the outgoing trunk which appears in the conductors 6134, 6135, 6136 and 6137. First, a circuit is closed for the vertical operating magnet 6145. The magnet 6145 attracts its armature 6152 which rotates the lever 6154, which in turn, bearing against the lever 6156, rotates the vertical rod 6140 against the action of the retractile spring 6160. In the drawing the vertical bar 6140 is shown in its normal or released position but its operating position may be understood by observing the vertical rod 6141, which is shown fully rotated by its vertical operating magnet 6146. The bar 6140, in rotating to its said position, brings the cam elements 6188 and 6185 around to a position where their camming surfaces are immediately above the ends of the respective levers 6186 and 6183. These levers are secured to the horizontal bars 6139 and 6138. The relative position of a cam to its cooperating lever is illustrated in connection with the positioned vertical bar 6141. Here the cam 6191 is shown as rotated to a point where it presents its camming surface to the lever 6189, which is attached to the horizontal bar 6138. In a similar manner all other cams on the vertical bar 6140, each individual to a horizontal link are similarly positioned with respect to levers on corresponding horizontal link bars.

At the same time, subsequently, or in any desired sequence, a circuit may be closed for the vertical operating magnet 6147. The magnet 6147, through its armature 6153, levers 6155 and 6159, rotates the vertical bar 6142 against the helical spring 6162. The bar 6142 is also shown in its normal position but when fully rotated it brings the cams 6307 and 6308 into cooperative relation with the corresponding levers 6197 and 6195 on the respective horizontal bars 6139 and 6138.

Thus, when the contacts of the incoming trunk and the contacts of the outgoing trunks are prepared, it is only necessary to operate the horizontal bar 6139, pertaining to the outgoing trunk, to bring about the connection. This is done by energizing the magnet 6144, which rotates the horizontal bar 6139 by attracting its armature 6149. The bar 6139 is shown in the drawing as being in its operated condition. As the bar 6139 rotates, the levers 6186, 6192 and 6197, attached thereto, are swung upwardly. The lever 6186, on its first upward movement encounters the inclined surface of the cam 6188 and being guided thereby is flexed to the right. Normally, the lever 6186, on rotating upwardly, would not encounter the flexible supporting spring 6173, but when flexed to the right by the cam 6188 the V shaped portion 6187 of the lever 6186 engages the flexible spring 6173. Due to this engagement the continued upward movement of the lever forces the spring 6173, upwardly, which, in turn, slides the card 6172 up in the channel member 6163. Upon the initial upward movement of the card 6172, conductors 6118, 6119, 6120 and 6121, which have a slight tension, normally overcome by the stronger spring 6173, engage the corresponding horizontal conductors 6106, 6107, 6108 and 6109. Thus the movable conductors engage the stationary horizontal conductors at the beginning of the upward movement of the card 6172. As the card 6172 continues to move upwardly, the diagonal slots have a camming effect on the flexible conductors whereby these conductors are moved laterally with a wiping action over the surface of the respective horizontal conductors with which they are in engagement.

Considering Fig. 63, for example, the advantage of the sinuating horizontal conductors will be readily seen. When the insulating card 6166, for example, is started in its upward movement the flexible conductor 6114 encounters the cooperating horizontal conductor 6102. As the card 6166 continues upwardly, the diagonal slot 6168 moves the conductor 6114 laterally to the right, causing it to slide or drag over the surface of the curved wire 6102. The result is that the surface of the wire 6102 is cleaned or polished for a distance equal to the stroke of the moving conductor 6114. Moreover, the moving conductor 6114 has its surface polished and cleaned over a considerable length due to the curved formation of the conductor 6102.

In a similar manner the lever 6197 encounters the cam 6307 and flexes to the right so that the V portion 6309 engages the spring 6310. The spring 6310, acting on the card 6178, causes the flexible conductors 6134, 6135, 6136 and 6137 to engage the corresponding conductors 6106, 6107, 6108 and 6109 with a wiping action. At the time the horizontal rod 6139 is actuated all other vertical bars including the bar 6141 are supposed to be in their normal condition, hence the lever 6192 on moving upwardly, fails to encounter the cam 6194 and the V shaped portion 6193 passes by without interfering with the supporting spring 6311. Likewise, all other levers on the rotating horizontal rod 6139 fail to engage the corresponding card supporting springs.

Following this, the vertical magnets 6145 and 6147 may be released permitting the bars 6140 and 6142 to return to normal position. The continued energization of the horizontal magnet 6139 holds the slidable cards 6172 and 6178 in their upward positions, and thereby maintains an electrical connection between the incoming trunk 6110, 6111, 6112, and 6113 and the horizontal link 6101, and 10 also maintains a connection between the horizontal link 6101 and the outgoing trunk appearing in conductors 6134, 6135, 6136 and 6137.

Should another connection be desired over 15 a trunk in the same vertical row, as, for example, the trunk appearing in the wire terminals 6130, 6131, 6132 and 6133, this can be obtained by operating the second horizontal bar 6138 after having reoperated the 20 vertical bar 6142 and after having operated another vertical bar representing another incoming trunk. The reoperation of the vertical bar 6142, controlling the same vertical row of outgoing trunks, brings the 25 cams 6307 and 6308 back into their operating positions. Cam 6307, in returning to its operating position, however, passes freely under the operated lever 6197, and, therefore, does not touch any of the parts involved 30 in the establishment of the first connection, whereby no disturbance is created in the talking circuit. The cam 6308 also moves to its operated position and when the horizontal bar 6138 is subsequently rotated 35 the lever 6195 is flexed so that the V shaped element 6196 engages the spring support 6312 and a second connection is effected between the incoming trunk, the horizontal link 6100 and between the horizontal link 40 6100 and the second outgoing trunk appearing in terminals 6130, 6131, 6132 and 6133 in the same vertical row or group of trunks. In a similar manner the vertical operating magnet may be released and the connection 45 is held by the continued energization of the horizontal magnet 6143.

When it is desired to release the connection first established, for example, the horizontal magnet 6144 is simply deenergized. 50 The spring 6151 rotates the bar 6139 to its normal position whereby the levers 6186 and 6197 permit the springs 6173 and 6310 to restore the slidable cards to their normal positions, thus disengaging the active and 55 passive contacts. As the levers 6186 and 6197 rotate downwardly, the V shaped portions 6187 and 6309 disengage from the spring wires 6173 and 6310, whereby said levers are permitted to flex back to their 60 normal positions.

When the connection is being released the slidable insulating card during the major part of its downward stroke causes the movable conductors to wipe over the surface of 65 the horizontal stationary conductors which

they are engaging. At the latter part of the downward movement of the card the diagonal notches engage the flexible conductors and carry them out of engagement with the horizontal stationary conductors. In this 70 way the wiping action between the active and passive contacts of the switch is secured both during the operation and release of said active contacts.

Detailed description of the system—establishment of connection through a single tandem office involving full transfer of record.

It will first be considered that the subscriber of line 101 in an originating office desires to converse with the subscriber of line 5416 at a terminating office which may be reached through a single tandem point. Referring to Fig. 59, this call corresponds 85 to one from the line 5916 in office 5902 through tandem office 5900 to the called line 5913 in office 5906. It is also assumed that the trunking distance from the calling to the called office is too great to permit of 90 transferring records directly from the calling to the called office. Assume that the name of the called office is one having the abbreviation G E R, which with respect to the dial operation, corresponds to series of 95 4, 3 and 7 impulses and also assume that the number of the called line 5416 is 1 3 2 6.

Initiation of the call and operation of the line switch.

When the calling subscriber of line 101 removes his receiver from the switchhook, a circuit is closed from battery through the winding of line relay 121, inner contact of cut-off relay 120, conductor 104, over the loop of the substation, conductor 103, outer contact of relay 120 to ground. The line relay 121 energizes and closes a circuit from battery through the winding of relay 129, 105 right back contact of relay 128, conductor 155, left contact of relay 121, conductor 156, winding of relay 133 to ground.

The relay 129, together with the relays 128 and 130 included within the broken rectangle, are individual to the vertical group 110 of lines appearing in the vertical row 110 of the line switch. The two subscribers' lines 101 and 102 shown belong to this vertical group. There will be for each of the remaining vertical groups of subscribers' lines a similar set of group relays. Relay 129 is energized in the manner explained through the left contact of the line relay of any subscriber's line in the first vertical group, which is the one illustrated.

Relay 129 closes a circuit from battery through the winding of relay 131, inner front contact of relay 129, conductor 156, winding of relay 133 to ground. Relay 131, 120 the function of which will be explained 125

- hereinafter, becomes energized. Relay 129 also closes a circuit for the group relay 130 traceable from battery through the left hand winding of said relay 130, outer front 5 contact of relay 129, conductor 157, left back contact of relay 135, outer right contact of relay 137, conductor 158, winding of relay 133 to ground. Relay 130 operates and closes a circuit from battery 10 through the winding of relay 128, inner left contact of relay 130 to ground. Relay 128 energizes and opens the circuit above traced for relay 129 permitting this latter relay to become deenergized.
- 15 When relay 130 operates it closes a holding circuit for itself as follows prior to the deenergization of relay 129; battery, through the right hand winding and inner right front contact of relay 130, winding 20 of relay 135, outer right back contact of relay 137 to ground over conductor 158. Relay 130 locks and relay 135 becomes energized in this circuit. Should a second call appear in the first vertical group, as, for 25 example, on line 102, relay 129 cannot again become operated so long as the relay 128 remains energized. Relay 128 for the time being is held energized, as explained, through the inner left contact of relay 130.
- 30 Relay 135, in operating, closes a circuit from battery through the winding of slow-to-release relay 136, inner right contact of relay 135, inner right back contact of relay 137 to ground over conductor 158. Relay 35 136 operates and the holding circuit for relays 130 and 135 is modified so that it now extends from battery through the right hand winding and inner right front contact of relay 130, winding of relay 135, contact 40 of relay 136 to the grounded conductor 158.
- Relay 130, on first energizing, closes a circuit from ground over conductor 158, outer right back contact of relay 137, left front contact of relay 135, outer right front 45 contact of relay 130, conductor 159, winding of the vertical operating magnet 116 to battery. Magnet 116 rotates the vertical rod associated with the row 110 to prepare the switch contacts of all lines in that row 50 for connection with the contacts of the horizontal links. The relay 135, which operates in series with relay 130 as described, closes a circuit from the grounded conductor 158, outer right contact of relay 135, left contact of relay 137, contact of slow-to-release relay 139, brush 144 of the allotter 55 143, which is standing in a position to allot the trunk 114, winding of the vertical operating magnet 118 to battery. Magnet 118 rotates the vertical bar belonging to the row 60 112 and prepares the contacts of the trunk 114 for connection with any of the horizontal link circuits. Magnet 118 also closes a circuit from battery through its winding 65 and inner contact, winding of relay 137,
- outer right contact of relay 135 to the grounded conductor 158. This circuit, including the winding of relay 137 however, is in parallel to the circuit above traced which leads directly to ground in shunt of the winding of relay 137. Hence, the relay 137 will not operate in series with magnet 118 so long as the shunt circuit, which extends through the brush 144 of the allotter switch, remains closed.
- 75 When the vertical magnet 116 operates it completes a circuit from ground through its contact, conductor 160, left contact of relay 134, outer left contact of relay 130, right contact of relay 121, left hand winding of relay 122 to battery.
- 80 Relay 122 is individual to the horizontal group of link circuits which serve the subscriber's line 101 in the vertical group 110 and the corresponding line in each of the 85 remaining vertical groups. Similarly, the relay 123 is a horizontal group relay individual to the group of link circuits which serve the subscriber's line 102 in the vertical group 110 and the corresponding lines 90 in all other vertical groups.
- 95 The relay 122 is operated, as above noted, and completes a circuit from battery through its right hand winding and right front contact, right back contact of horizontal group relay 123, assuming this relay is deenergized due to the fact that no line in that particular horizontal group is calling at the time, winding of relay 134, conductor 160 to ground at the contact of magnet 116. 100 Thus far the vertical magnets 116 and 118 have been operated to prepare the line switch for operation but a horizontal link bar has not been actuated to connect the line to the link and the link to the allotted trunk.
- 105 The vertical magnet 118 also closes a circuit from ground through its outer contact, conductor 151, winding of the individual trunk relay 146 to battery. Relay 146 operates and ground is extended over conductor 151 through the right contact of relay 146, brush 145, right contact of relay 140, contact and winding of the stepping magnet 138, winding of slow relay 139 to battery. The stepping magnet 138 energizes and 110 interrupts its own circuit and thereby advances the brushes 144 and 145 of the allotter switch to their next position terminals. If the next trunk is busy the brush 145 will encounter a ground potential on the corresponding terminal and the stepping magnet 138 will continue to operate to advance the brushes through another position. This action continues until the allotter switch 115 finally locates the first idle trunk.
- 120 The relay 139, which also energizes in series with the stepping magnet 138, opens the shunt circuit previously traced around the winding of relay 137. Relay 137 immediately operates and in so doing opens 125 130

the original operating circuit of relay 135. Relay 135, however, is held, as above explained, to the front contact of the slow relay 136. Relay 137 also opens the holding circuit of relay 136. Relay 136 having its circuit opened commences to release. The releasing period of the slow relay 136 is calculated to be sufficient for permitting the operation of the horizontal link bar magnet 10 of the line switch 100. During the holding period of relay 136 and following the operation of relay 137, a circuit is completed from the grounded conductor 158, inner right front contact of relay 137, right contact of relay 134, left back contact of relay 123, left front contact of relay 122, front contact of relay 127 (assuming the horizontal link 107 and its associated magnet 125 to be busy), back contact of relay 126, 20 winding of the horizontal magnet 124 to battery. The horizontal magnet 124 operates the rod individual to the link 106, whereby the subscriber's line 101 is connected to the link 106 and also the trunk 25 114 is connected to said link.

The subscriber's line 101 is now connected through the line switch 100 to the trunk 114 leading to the district selector switch 1000. When this connection is effected a circuit is 30 closed from ground through the outer contact of magnet 118, test conductor 163, contacts of the trunk 114, test conductor 164 of the link 106, contacts of the line 101, conductor 105, winding of the cut-off relay 35 120 to battery. Cut-off relay 120 operates and opens the circuit of line relay 121 and this latter relay becomes deenergized. Another circuit is closed from battery through the winding of the horizontal magnet 124, 40 winding of relay 126, horizontal link conductor 164, thence to ground, as above traced, at the outer right contact of magnet 118. Magnet 124 is held but relay 126 does not operate since it is shunted by the direct 45 path to ground through relay 133.

After an interval of time the slow relay 136 becomes deenergized and in so doing opens the holding circuit of relays 130 and 135. Relay 130 opens the original energizing circuit of relay 128. If no other line in the same or in any vertical group is calling at this time the relay 131 is deenergized and relay 128 releases since it cannot lock over the circuit through the left contact of relay 131 and the contact of relay 132. If another call exists in the first vertical group while all other vertical groups are free from calls, relay 131 will be operated, as hereinbefore explained, and relay 60 132 will also be operated. Under these conditions relay 128 also releases upon the deenergization of relay 130 since it cannot lock due to the fact that the left contact of relay 132 is opened.

65 Relay 136 also opens the circuit of the

vertical magnet 116 and this magnet deenergizes to restore the vertical rod to its normal position. Magnet 116 opens the holding circuit of the horizontal group relay 122 and relay 134. Relay 122 releases and restores 70 the starter wire circuit in the horizontal groups so that a call may be made in the next succeeding group. Relay 122 removes the shunt from relay 126 which operates in series with magnet 124. Relay 126 extends 75 the start circuit to the next horizontal link in the group. Relay 135, upon deenergizing opens the above traced circuit for magnet 118 and relay 137. Magnet 118 restores the associated operating rod to its normal position and relay 137 also releases. Thus the vertical group relays 129, 128 and 130, the horizontal group relay 122 and the common relays 133, 134, 135, 136, 137, 131 and 132 are again in their normal condition. The allotter switch 143 has advanced to allot the next idle trunk in order. The subscriber's line 101 is extended through the line switch 100 to the district selector and this connection is maintained solely by the energization 80 of the horizontal link magnet 124 which is held, as will be explained hereinafter, over a circuit leading to the grounded sleeve conductor 150.

Before proceeding with the operation of the sender selector switch a brief explanation will be given of the provision for taking care of simultaneous calling lines in the line switch. If a plurality of subscribers belonging to the same vertical group initiate 95 calls simultaneously, the relays 129, 130 and 128 are operated in the manner described. Due to the preferred order in which the horizontal group relays 122, 123, etc., are arranged, the subscriber's line having first 100 choice, such for example as the line 102, will cause this horizontal group relay 123 to lock while the remaining horizontal group relays 122, etc., will immediately release, their holding circuits being opened by the relay 105 123. Therefore, one subscriber's line will succeed in putting through a call and the remaining simultaneously calling lines in that vertical group will be required to wait until the horizontal group relay 123 is deenergized.

If two subscribers in different vertical groups of lines initiate calls simultaneously, the one in the first vertical group will succeed while the call in the second vertical group in order will be required to wait. The vertical group relay 130 for example, pertaining to the first calling subscriber's line, on operating, locks, as above described, through the winding of relay 135. The corresponding vertical group relay in the second calling group will be energized through its left hand winding but its locking circuit through the right hand winding, which normally extends by way of conductor 166, is 115 120 125 130

opened at the contact of relay 130. Consequently, the second vertical group relay becomes deenergized and the call in the corresponding group must wait for the first 5 call to be satisfied.

Should two lines in the first vertical group 110 initiate calls simultaneously with a line in another vertical group, one call in the first vertical group will be satisfied but the 10 second call therein would be required to wait until the call in the other group had been taken care of. Due to the calling line 102, for instance, in the first vertical group having initiated a call, the relays 130, 129 and 15 128 are operated and the switch is prepared for extending said line to an idle trunk. Relay 128, it will be recalled, upon operating through the contact of relay 130, opens the circuit of relay 129. Moreover, relay 128 20 closes a holding circuit for relay 131 which extends over conductor 155 through the left contact of the line relay 167, and relay 131 is maintained energized after the deenergization of relay 129. As soon as the horizontal link is operated and the line 102 is 25 extended through the trunk, the cut off relay 168 is energized in the manner explained to permit the deenergization of the line relay 167. Relay 167 opens one branch of the 30 holding circuit of relay 131. However, since another line in the same vertical group, namely line 101 is calling simultaneously, relay 131 is maintained energized in a second branch which extends through the left 35 contact of the line relay 121 to ground. A time later when the slow relay 136 deenergizes and opens the circuit of relay 130 this relay releases and opens the original energizing circuit of relay 128. Relay 128 40 retains its armatures attracted by means of the following circuit: battery, through the winding and left contact of relay 128, left contact of relay 131, contact of relay 132 to ground. Relay 128, by remaining energized, 45 prevents the reenergization of relay 129 in response to the call on line 101 and therefore this second line is required to wait.

As soon as the relay 130 releases and the call on line 102 has been taken care of, the 50 group relay, corresponding to relay 130 of the next group containing the other calling line, is energized in series with relay 135 and this call is satisfied in exactly the same manner as that already explained.

55 Whenever a plurality of calls occur in one vertical group and no calls are present in any other vertical group, relay 129, on deenergizing, completes a circuit from ground over conductor 158, outer right back contact of relay 137, outer left back contact of relay 135, conductor 157, outer left back contact of relay 129, thence in series through the outer left back contact of other group relays corresponding to relay 129, right contact of relay 131, winding of the slow-to-

release relay 132 to battery. Relay 132 operates and opens the circuit previously traced which would otherwise maintain relay 128 operated by reason of the second call in the vertical group. Relay 128 thereupon 70 becomes deenergized and another call in the same group may be satisfied by the re-operation of relay 129 in the manner above explained.

Operation of the sender selector.

75 During the foregoing operations of the line switch, all of which take place in a very brief space of time, the sender selector switch 300 is also being operated to extend 80 the trunk 114 to the allotted idle recording sender. Returning to the point where the vertical magnet 118 of the line switch is operated, a circuit is closed by this magnet for the relay 313 of the sender selector and 85 may be traced as follows: battery through the winding of relay 313, conductor 334, outer right contact of relay 230, right back contact of slow release relay 204, conductor 150, right front contact of trunk relay 146, 90 conductor 151, right contact of magnet 118 to ground. Relay 313 operates and locks in a circuit from battery through its winding and inner left contact, conductor 335, outer left back contact of relay 201 to ground. 95 Relay 313 completes a circuit from ground through its outer right contact, conductor 336, winding of relay 204 to battery. Relay 204, which has a slow-to-release characteristic, operates and applies ground potential to the holding or sleeve conductor 150. The application of this ground potential to the conductor 150 occurs during the period that relay 136 is still holding its armature attracted. New holding circuits are therefore prepared for the horizontal magnet 124, relays 126, 120 and 146. These circuits, instead of extending to ground at the outer right contact of magnet 118 as 100 previously traced, may be followed in an obvious manner through the right front contact of relay 146 to the holding conductor 150. 105

110 115 Relay 313, in operating, completes a circuit for the vertical group relay 315 traceable from battery through the winding of said relay, right back contact of vertical group relay 314, outer left contact of relay 313, conductor 338, winding of relay 318 to ground. Relays 315, 314 and 316, included in the broken rectangle, are individual to the first vertical group 301 and the remaining relays of the sender selector control circuit correspond closely to the controlling relays of the line switch 100, above described. Relay 315 closes a circuit from battery through the winding of relay 319, inner front contact of relay 315, winding of relay 318 to ground. Relay 319 operates in this circuit. 120 125 130

Relay 315 also closes a circuit from battery through the left hand winding of vertical group relay 316, outer left front contact of relay 315, left back contact of relay 317, 5 outer right contact of relay 323, conductor 340 to ground through the winding of relay 318. Relay 316 operates and closes a locking circuit for itself from battery through its right hand winding and inner right front contact and winding of relay 317, outer right contact of relay 323 to the grounded conductor 340. Relay 316, at its inner left contact, closes a circuit for relay 314 and this latter relay opens the energizing circuit of 10 relay 315. Relay 317 also operates in series with relay 316 and closes a circuit for the slow-to-release relay 322 traceable from battery through the winding of relay 322, inner right contact of relay 317, inner right back contact of relay 323 to the grounded conductor 340. Relay 322 operates and closes a holding circuit for relays 316 and 317. This circuit extends through the right hand winding and inner right front contact 15 of relay 316, winding of relay 317, contact of relay 322 to the grounded conductor 340.

With relays 316 and 317 operated a circuit is closed from battery through the vertical operating magnet 329, outer right front contact of relay 316, left front contact of relay 317, contact of relay 322 to ground over conductor 340. Magnet 329 prepares the vertical operating bar and also closes a circuit from ground through its contact, 20 left contact of relay 321, outer left contact of relay 316, inner right contact of relay 313, left hand winding of the horizontal group relay 312 to battery. Relay 312 becomes energized and closes a circuit from battery through its right hand winding and right front contact, conductor 341, winding of relay 321 to ground at the contact of magnet 329. Relay 312 locks and relay 321 becomes energized in this circuit. 25

At the time relay 317 operates a circuit is closed from battery through the winding of the vertical operating magnet 331, brush 327 of the allotter switch 326 (which is standing in a position to allot the circuit 332 leading to the recording sender illustrated in the drawing), contact of the slow-to-release relay 325, left contact of relay 323, outer right contact of relay 317 to the grounded conductor 340. The vertical magnet 331 operates and prepares the contacts in the row 304. Magnet 331 closes a circuit from battery through its winding and inner contact, winding of relay 323, outer right contact of relay 317 to the grounded conductor 340. Relay 323 is shunted, however, by the circuit previously traced for energizing the magnet 331 so long as the allotter switch 326 remains in its present condition. The magnet 331 also closes a circuit from ground through its outer contact, conductor 343, brush 328 of the allotter switch, contact and winding of the stepping magnet 324, winding of the slow-to-release relay 325 to battery. The magnet 324 operates, 30 interrupts its own circuit and advances the brushes 327 and 328 forward to allot the next idle recording sender for use. The relay 325, which also energizes in series with the stepping magnet 324, opens the previously traced shunt circuit around the winding of relay 323. Relay 323 now operates and in so doing opens the circuit of the slow-to-release relay 322.

With relay 323 energized and relay 322 holding its armature attracted for an interval, a circuit is closed from the grounded conductor 340, inner right front contact of relay 323, right contact of relay 321, left front contact of relay 312, front contact of relay 311—assuming the horizontal link 308 to be engaged at this time—left back contact of relay 309, winding of the horizontal link magnet 310 to battery. Magnet 310 operates the bar associated with the horizontal link 307, which is assumed to be idle, and the trunk circuit 114 is thus connected through the link 307 to the circuit 322 extending to the recording sender. When this connection is effected a circuit is first closed from battery through the winding of magnet 310, winding of relay 309, horizontal conductor 344, contacts of the sender selector switch, conductor 343, outer contact of magnet 331 to ground. The horizontal magnet 310 is held temporarily in the circuit traced and the relay 309, being shunted, does not operate at this time.

The sender selector, in operating, closes a circuit from ground through the outer contact of the magnet 331, conductor 343, contacts of the sender selector, conductor 346, winding of relay 201 to battery. Relay 201 operates and at its outer left contact opens the circuit of relay 313. Relay 313 releases and opens the circuit previously traced for the relay 204. Relay 204, however, is held energized after the release of relay 313 by means of the following circuit: battery, through the winding of relay 204, outer left front contact of relay 201 to ground.

Relay 201 extends the talking conductors 148 and 149 of the trunk circuit 114 through to the conductors 211 and 213 which lead through the sender selector switch to the recording sender. This results in the completion of the impulse circuit which includes the calling subscriber's line and the impulse relay 400 of the recording sender. The impulse circuit may be traced as follows: battery, through the right hand winding of relay 400, normal inner right hand contact of relay 409, conductor 420, right back contact of relay 411, inner left contact of relay 412, conductor 350, contacts of the sender selector switch, conductor 213, inner

left front contact of relay 201, conductor 149, contacts of the line switch 100, horizontal conductor of link 106, contacts of the line switch, conductor 104, over the loop of 3 the calling line, conductor 103, contacts of the line switch, trunk conductor 148, inner right front contact of relay 201, conductor 211, contact of sender selector, conductor 351, outer left contact of relay 412, left back 10 contact of relay 411, conductor 421, outer right contact of relay 409, upper winding of coil 422 to ground. The impulse relay 400 operates in this circuit and closes a circuit from battery through the winding of 15 the slow-to-release relay 401, left contact of relay 400 to ground. Relay 401 operates and closes a circuit from ground through its left contact, conductor 423, winding of relay 402 to battery. Relay 402 operates and at 20 its innermost right contact places a ground on the holding conductor 343.

The above events have all taken place while the slow-to-release relay 322 is maintaining its armature attracted following the 25 energization of relay 323. Hence, the subscriber's line is connected through to the recording sender and the slow relay 402 is operated to place a holding ground on the conductor 343 prior to the release of relay 30 322, which, as will presently be seen, brings about the release of the vertical magnet 331. After the interval has expired relay 322 releases its armature and opens the circuit of relays 316 and 317. Relay 316 opens the 35 circuit of relay 314. Relay 314 opens the circuit of relay 319 which, in turn, deenergizes. Relay 316 furthermore opens the holding circuit of the vertical magnet 329 and this magnet restores the associated rod 40 to its normal position. Magnet 329 also opens the circuit of relays 321 and 312.

Relay 317, in releasing, opens the holding circuit of magnet 331 and relay 323. Magnet 331 restores the vertical rod to normal 45 and at the same time disconnects its outer armature from the holding conductor 343. Conductor 343, as above noted, however, is already grounded by the operation of relay 402 and therefore the connection through 50 the sender selector is now held by means of the following circuit: battery, though the winding of the horizontal magnet 310, winding of relay 309, conductor 344, contacts of the sender selector, conductor 343 to ground 55 at the contact of relay 402. The operating relays and circuits of the sender selector switch 300 are now restored to their normal condition ready to extend another trunk to the next allotted sender while the present 60 connection is held by the maintained energization of the horizontal magnet 310 alone.

The relay 201, which at first was operated and held over the above traced circuit leading to ground at the outer right contact of 65 magnet 331, is now maintained by the

ground applied to conductor 343 by the relay 402.

Setting the recording sender in accordance with the wanted designation.

70

As soon as the recording sender is attached to the trunk by the sender selector and is ready for receiving impulses from the calling line, a dial tone is transmitted back to the calling subscriber's station, notifying him that he may proceed to manipulate his calling transmitter. For this purpose a circuit is closed from the source of dial tone current 732, Fig. 7, outer left back contact of relay 710, conductor 733, condenser 424, lower winding of coil 422, conductor 425 to ground at the outermost left contact of relay 402. Current in this circuit induces a flow of current in the upper winding of coil 422 which is transmitted over the subscriber's line to produce a characteristic tone in his receiver.

When relay 401 was first operated a circuit was closed from battery through the coil 426, conductor 427, left hand winding of relay 407, right front contact of relay 401 to ground. Relay 407, however, did not operate in this circuit due to the following shunt around its winding: battery, through the winding of coil 426, right contact of relay 400, right front contact of relay 401 to ground.

The subscriber on hearing the dial tone in his receiver manipulates his dial to transmit a series of four impulses representing the first letter G of the office code. On the first opening of the line the relay 400 releases its armatures but relay 401 being slow to release maintains its armature attracted. Relay 400, at its right contact, opens the shunt around the left hand winding of relay 407 and this latter relay immediately operates. Relay 407 closes a holding circuit for itself from battery through its right hand winding and inner right contact, outer left back contact of relay 408 to the grounded conductor 425. Relay 407 also closes a circuit from battery through the winding of relay 404, conductor 428, outer left contact of relay 407 to the grounded conductor 425. Relay 404 operates and closes a locking circuit for itself from battery through its winding and left front contact, right contact of relay 403 to ground on conductor 425. Relay 407 furthermore closes a momentary holding circuit from battery through the winding of the slow-to-release relay 405, conductor 429, outer right contact of relay 407 to ground on conductor 425; it will be noted that relay 405 was operated when relay 402 energized, the circuit being traced from ground on conductor 425 and thence through back contacts of relays 403 and 404.

Relay 407 also establishes a circuit from battery through the right hand winding of 120

relay 408 to ground at the inner left contact of relay 407. Relay 408 operates and closes a circuit from battery through its left hand winding and inner left contact to the grounded conductor 425. Relay 408 completes a circuit from battery through its right hand winding and right contact, conductor 430, outer right back contacts of counting relays 416, 415, 414 and 413 in series, winding of relay 413, outer left back contact of relay 414, conductors 431 and 432, outer left contact of relay 403, left front contact of relay 404, right back contact of relay 403 to the grounded conductor 425. The counting relay 413 is not operated in this circuit so long as relay 407 is held energized to maintain the shunt around the winding of said counting relay. This shunt, as above traced, leads from battery through the right hand winding of relay 408, and thence directly to ground at the inner left contact of relay 407. At the end of the first impulse the subscriber's line is closed and the relay 400 operates. Relay 400 replaces the shunt around the winding of relay 407 and this latter relay deenergizes. Relay 407 opens the shunt around the counting relay 413 and this relay is operated in series with the right hand winding of relay 408.

It will be noted that the operating circuit of the counting relay 413 leads through the back contact and its outer right hand armature. This relay and relays 414, 415 and 416 and 417 as well are arranged such that the back contact of the outer right hand armature is maintained closed in the operation of the relay until a slight interval after the front contact of the inner right hand armature has closed to complete the locking circuit. Therefore, the relay 413 is operated in the circuit above traced and on making its inner right front contact closes a locking circuit for itself as follows: battery, through the inner right contact and winding of relay 413, outer left back contact of relay 414, conductor 431, conductor 432, and thence as above traced to the grounded conductor 425.

The instant relay 407 releases it opens the original energizing circuit of relay 408. The resistance of relay 413 is included in series with the right hand winding of said relay 408, causing a reduction of the flow of current through this winding. Shortly thereafter when relay 413 makes its inner right front contact a shunt effect on the right hand winding of relay 408 is produced by closing the above traced circuit from battery through the inner right front contact and winding of relay 413 to ground. Following this the relay 413 opens its outer right back contact and severs completely the circuit through the right hand winding of relay 408. The left hand winding of relay

408 is wound differentially with respect to the right hand winding. Hence, the current flow through the right hand winding of the relay 408 after being reduced by two successive steps is finally differentiated by the flux produced in the left hand winding and the relay releases its armatures quickly.

When the next impulse is sent relay 407 operates and closes the above traced circuit for relay 408. Relay 408 energizes and closes a circuit from battery through its right hand winding and right contact, conductor 430, outer right back contacts of relays 416, 415 and 414 in series, outer right front contact of relay 413, winding of relay 414, outer left back contact of relay 415 to ground over conductor 431. Relay 414 remains shunted while relay 407 is energized, as explained in connection with relay 413. At the end of the impulse the subscriber's line closes and relay 407 is shunted to remove the short circuit from around the winding of counting relay 414. Relay 414 operates in series with relay 408 in the manner above described and locks in a circuit from battery through its inner right front contact and winding, outer left back contact of relay 415 to the grounded conductor 431. Relay 414, at its outer left back contact, opens the circuit of the previously energized relay 413 permitting this latter relay to release. When the second impulse is transmitted, as explained in connection with relay 413, relay 414, on operating, first shunts the right hand winding of relay 408 and then opens the circuit of such winding permitting said relay to become differentiated and released.

Upon the transmission of the third impulse relay 408 is again energized and closes a circuit from battery through its right hand winding and right contact, conductor 430, outer right back contacts of relays 416 and 415, outer right front contact of relay 414, winding of relay 415, outer left contact of relay 416 to ground over conductor 432. Relay 415 operates as soon as the impulse terminates and relay 407 is released to remove the shunt. Relay 415 opens the circuit of relay 408 and this latter relay becomes released. Relay 415, on operating, locks in a circuit from battery through its inner right front contact and winding, outer left contact of relay 416 to the grounded conductor 432. Relay 415, operating, opens the locking circuit of relay 414 and relay 414 thereupon restores to normal.

Finally, upon the transmission of the last of the four impulses in the series, relay 407 becomes energized and closes the operating circuit of relay 408. Relay 408 completes a circuit from battery through its right hand winding and contact, conductor 430, outer right back contact of relay 416, outer right front contact of relay 415, winding of relay

416, outer left back contact of relay 417, conductor 431 to ground. At the end of the impulse relay 407 deenergizes removing the shunt from the winding of relay 416 and said relay 416 energizes in series with relay 408. When relay 416 is fully operated it closes a locking circuit for itself from battery through its inner right front contact and winding, outer left back contact of relay 417 to ground over conductor 431. Relay 416 also opens the circuit of relay 408 and the last mentioned relay retracts its armatures. Relay 416, furthermore, opens, at its outer left contact, the holding circuit of relay 415. Thus, at the end of the impulse series relay 416 is energized and the remaining counting relays are in their inert condition.

During the transmission of the impulse series the above traced circuit for relay 405 was repeatedly opened and closed by the action of relay 407. Relay 405, however, being slow to release retains its armature during the brief interruptions of its circuit. At the end of the impulse series, however, the circuit of relay 405 is held opened for a sufficient interval to permit its release. Relay 405 deenergizes and closes a circuit from ground by way of conductor 425, contact of relay 405, right contact of relay 404, inner left contact of relay 403, conductor 434, right back contact of relay 710, winding of relay 709 to battery. Relay 709 becomes energized and establishes a circuit from battery through its winding and inner upper contact, conductor 734, winding of relay 403, contact of relay 404, contact of relay 405 to the grounded conductor 425. The relay 403 does not operate in this latter circuit due to the fact that its winding is shunted by the first circuit traced for the energization of relay 709. Relay 709 operates and connects the leads from the counting relays in Fig. 4 through to the relays 703, 704, 705 and 706 of the register 700.

Since the counting relay 416 alone is energized a circuit is closed from the grounded conductor 432, outer left back contact of relay 413, inner left contact of relay 416, conductor 436, next to the lowermost contact of relay 709, winding of relay 705, conductor 735, winding of relay 708 to battery. Relays 708 and 705 energize and lock in a circuit traceable through the inner left contact of relay 705, conductor 736, conductor 737, conductor 738 to ground at the middle right hand armature of relay 402. Relay 708 established a circuit from ground over conductor 736, contact of relay 708, winding of relay 710 to battery.

Relay 710, at its right back contact, opens the shunt around the winding of relay 403 and the latter relay operates in series with relay 709 in the circuit hereinbefore traced.

Relay 403 opens the holding circuit of relay 404 at its right contact. Relay 404, on deenergizing, opens the circuit of relays 403 and 709 permitting these relays to retract their armatures. Relay 403 also causes the release of all energized counting relays; in this particular case only the relay 416 is operated. The impulse receiving circuit is now in condition to receive the next series of impulses. Relay 709 in the recording circuit, upon deenergizing, disconnects the conductors extending from the counting relays to the first register 700.

The subscriber next manipulates his dial in accordance with the second letter E of the office code to transmit a series of three impulses. The impulse receiving mechanism in Fig. 4 functions in the same manner as explained in connection with the first impulse series, and when the third impulse has been received counting relay 415 alone is operated while relays 413 and 414 have been deenergized successively. After an interval relay 405 releases and the circuit above traced from grounded conductor 425, contact of relay 405, right contact of relay 404, inner left contact of relay 403 and conductor 434 now extends through the right front contact of relay 710, right back contact of relay 716, winding of relay 717 to battery. Relay 717 operates and extends the leads from the counting relays through to the relays of the second register 701. Relay 717 also closes a circuit from battery through its winding and inner upper contact, conductor 734, winding of relay 403, right contact of relay 404, thence to ground over conductor 425. As before explained, relay 403 does not operate due to the fact that it is shunted by the original circuit through the winding of relay 717.

Since the counting relay 415 is operated a circuit is completed from the grounded conductor 431, outer left front contact of relay 415, conductor 437, innermost lower contact of relay 717, winding of relay 711, winding of relay 715 to battery. Another circuit is traceable from grounded conductor 431, inner left front contact of relay 415, conductor 438, next to the inner lower contact of relay 717, winding of relay 712, winding of relay 715 to battery. Relays 711, 712 and 715 operate and lock in a circuit traceable from battery through the winding of relay 715, thence in parallel through the windings and inner left contacts of relays 711 and 712, conductor 742 to the grounded conductors 737 and 738. Relay 715 closes a circuit from battery through the winding of relay 716, contact of relay 715 to the grounded conductor 742. Relay 716 operates and locks through its winding and left contact to the grounded conductor 742. Relay 716, at its right back contact, opens the shunt circuit around the winding of relay 403.

Relay 403, in operating, opens the circuit of relay 404 and the circuit of the counting relay 415. Relay 404 releases and opens the circuit of relays 403 and 717. Relay 717 disconnects the counting relay leads from the register 701.

Next the subscriber transmits a series of seven impulses representing the third code letter R of the office designation. As previously explained, the counting relay 416 at the end of the fourth impulse is energized and all other counting relays are in deenergized condition. At the beginning of the fifth impulse the subscriber's line opens and relay 407 becomes energized to close the operating circuit for relay 408. Relay 408 completes a circuit from battery through its right hand winding and contact, conductor 430, outer right front contact of relay 416, outer right back contact of relay 417, winding of relay 417 to the grounded conductor 431. Relay 417 operates as soon as the subscriber's line is closed and relay 407 becomes deenergized and in so operating relay 417 completes a locking circuit for itself as follows: battery, through the inner right contact and winding of relay 417 to the grounded conductor 431. Relay 417 opens the circuit of relay 408 and also opens the circuit of relay 416 whereby these last two mentioned relays become deenergized. At the beginning of the sixth impulse relay 408 operates and completes a circuit from battery through its right winding and right contact, conductor 430, outer right back contacts of relays 416, 415, 414 and 413 in series, winding of relay 413, outer left back contact of relay 414 to ground at conductor 431. At the end of the impulse relay 413 operates and locks in the manner hereinbefore explained. When the line opens at the beginning of the seventh impulse the relay 408 operates in the usual manner and completes a circuit from battery through its right hand winding and contact, conductor 430, outer right back contacts of relays 416, 415 and 414, outer right front contact of relay 413, winding of relay 414, outer left back contact of relay 415 to the grounded conductor 431. When the impulse has ceased relay 414 operates and locks as above explained. Relay 414 opens the circuit of relay 408 and also opens the circuit of the preceding counting relay 413. Relay 414 in addition closes a circuit from battery through the winding of relay 418, inner left contact of relay 414, conductor 439, outer left front contact of relay 417, to the grounded conductor 431. Relay 418 energizes in this circuit and locks in a circuit from battery through its winding and inner right contact to ground over conductor 431. Thus, at the end of seven impulses counting relays 414, 417 and 418 are operated.

65 After an interval following the last of

the third series of impulses the slow relay 405 retracts its armature and closes a circuit from ground through the outermost left contact of relay 402, conductor 425, contact of relay 405, right contact of relay 404, inner left contact of relay 403, conductor 434, right front contact of relay 710, right front contact of relay 716, right back contact of relay 723, winding of relay 724 to battery. Relay 724 operates and extends the counting relay leads through the register 702. Relay 724 also closes a circuit from battery through its winding and inner upper contact, conductor 734, winding of relay 403, back contact of relay 404, contact of relay 405 to ground over conductor 425. Relay 403 remains shunted until relay 723 operates.

With the counting relay 414 operated a circuit may be traced from ground over conductor 431, outer left front contact of relay 414, conductor 438, next to the lowermost contact of relay 724, winding of register relay 719, conductor 743, winding of relay 722 to battery. Another circuit may be traced from ground over conductor 431, inner left front contact of relay 417, inner left contact of relay 413, conductor 441, innermost lower contact of relay 724, winding of relay 721, winding of relay 722 to battery. Relays 722, 719 and 721 operate and lock in a circuit from battery through the winding of relay 722, thence in parallel through the windings and inner left contacts of relays 719 and 721, conductor 744, conductor 737 to ground. Relay 722 completes a circuit from battery through the winding of relay 723, contact of relay 722 to the grounded conductor 744. Relay 723 operates and locks in a circuit through its winding and left contact to the grounded conductor 744. Relay 723, at its right back contact, opens the shunt circuit around the winding of relay 403. Relay 404 retracts its armatures opening the circuit of the energizing counting relay and also the circuit of relay 405. Relay 405 releases and opens the circuit of relays 403 and 724 whereby these two relays become deenergized.

Following this the subscriber sends four series of impulses representing the thousands, hundreds, tens and units digits of the called line number which is assumed to be 1326. The first series consisting of one impulse is received in the manner explained and at the end of this impulse relay 413 alone is energized. After an interval following the impulse slow relay 405 releases and a circuit is closed from grounded conductor 425 through the contact of relay 405, right contact of relay 404, inner left contact of relay 403, conductor 434, right front contact of relays 710, 716 and 723 in series, right back contact of relay 808, winding of relay 809 to battery. Relay 809 operates and ex-

- tends the counting relay leads through to the relays 803, 804, 805 and 806 of the thousands register 800. Relay 809 also completes a circuit from battery through its winding and 5 inner upper contact, conductor 734, winding of relay 403, right contact of relay 404, contact of relay 405 to ground over conductor 425. Relay 403 being shunted remains de-energized until relay 808 is operated.
- 10 With the counting relay 413 energized at the end of the thousands impulses and with the counting relay leads extended through to the thousands register, a circuit may be traced from ground over conductor 431, 15 outer left front contact of relay 413, outer right back contact of relay 418, conductor 437, lowermost contact of relay 809, winding of relay 803, winding of relay 807 to battery. A branch of this circuit extends by way of 20 conductor 829, winding of relay 826 to battery. Relays 807, 803 and 826 operate and lock in a circuit from battery through their windings, inner right front contact of relay 803, conductor 830 to the grounded conductor 25 or 737. Relay 807 closes a circuit from battery through the winding of relay 808, contact of relay 807 to ground over conductor 830. Relay 808 operates and locks in a circuit from battery through its winding and 30 innermost left contact to ground over conductor 830. Relay 808, at its right back contact opens the shunt circuit around the winding of relay 403 and this latter relay operates releasing in turn the counting relay 35 413 and relay 404. Relay 404 opens the circuit of relays 403 and 809 whereby these relays retract their armatures.
- The calling subscriber now manipulates the transmitter 171 to send a series of three 40 impulses representing the hundreds digit. At the termination of the hundreds series of impulses, the counting relay 415 is operated and after an interval of time expires the slow-to-release relay 405 retracts its armature. Relay 405 completes a circuit from 45 ground over conductor 425, contact of relay 405, right contact of relay 404, inner left contact of relay 403, conductor 434, thence through the right front contacts of relays 50 710, 716, 723 and 808, right back contact of relay 818, winding of relay 819 to battery. Relay 819 operates and extends the counting relay leads to the relays of the hundreds register 801. Relay 819 also closes a circuit 55 from battery through its winding and inner upper contact, conductor 734, winding of relay 403, thence, as above traced, to ground over conductor 425. Relay 403 being shunted at this time does not operate.
- 60 With the counting relay 415 in energized condition and the controlling leads extended through the hundreds register, a circuit may be traced from ground over conductor 431, outer left front contact of relay 415, conductor 437, lowermost contact of relay 819, 65 winding of relay 810 to battery. Another circuit is established from the grounded conductor 431 through the inner left front contact of relay 415, conductor 438, next to the lowermost contact of relay 819, thence 70 through the winding of relay 811 to battery. Relay 810 and 811 operate and lock in circuits traceable through the windings of these relays and their inner left contacts to the grounded conductor 737. The relay 818 75 is now operated in a circuit from battery through its winding, outer left contact of relay 810 to ground over conductor 832. Relay 818 locks in a circuit from battery through its winding and inner left contact 80 to ground over conductor 832. Relay 818, at its right back contact, opens the shunt around the winding of relay 403 and this latter relay energizes to cause the release of 85 relays 404 and 415. Relay 404, on releasing, opens the circuit of relays 403 and 819 whereupon these relays retract their armatures.
- Next the calling subscriber operates his dial 171 to transmit a series of two impulses 90 characterizing the tens digit of the wanted number. As already explained in detail, a series of two impulses results in the energization of the counting relay 414 which locks in the circuit controlled by relay 403. 95 After the required interval following the tens series the slow relay 405 retracts its armature and the above traced circuit from ground by way of conductor 434 is now completed through the right front contacts of 100 relays 710, 716, 723, 808 and 818, right back contact of relay 910, winding of relay 911 to battery. Relay 911 operates and extends the controlling leads from the counting relays through to the relays of the tens register 900. Relay 911, moreover, completes a circuit from battery through its winding and inner upper contact, conductor 734, winding of relay 403, and thence as previously traced to ground over conductor 425. 110 Relay 403 being shunted does not operate at this time.
- Since only the one counting relay 414 remains energized at the end of the tens series of impulses, the following circuit alone may 115 be traced for operating the tens register: ground, over conductor 431, outer left front contact of relay 414, conductor 438, next to the lowermost contact of relay 911, winding of relay 903 to battery. Relay 903 operates and locks in a circuit through its winding and inner left contact, conductor 925, to ground over the holding conductor 737. A circuit may now be traced from battery through the winding of relay 910, outer left contact of relay 903 to ground over conductor 925. Relay 910 actuates and locks in a circuit from battery through its winding and inner left contact to ground over the conductor 925. Relay 910, at its right 120 125 130

back contact, opens the short circuit around the winding of relay 403. Relay 403 operates in series with relay 911 and opens the holding circuits of relay 404 and counting relay 414. Relay 404, upon releasing, opens the circuit of relays 403 and 911 and these relays in turn deenergize.

Lastly, the calling subscriber sends a series of six impulses over the line representing the units digit of the called subscriber's line. The receiving mechanism in Fig. 4 responds to the series of impulses and at the end of the last impulse counting relays 413 and 417 are energized and locked in the manner explained while the remaining counting relays are inert. After the necessary interval has elapsed the slow relay 405 retracts its armature and the circuit hereinbefore traced from grounded conductor 425 to the conductor 434 may now be followed through the right front contacts of relays 710, 716, 723, 808, 818 and 910 through the outer right back contact of relay 927, winding of relay 928 to battery. Relay 928 operates and extends the controlling leads from the counting relays through to the units register 901. Relay 928, furthermore, completes a circuit from battery through its winding and inner upper contact, conductor 734, winding of relay 403, thence as traced to the grounded conductor 425. In the same manner as previously explained, relay 403 is shunted and does not operate until relay 927 is energized. Since the counting relay 413 is actuated a circuit may be traced from the grounded conductor 431, outer left front contact of relay 413, conductor 442, outer right back contact of relay 418, conductor 437, lowermost contact of relay 928, winding of relay 912 to battery. Another circuit is traceable from the grounded conductor 431 through the inner left front contact of relay 417, inner left back contact of relay 418, conductor 441, innermost lower contact of relay 928, winding of relay 915 to battery. Relays 912 and 915 operate and lock in circuits through their windings and inner left contacts, conductor 929, thence to ground at the holding conductor 737. Relay 927 is also operated in a circuit from battery through its winding, outer left contact of relay 912 to the grounded conductor 929. Relay 927 actuates and closes a locking circuit through its inner right contact to the conductor 929. Relay 927, at its outer right back contact, opens the shunt circuit around the winding of relay 403. Relay 403 operates in series with relay 928 in the circuit above traced and opens the holding circuits of relays 404, 413, and 417. Relays 413 and 417 release and relay 404 also restores and relay 404 opens the circuit of relays 403 and 928 causing these relays to become deenergized.

A complete registration has now been made in the office and numerical registers of the recording sender. The called subscriber's line is assumed to be a single party direct line. Where a called line has a plurality of stations thereon an extra series of impulses may be transmitted following the numerical portion of the designation to cause the setting of the register 906 in identically the same manner as that described in connection with the other registers of the sender. The stations digit serves in any well known and approved manner to determine the character of ringing current to be applied to the called line.

After all series of impulses have been transmitted over the line and received by the impulse mechanism in Fig. 4, the counting relays are restored to their normal condition and the impulse relay 400 remains energized in series with the subscriber's line. Relay 400, as above explained, maintains the energization of slow relays 401 and 402 to hold the connection in its present condition under the control of the calling subscriber's switchhook.

Association of the recording sender with the district marker.

The record of the wanted line having been made in the recording sender, the next operation to take place is the association of this particular sender with the district marker which is common to a number of such senders and which controls the group of district selector switches containing the particular switch 1000 to which the selected trunk 114 extends. The district marker is concerned only with a portion of the entire designation; namely, the office code and the thousands digit. Hence, the sender may be associated with the marker immediately that the office and thousands records are received by the sender and this association need not await the receipt of the remaining part of the designation. In other words the recording sender is connected to the district marker the instant the thousands digit has been recorded on the sender. In the case of a local call, namely, one to be completed to a called line in the same central office, the thousands digit is required for governing the district marker to control selection at the district switch of a terminal group of lines. The office code in such calls serves only for class purposes. On interoffice calls, however, as in the one now being considered no local selection of line groups at the originating office is involved and hence the thousands digit, although received by the district marker, will not be needed. As will be seen it is the office code which governs the marker to select a group of trunks outgoing from the calling office to the tandem office.

It will be recalled that following the registration of the thousands digit, the relay 808 is operated. The relay 808 completes a circuit from ground over conductors 737 and 830, middle left contact of relay 808, conductor 835, conductor 740, winding of relay 505 to battery. Relay 505 operates and locks in a circuit from battery through its winding and right contact to ground over conductors 506 and 507. Relay 505 closes a start circuit for the sender connector 1400 in order that the multi-contact relay 1401, which is individual to the recording sender concerned, may be operated to connect such sender to the district marker. The start circuit is traceable from ground over conductor 507, conductor 509, inner left back contact of relay 510, outer left back contact of relay 511, conductor 512, inner left front contact of relay 505, outer right back contact of relay 513, conductor 514, winding of relay 1409 to battery. Relay 1409 serves to initiate the operation of the sender connector device 1400. Before proceeding with the operation of the sender connector 1400, an explanation will be given of the plan employed for grouping the multi-contact operating relays of the sender connector.

Where there are a comparatively large number of recording senders, all of which have access to the marker, it is advisable to provide some means for distributing evenly among the different senders the availability which they have in gaining access to the district marker. To this end the total number of senders are divided into several small groups as regards their appearance in the sender connector 1400. Two such groups, namely the groups 1422 and 1423 are illustrated. The last group in the series 1423 is represented by the two multi-contact relays 1401 and 1402, each of which is individual to a recording sender. Obviously, more than two senders may be assigned to a group if desirable. The relays 1413 and 1414 are common to the last group 1423. The next to the last group 1422 also is illustrated as having two recording senders to which the relays 1403 and 1404 are respectively connected. Relays 1415 and 1416 are the group relays common to the group 1422. As will be taken up later on, the circuit arrangement of the connector 1400 is such that each group of senders has preference over all succeeding groups in the series in the event that two senders occurring in different groups are attempting simultaneously to gain access to the district marker. The plan, however, is such that if two senders in one group and another sender in a succeeding group are attempting connection to a district marker simultaneously, one sender in the first group will succeed in appropriat-

ing the district marker but the second sender 65 in the first group will be required to wait until the sender in the succeeding group has been connected to the marker. That is to say, a second sender, in any group seeking access to the district marker must wait until 70 one sender in each of all such succeeding groups as have any sender simultaneously attempting connection with the marker, has been so connected.

Since the groups 1422 and 1423 are respectively the next to the last and the last groups of senders in the series, it follows that all preceding groups have preference over these two and that the group 1422 has preference over the group 1423 as regards 75 two senders simultaneously attempting connection to the marker. The recording sender shown in Figs. 4 to 10, inclusive, belongs in the last group 1423 and is individual to the multi-contact relay 1401 in such group. Hence, the individual relay 1409 is operated as described when the sender is ready 80 for connection to the marker. Relay 1409 completes a circuit from ground through its right contact, common conductor 1424, right back contact of relay 1413, winding of relay 1414 to battery. Relay 1414 operates and locks in a circuit from battery through its winding and right contact, left back contact of relay 1416, thence through the left 85 back contacts of all corresponding relays 1416 of the preceding groups, conductor 1425, outer right back contact of relay 1101, conductor 1116, contact of relay 1104 to ground. The closure of this locking circuit for relay 1414 depends upon the fact that all corresponding relays in preceding groups are deenergized indicating that no other group having a higher preference is requiring connection to the marker at this time. 90 On this assumption the relay 1414 locks in the circuit traced and completes a circuit from battery through the right hand winding of relay 1405, left contact of relay 1409, left back contact of relay 1410, through the 95 back contacts of all corresponding relays in the group 1423 (assuming that no other sender in this group is attempting connection to the marker), left front contact of group relay 1414, thence over the conductor 1425, as previously traced, to ground at the contact of relay 1104. Relay 1405 becomes 100 energized and closes a circuit from battery through the winding of relay 1413, inner right front contact of relay 1405 to ground. Relay 1413 operates, opens the original circuit of relay 1414, and closes a circuit from 105 ground through the right contact of relay 1409, conductor 1424, right front contact of relay 1413, conductor 1426, winding of relay 1102 to battery. Relay 1102 attracts 110 its armatures and closes a locking circuit for relay 1413 as follows: battery, through the 115 120 125

winding and inner left contact of relay 1413, conductor 1427, left contact of relay 1102, contact of relay 1103 to ground.

With relay 1413 operated a locking circuit

- 5 for relay 1405 is completed from battery through the left hand winding and left contact of relay 1405, left back contacts of relay 1406 and the corresponding relays in the same group, outer left contact of relay 1413, outer left back contact of relay 1415, outer left back contact of similar relays in preceding groups, conductor 1429, winding of relay 1101, conductor 1116 to ground at the contact of relay 1104. Relay 1405 locks
- 10 and relay 1101 is operated in this circuit. Relay 1101, at its outer right contact, opens the holding circuit of relay 1414 permitting this latter relay to release its armatures. Relay 1414 opens the original energizing
- 15 circuit of relay 1405.

With relays 1405 and 1101 energized a circuit is established from battery through the winding of the multi-contact relay 1401, outer right contact of relay 1405, conductor 1430, inner left contact of relay 1101 to the grounded conductor 1116. Relay 1401 moves its gang of contacts into engagement with the corresponding horizontal wires of the connector 1400 whereby the leads coming from the recording sender are extended through to the district marker. Relay 1401, moreover, completes a circuit from ground through its contact, conductor 1431, outer left contact of relay 1101, inner right back contact of relay 1100, winding of relay 1106 to battery. The energization of the relay 1106 gives an indication to the recording sender that the district marker has been associated and is ready to receive the office and thousands records. Before going on with this an explanation will be given as to the operation of the sender connector 1400 when a number of senders are simultaneously seeking to be connected to the district marker.

Considering, for example, that both senders illustrated in the group 1422 and the sender shown in the drawing which belongs to the group 1423 are simultaneously attempting to be connected to the marker. Relays 1411 and 1412 being operated circuits are closed in an obvious manner for the energization of relay 1416. Relay 1416 operates and locks in the manner explained through its winding and right contact, conductor 1425 to the grounded conductor 1116. Relay 1416 closes a circuit from battery through the right hand winding of relay 1408, left front contact of relay 1412, left front contact of relay 1416, conductor 1425 to ground. The corresponding circuit for the relay 1407 of the other sender in the group is closed at the left contact of relay 1411 but is held opened by the left

contact of relay 1412, which has first preference. Relay 1408 completes a circuit from ground through its inner right contact, winding of relay 1415 to battery. Relay 1415 operates and a circuit is closed from battery through the winding of relay 1102, conductor 1426, right front contact of relay 1415, thence to ground at the right contact of either relay 1412 or relay 1411. Relay 1102 operates and a locking circuit for relay 1415 is established as follows: battery, through the winding and inner left contact of relay 1415, conductor 1427, left contact of relay 1102, contact of relay 1103 to ground. Relay 1415 closes a circuit from battery through the left hand winding and left contact of relay 1408, outer left front contact of relay 1415, conductor 1429, winding of relay 1101, to ground on conductor 1116. Relay 1101 operates and as above noted opens the holding circuit of relay 1416. Relay 1408 operates and in the manner above explained completes a circuit for the multi-contact relay 1404 which operates and connects the corresponding sender to the district marker. Relay 1101 opens the circuit of relay 1412 which retracts its armatures.

When the district marker has completed its function it is disconnected from the recording sender in a manner to be explained hereinafter. The disconnection results in the deenergization of relays 1408, 1404 and 1412. Relay 1412, at its right contact, removes ground from the circuit previously traced for relay 1102. However, relay 1102 is now held by a circuit leading to ground at the right contact of relay 1411 since the other sender in the same group is waiting to be connected to the district marker. Relay 1408, upon deenergizing, opens the original energizing circuit of relay 1415. Relay 1415, however, is locked in the circuit traced through the contacts of relays 1102 and 1103. Hence, the relay 1416 cannot again be operated to connect the second sender in the group 1402 to the district marker.

With relays 1101 and 1416 deenergized after the first sender in the first group has been disconnected from the marker, a circuit is closed for holding the relay 1414 as follows: battery, through the winding and right contact of said relay, left back contact of relay 1416, conductor 1425, thence to the grounded conductor 1116. Relay 1414 in the fashion already explained brings about the operation of relays 1405, 1413 and 1401 and the recording sender in the last group 1423 is connected to the district marker.

After the second sender has been disconnected from the marker the other sender in the first group 1422 waiting connection may now be associated with the marker provided

there is no other sender in any other group waiting for connection to the marker. Since there is no other group of senders active at this time all relays 1414, 1416, etc., are in deenergized condition. Hence, a circuit is closed when the last one of these relays releases traceable from battery through the winding of relay 1103, right contact of relay 1102, conductor 1118, left back contact of relay 1414, left back contact of relay 1416, etc., to the conductor 1425, outer right back contact of relay 1101 to the grounded conductor 1116. Relay 1103 operates and opens the holding circuit of relay 1415. Relay 1415 immediately releases and in the manner above described the other sender in group 1422 is associated with the district marker.

When relay 1415 releases it opens the circuit of relay 1102. Relay 1102 becomes deenergized and in turn releases the relay 1103.

Returning now to the point where the recording sender shown in the drawing is associated with the district marker by the operation of the multi-contact relay 1401 and relay 1106 is energized, a circuit may be traced from ground over conductor 1116 through the outer right front contact of relay 1101, outer left front contact of relay 1106, conductor 1120, contacts of relay 1401, conductor 1432, outer left back contact of relay 513, conductor 515, contacts of the sender selector switch 300, conductor 352, innermost right back contact of relay 205, conductor 221, winding of the vertical operating magnet 1015 to battery. Thus, the vertical magnet 1015, controlling the vertical row of contacts 1008 in which appears the trunk 114 to which the calling subscriber's line has been extended, has been selected and operated. The magnet 1015 prepares the contacts of the trunk for connection to a horizontal link circuit. Magnet 1015 also closes a circuit from battery through the winding of relay 208, conductor 222, left front contact of magnet 1015, conductor 223, outer right contact of relay 201 to grounded conductor 150. Relay 208 locks through its inner upper contact and the inner right contact of relay 230 to ground over conductor 223 as traced.

Also at the time relay 1101 operates a circuit is established from battery through the winding of slow-to-release relay 1112, left back contact of relay 1114, inner right contact of relay 1101 to the grounded conductor 1116. Relay 1112 energizes and closes a circuit from battery through the winding of the slow-to-release relay 1113, contact of relay 1112, thence, as traced, to the grounded conductor 1116. Relay 1113 operates and completes a circuit from battery through the winding of slow-to-release relay 1114, inner front contact of relay 1113 to ground as traced. Relay 1114 operates and

opens the circuit of relay 1112, which, after an interval of time, retracts its armature. Relay 1112 opens the circuit of relay 1113 which, after a second interval, becomes deenergized. With relay 1113 released and relay 1114 maintaining its energization a circuit is momentarily completed from ground over conductor 1116 through the inner right contact of relay 1101, inner back contact of relay 1113, inner right contact of relay 1114, conductor 1121, winding of release relay 1100 to battery. The combination of slow operating relays 1112, 1113 and 1114 act in this manner to measure a given interval of time following the operation of relay 1101. If at the end of this interval relay 1101 does not become deenergized, indicating that the marker completed its functions, the relay 1100 is operated as described and brings about the release of the marker and the sender connector 1400 in a manner to be related hereinafter.

At the time relay 1106 operates it closes a circuit from ground over conductor 1116, outer right front contact of relay 1101, outer left front contact of relay 1106, conductor 1122, outer left back contact of relay 1346, winding of slow-to-release relay 1348 to battery. Relay 1348 becomes energized and completes a circuit from ground through its left contact, winding of slow-to-release relay 1347 to battery. Relay 1347 operates in this circuit.

At the time relay 1101 operates and before relay 1106 operates, a circuit is closed momentarily as follows: battery, through the winding of relay 1105, outer left back contact of relay 1106, outer right front contact of relay 1101, to ground at the contact of relay 1104. When relay 1106 operates the energizing circuit of relay 1105 is broken, but relay 1105 being slow-to-release holds the conductor 1125 open for an interval to insure that all relays of the registers 1201, 1202 and 1203 are operated before selection of the translator relay is made.

Transfer of office and thousands records from the recording sender to the district marker.

The apparatus is now in condition for marking at the district selector switch 1000 the particular group of outgoing trunks which lead into the desired tandem office. For this purpose the office code record and the record of the thousands digit, already established in the sender, are transferred into the district marker.

The transfer of the first portion of the office record from the register 700 to the register 1201 of the district marker will now be described. Since the register relay 705 alone is operated a circuit may be traced from ground through the contact of relay 1104 in the district marker, conductor 1116,

inner left contact of relay 1106, conductor 1123, contacts of multi-contact relay 1401, conductor 1434, conductor 747, outermost right contact of relay 705, conductor 772, 5 contacts of relay 1401, conductor 1435, winding of relay 1225 to battery. Thus, the register relay 1225 operates and the remaining three relays 1224, 1226 and 1227 remain inert.

- 10 The second and third portions of the office designation are transferred from the recording sender to the marker registers 1202 and 1203 in a similar manner. With the register relay 711 operated a circuit is completed 15 from the grounded conductor 1116 over conductor 1434, as above traced, conductor 747, outermost right contact of relay 711, conductor 748, contacts of relay 1401, conductor 1436, winding of register relay 1231 to 20 battery. With register relay 712 energized another circuit is established from ground over conductors 1434 and 747, outermost right contact of relay 712, conductor 749, contacts of relay 1401, conductor 1437, 25 winding of relay 1230 to battery.

Since relay 719 of the office register 702 is operated a circuit is established from the grounded conductor 1434, conductor 747, outermost right contact of relay 719, conductor 750, contacts of relay 1401, conductor 1438, winding of relay 1234 to battery. With relay 721 operated another circuit is closed over the grounded conductors 1434 and 747 through the outermost right contact of relay 721, conductor 751, contacts of 30 relay 1401, conductor 1439, winding of relay 1232 to battery.

Considering the thousands digit it will be recalled that the relay 803 of the thousands register 800 is operated while the line relays 40 804, 805 and 806 are deenergized. A circuit is, therefore, completed from ground over the conductor 1434, conductor 747, lowest back contact of relay 824, outer right 45 back contacts of relays 806, 805 and 804 in series, conductor 836, innermost upper back contact of relay 824, conductor 837, contacts of relay 1401, conductor 1440, winding of relay 1238 to battery. Relay 1238 which 50 represents the first terminal line group of 2000 subscribers' lines operates in this circuit but is ineffective since the present call is an interoffice one.

The office designation having thus been 55 transferred to the three registers 1201, 1202 and 1203, these registers now become effective to control the translator 1200, 1220 to determine the class of the call and to prepare for the group selecting operation of the 60 district selector switch. The three registers 1201, 1202 and 1203, each capable of taking any one of ten different settings according to the number of impulses in the series representing the three abbreviation letters of 65 the office designation, cooperate with each

other to provide a large number of different conditions in the translator 1200. The first register 1201, for instance, is capable of selecting any one of ten different multi-contact relays of which five such relays 1208 70 to 1212, inclusive, are shown. Relay 1208, in operating, applies ground, as will be shown hereafter, to a certain pair of horizontal conductors in the section 1223 and also applies ground to a certain horizontal 75 conductor in the section 1222. Likewise, each of the remaining relays 1209, 1210, etc., applies ground potential to a different pair of conductors in the section 1223 and also applies ground potential to a different conductor in section 1222. 80

The register 1202, representing the second letter of the office abbreviation, is capable of applying ground potential to any one of the ten horizontal conductors in the portion 85 1200 of the translator. Moreover, the third register 1203 is arranged to select any one of ten multi-contact relays of which seven, 1213 to 1219, inclusive, are shown. The contacts of each of the relays 1213, 1214, 90 1215, etc., are connected arbitrarily to the windings of a plurality of multi-contact relays, three of which, relays 1205, 1206 and 1207 are shown in the drawing. The contacts of the relays 1205, 1206 and 95 1207 are connected in arbitrary fashion to the class leads and to the other leads which terminate in the distributing rack 1239.

From the above description it will be seen that the three code registers 1201, 1202 and 1203 of the district marker cooperate with 100 each other in accordance with the office designation transmitted over the calling subscriber's line to the recording sender and then transferred to the district marker for the purpose of applying the necessary conditions to the proper ones of the conductors terminating in the distributing rack 1239 whereby class information is secured for governing the operation of the sender and 105 whereby group selection at the district switch may take place. This arrangement affords an opportunity for making changes readily in the office codes by a simple wiring operation in the district marker translator, of which there is only one for a large number of recording senders. The economical advantage of making the changes in the marker translator instead of making them 110 in each of the several different recording senders is obvious without explanation. The necessity for making such changes may arise 115 frequently in commercial practice.

The particular call now being extended, 120 namely, a full mechanical tandem call, requires the setting of the district selector and office selector switch in the calling office, switches in the tandem office, and also switches in the final office. For this purpose 125 the recording sender requires additional 130

class information and accordingly certain of the class leads in the group 1236 which co-operate with the lower section 1223 of the translator 1200, need be affected so far as 5 controlling the recording sender in concerned. Since the office selector is needed a class relay is operated in the sender to govern the sender operation accordingly. Also the sender must be informed that the 10 call leads through a tandem point, that the entire record is to be sent to the tandem office, that only one tandem point is necessary, that the called office is a mechanical one and should receive such other information 15 as is required. Where the connection is one to a distant office the talking circuit requires a maximum of loading, the translator 1200 in response to the office code influences the class conductors 1460, 1461 and 20 1263 which lead to the class horizontal link 1031 of the district selector switch 1000. It will be explained hereinafter how the translator prepares circuits over these conductors through the class horizontal link 1031 to 25 adjust the equipment in the trunk 114, illustrated in Fig. 2, for the proper talking circuit and for the necessary supervisory conditions.

Inasmuch as the relay 1225 of the register 30 1201 is operated, a circuit is completed from the grounded conductor 1116, inner left contact of relay 1106, contact of relay 1105, conductor 1125, conductor 1243, inner right contact of relay 1224, inner right front contact 35 of relay 1225, winding of multi-contact relay 1210 to battery. Relay 1210 operates and connects the horizontal conductor 1244 to the two horizontal conductors 1245 and 1246. Relay 1210 also connects the 40 horizontal conductor 1247 to the horizontal conductor 1248. With the relays 1230 and 1231 of the second register operated a circuit may be traced over the grounded conductors 1125 and 1243 to the inner right 45 back contacts of relays 1228 and 1229, inner right front contact of relay 1230, inner left front contact of relay 1231 to the horizontal conductor 1249. Moreover, with the register relays 1234 and 1232 of the third 50 register operated, a circuit is completed over the grounded conductor 1243 through the outer left contact of relay 1235, left contact of relay 1232, left back contact of relay 1233, outer left front contact of relay 1234, winding 55 of multi-contact relay 1219 to battery. Relay 1219 operates and engages its contacts respectively with each of the horizontal conductors of the portion 1200 of the translator. Since the register 1202 has applied 60 ground potential to the horizontal conductor 1249, a circuit is completed over this conductor through contacts of the relay 1219, conductor 1250, winding of multi-contact relay 1205 to battery. Relay 1205 thereupon 65 operates and connects its contacts with the

horizontal conductors in the portion 1220 of the translator.

Class indications.

Since, as hereinbefore noted, the recording sender requires certain information regarding the class of the call the particular contacts of the relay 1205, which engage the grounded horizontal conductors 1245 and 1246, are connected to the class leads on the 70 distributing rack 1239. A circuit is traceable from ground through the outer right contact of relay 1106, conductor 1132, conductor 1244, thence through the contacts of relay 1210 to conductors 1245 and 1246, 75 thence through contacts of relay 1205 and conductors 1240 and 1241, windings of relays 1450 and 1451 to battery. With relay 1451 operated a circuit is established from ground through its outermost right contact, 80 conductor 1452, contact of relay 1401, conductor 1456, winding of relay 657 to battery. Relay 657 operates and locks in a circuit from battery through its right hand winding and inner right hand contact, conductors 658 and 507 to ground. Another circuit is traceable from ground through the 85 middle contact of relay 1451, conductor 1454, contact of relay 1401, conductor 1457, winding of relay 501 to battery. Relay 501 operates and locks through its inner upper contact to the grounded conductor 506. Another circuit is closed from ground through the inner contact of relay 1451, conductor 1453, contact of relay 1401, conductor 1458 90 winding of relay 613 to battery. Relay 613 operates and locks through its inner left contact to grounded conductor 658. With relay 1450 operated a circuit is closed from ground through the middle contact of this 95 relay, thence over conductor 1455, contact of relay 1401, conductor 1459, winding of relay 502 to battery. Relay 502 operates and locks through its inner right contact to the 100 grounded conductor 506. As will be explained hereinafter, these various relays which have been operated in the sender by the translator of the district marker determine the subsequent operation of the sender in accordance with the particular class of 105 call being extended.

Where the call involves a connection through a tandem office to a distant full mechanical office, it will be necessary to have the maximum loading in the repeating coil 227 of the trunk 114 and it will also be necessary to provide for reverse battery supervision. To accomplish this a common class horizontal link 1031 is provided on each district selector switch 1000. When the vertical operating magnet 1015 operates it closes at its outer right contact a circuit for the horizontal magnet 1027. The magnet 1027 rotates its associated bar and connects the horizontal conductors 1031 to the 110 115 120 125 130

- associated contacts in the vertical row 1008. Therefore, a circuit is now traceable from ground through the outer right contact of the class relay 1450, conductor 1460, thence 5 through the upper conductor of the link 1031 to conductor 1032, winding of relay 207 to battery. Relay 207 operates and locks through its winding and lowermost contact to the grounded conductor 150.
- 10 Another circuit is closed from ground through the inner contact of class relay 1450, conductor 1461, through the middle conductor of the link 1031 to conductor 1033, through the winding of relay 206 to battery. Relay 206 operates and locks through its lowermost contact to the grounded conductor 150.

Marking the groups of trunks at the district selector switch.

- 20 With the multi-contact relay 1205 operated a circuit completed for selecting one of a number of relays 1306, 1307, 1308, 1309, etc. Each of these relays represents a 25 group of trunks outgoing from the district selector switches. Certain of these relays may be individual respectively to the different groups of trunks leading to the terminal group in the local office. Other relays 30 may be individual to the groups of trunks extending to the office selector switches 1800. Still other relays represent groups of trunks leading to special positions. The relay 1309 is the one which designates the group of trunks containing the 35 trunk 1028 leading to the particular office selector that has accesss to trunks extending to the tandem office. Hence, the following circuit for relay 1309 may be traced: 40 grounded conductors 1125, 1243, 1251, 1252 to the horizontal conductor 1247, thence through contacts of relay 1210 to the horizontal conductor 1248, contacts of relay 1205, conductor 1253, winding of relay 1309 to battery. The relay 1309 is in 45 this manner selected and operated as a result of the combined effects of the office registers to mark the group of trunks leading from the district selector switch to the 50 office switch.

Testing the selected group of trunks.

- 55 The next operation to be performed is to test the trunks of the selected outgoing group and to test the horizontal links of the particular district selector switch involved to ascertain an idle trunk in such group which is accessible to an idle one of the horizontal links.

- 60 Referring back to the time when the district marker was first connected through the sender connector 1400 to the recording sender, it will be recalled that a circuit was established for the operation of the vertical operating magnet 1015 of the particular

district selector switch 1000 in which appears the trunk 1114. In a manner about to be described the vertical operating magnet 1015 serves to associate the district selector switch 1000 with the common district marker. There are, as hereinbefore observed, a plurality of district selectors to which the marker is common. Hence, it is necessary whenever a particular one of the district selectors is appropriated for use to 70 associate the common marker with that district selector to the exclusion of all others. To this end the district selector switch 1000 is provided with three multi-contact relays 1323, 1320 and 1326, which are individual thereto. Another district selector switch, not shown, is provided with three multi-contact relays 1322, 1319 and 1325. It is the purpose of these multi-contact relays to associate the common marker with 75 the individual district selector switch. Therefore, when any one of the incoming vertical magnets, such as the magnet 1015 is operated, a circuit is closed from ground through the inner right contact of such 80 magnet, conductor 1034, thence in parallel through the windings of relays 1325, 1320 and 1326 to battery. These relays operate, and as will be explained later on, extend the operating circuits of the horizontal link 85 magnets through to the common testing relays in the marker.

90 As hereinbefore noted, when any one of the incoming vertical magnets 1015, 1016, 1017, etc., is operated, a circuit is closed through its outer right contact, conductor 1035, left hand winding of the horizontal magnet 1027. The magnet 1027 operates the bar individual to the link 1031 of the 95 district selector switch.

100 The relay 1309, in operating, completes a circuit from battery through the winding of relay 1346, conductor 1450, lowermost contact of relay 1309 to ground. The relay 1346 energizes and opens the circuit of relay 1348. The relay 1348 remains energized for an interval before it releases its armatures and after this the relay 1347, being slow to release, retains its armatures retracted for a still further interval. The 105 interval of time measured by the relays 1348 and 1347 is sufficient for associating the common testing relays 1300 and 1343 with the district selector switch 1000, for 110 selecting an idle link and outgoing trunk circuit in the proper group and for effecting a connection over such link and trunk. Relay 1348 measures the interval for testing, while relay 1347 measures the time necessary for making the connection, as will 115 be explained hereinafter. With relay 1346 operated a circuit is completed as before traced over the grounded conductor 1122, outer left front contact of relay 1346, left contact of relay 1347, conductor 1351, con- 120

- 125 65 operating magnet 1015 of the particular 130

tact of relay 1326, conductor 1352, middle lower contact of relay 1309, winding of relay 1315 to battery. Relay 1315 is individual to the selected group of outgoing trunks appearing in the upper half of the vertical row 1011 of the district selector switches. The relay 1315 associates the testing relays 1300 with the test conductors of the outgoing trunks 1029, 1028, etc., in the upper half of the vertical row 1011. The testing relay 1338 serves to test the first trunk 1029 in the group. The testing relay 1341 serves to test the second trunk 1028 and so on. Moreover, the relay 1338 is arranged to make a test of the horizontal link 1006, which has access to the outgoing trunk 1029 in the selected group. Also relay 1341 is arranged to make a test of the next horizontal link 1007 having access to the outgoing trunk 1028. To this end the relays 1338, 1341, etc., are provided with two windings, the right hand windings being employed for testing the outgoing trunks, and the left hand windings for testing the corresponding horizontal links.

At the time the marker is associated with the district selector switch 1000, it will be assumed that either the first trunk 1029 in the desired group or the link 1006 is busy, or that both are busy. If the trunk is busy a path may be traced from battery through the right hand winding of relay 1338, right contact of relay 1337, contact of relay 1315, conductor 1353 to the test conductor of trunk 1029. If the link is busy a path may be traced from battery through the left hand winding of relay 1338, outer left back contact of relay 1337, contact of relay 1323, conductor 1354 to the test conductor 1037 of the horizontal link 1006. If both link and trunk are busy both of these circuits are closed. The test relay will operate on either or both of its windings. Relay 1338 locks in a circuit from battery through its right hand winding and right contact, conductor 1355, middle right contact of relay 1346 to ground. Relay 1338 remains locked in this circuit even though the busy condition on link 1006 may subsequently be withdrawn in order to maintain undisturbed the starter circuit which will be explained presently. Relay 1338 also completes a circuit from battery through the winding of relay 1336, left contact of relay 1338 to ground over conductor 1355. Relay 1336 operates and at its outer left contact closes an energizing circuit for relay 1337. In a manner similar to this the testing relays allotted to the remaining trunks in the group and to the corresponding link circuits are operated, either due to the energization of one or the other or both of their windings, or else remain unoperated according to the conditions existing on the trunks and links. It is assumed, however, that trunk 1028 and its

link 1007 are idle and therefore test relay 1341 remains inert.

During the preparation of the testing relays, as above described, all of which takes place in a brief interval of time, the slow-to-release relay 1348 is maintaining its armatures attracted. Returning to the point where relay 1346 is operated a circuit is closed from ground through the inner left contact of relay 1346, right front contact of relay 1347, conductor 1360, innermost upper contact of relay 1309, conductor 1361, contacts of relay 1326, conductor 1362, winding of vertical magnet 1018 to battery. The magnet 1018 rotates the associated operating rod and prepares the contacts of each of the trunks in the vertical row 1011 for connection with the corresponding horizontal link circuit. Magnet 1018 also closes a circuit from ground through its contact, conductor 1040, contact of relay 1326, winding of relay 1349 to battery. Relay 1349 operates in this circuit.

As soon as the necessary time interval has expired the relay 1348 retracts its armatures and opens the circuit of relay 1347. While relay 1347 is maintaining its energization, a circuit is completed over the grounded conductor 1122 through the right contact of relay 1349, right contact of relay 1348, innermost right contact of relay 1346, conductors 1363 and 1371, contacts of relay 1315, inner left front contact of relay 1336, inner left back contact of relay 1339, winding of relay 1340 to battery. Relay 1340 attracts its armatures and closes the series start circuit for the windings of the horizontal operating magnet 1026 as follows: ground, through the left contact of relay 1349, conductors 1364 and 1372, contacts of relay 1315, right front contact of relay 1336, right back contact of relay 1339, thence through the left front contact of relay 1340, contacts of relay 1323, conductors 1358 and 1365 in parallel through the windings of the magnet 1026 to battery.

Magnet 1026 rotates the horizontal bar and thereby establishes connection between the link circuit 1007 and the incoming trunk 114 and between the link 1007 and the selected idle outgoing trunk 1028. Immediately that the link 1007 is connected to the trunk 114, a circuit is closed from battery through the right hand winding of magnet 1026, contacts of the selector switch 1000, to the grounded test conductor 150 of the trunk 114. Therefore, the horizontal magnet 1026 is locked in a holding circuit dependent upon the test conductor 150 and independent of the original operating circuits established in the common marker.

After the lapse of a second interval of time the relay 1347 retracts its armatures and opens the circuit of relay 1315. Relay 1315 releases and disconnects the testing re-

lays 1300 from the sleeve conductors of the outgoing group of trunks. Relay 1340 thereupon releases and opens the original energizing circuits of the horizontal magnet 1026. Relay 1347 also opens the circuit of the vertical magnet 1018. Magnet 1018 de-energizes and restores the associated bar to its normal position ready for another use. Relay 1347, moreover, completes a circuit 10 from ground through the inner left contact of relay 1346, right back contact of relay 1347, conductor 1121, winding of the release relay 1100 to battery.

15 *Release of the district marker.*

When relay 1100 operates it closes a temporary locking circuit for itself from battery through the winding and inner right front contact of said relay, outer left contact of relay 1101, conductor 1431 to ground at the contact of relay 1401. Relay 1100 also completes a circuit from ground through its outermost right contact, winding of relay 1104 to battery. Relay 1104, 20 which provides holding ground for the various energized relays in the district marker, is designed to be slow both in attracting and in releasing its armature. Hence, the relay 1104 does not open its contact until a 25 definite interval following the operation of relay 1100. Relay 1100, furthermore, opens the circuit of relay 1106. Relay 1106 removes ground from the conductor 1125, whereupon the relays 1225, 1230, 1231, 1232, 30 1234, 1219, and 1205 become deenergized. The release of the translator multi-contact relays opens the circuit of relay 1309, which also retracts its armatures. Relay 1309 releases and also relay 1346 which in turn 35 40 opens the locking circuits of the test relays.

While the slow relay 1104 is still in its retracted condition following the operation of relay 1100, a circuit is completed momentarily from ground over conductor 1116, 45 through the outer left contact of relay 1100, conductor 1126, contact of relay 1401, conductor 1441, winding of relay 513 to battery. Relay 513 energizes and locks in a 50 circuit from battery through its winding and inner right contact to ground over conductors 506 and 507. Relay 513, at its outer left back contact, opens the circuit, previously traced, for the vertical magnet 1015. Magnet 1015 releases the associated bar and 55 the connection through the district selector switch is now held alone by the maintained operation of the horizontal magnet 1026. Magnet 1015, on releasing, closes a circuit from battery through the winding of relay 60 65 205, inner lower front contact of relay 208, conductor 224, left back contact of magnet 1015, conductor 223, to ground through the right contact of relay 201 as traced. Relay 205 operates and locks through its left contact.

When relay 1104 finally operates it removes ground potential from conductor 1116, whereupon relays 1405 and 1101 release. Relay 1405 opens the circuit of relays 1401 and 1413, which also become de-energized. Relay 1401 opens the temporary locking circuit for relay 1100 and this relay, after an interval, retracts its armature. Relay 1100 opens the circuit of relay 1104 which becomes deenergized after the lapse 75 of a given time interval. Relay 1401, on releasing, disconnects the recording sender from the common district marker. The relay 1238 of the thousands register releases when 1106 operates. At the time the vertical operating magnet 1015 releases following the energization of relay 513, it opens the circuit hereinbefore traced for the multi-contact relays 1323, 1320 and 1326. These relays become deenergized and disconnect 80 the common district marker from the selector switch 1000.

Thus the operation of the release relay 1100, following selection by the district switch, brings about a disconnection of the 90 marker from the recording sender and also a disconnection of the marker from the selector switch. The marker being released is restored to use and may again be associated with another sender and with the 95 same or with another district selector switch.

The apparatus is now in condition to control the operation of the office selector to select an idle trunk leading to the tandem 100 office.

Association of the sender with the office marker and transfer of record.

The next phase in the operation is to connect the recording sender with the office marker shown in Figs. 19, 20 and 21 and to thereupon transfer the office record registered on the registers 700, 701 and 702 to the corresponding registers 2002, 2003, 105 and 2004 of the office marker. Relay 513, upon energizing, during the release of the district marker establishes a circuit traceable over the grounded conductor 507, conductor 509 through the inner left back contact of 110 relay 510, outer left contact of relay 511, conductor 512, inner left contact of relay 505, outer right front contact of relay 513, outer left back contact of relay 504, outer 115 right front contact of relay 502, conductor 549, winding of relay 2206 to battery. Relay 2206 operates and closes a circuit from ground through its right contact, right back contact of relay 2212, winding of relay 2211 to battery. Relay 2211 operates and locks 120 in the following circuit provided no sender in another group is attempting connection with the office marker: battery, through the winding and right contact of relay 2211, left back contact of relay 2205 and through the 125 130

left back contact of similar relays, conductor 2215, outer right back contact of relay 1901, conductor 1930, to ground at the contact of relay 1903. Relay 2211 establishes a circuit 5 from battery through the right hand winding of relay 2207, left contact of relay 2206, thence over the circuit traced to ground at the contact of relay 1903. Relay 2207 completes a circuit from battery through the 10 winding of relay 2212, to ground at the inner right contact of relay 2207. Relay 2212 closes a circuit from battery through the left hand winding and left contact of relay 2207, left back contact of relay 2210 through 15 the left back contacts of similar relays in the same group, outer left contact of relay 2212, conductor 2216, outer left back contact of relay 2204 and through the contacts of similar relays, conductor 2217, winding 20 of relay 1901 to ground over conductor 1930. Relay 1901 operates and relay 2207 locks in this circuit. A circuit is now traceable from battery through the winding of multi-contact relay 2208, outer right contact of 25 relay 2207, conductor 2218, inner left contact of relay 1901, to grounded conductor 1930. Relay 2208 operates its contacts and connects the recording sender to the common office marker.

30 Relay 1904 is energized in a circuit from battery through its winding, conductor 2214, right front contact of relay 2212, to ground at the right contact of relay 2206. Relay 1904 closes a holding circuit for relay 35 2212 traceable from battery through the winding and inner left contact of relay 2212, conductor 2219, left contact of relay 1904, to ground at the contact of relay 1905. Relay 2212 is locked while relay 2211 becomes 40 released since its circuit is opened at the right back contact of relay 1901 and also at the right back contact of relay 2212.

The arrangement of the multi-contact relays of the sender connector 2200 for the 45 office marker is substantially the same as that discussed in detail in connection with the sender connector 1400 of the district marker and it is not thought necessary to go further into the description thereof.

50 Relay 1901, in operating, closes a circuit from battery through the winding of relay 1902, inner right back contact of relay 1900, outer left contact of relay 1901, conductor 1908, contact of relay 2208 to ground.

55 Relay 1902 completes a circuit from ground through its inner right contact, conductor 1909, contact of relay 2208, conductor 2220, outer left contact of relay 502, inner left back contact of relay 504, conductor 60 556, through contacts of the sender selector switch 300, conductor 353, middle right contact of relay 205, uppermost front contact of relay 208, conductor 225, through contacts of the district selector switch 1000 65 involving link circuit 1007, tip conductor of

trunk 1028, outer left back contact of relay 1715, conductor 1716, winding of the vertical operating magnet 1813 of the office selector switch 1800 to battery. Magnet 1813 rotates the associated rod and prepares the contacts of trunk 1028 for connection with the horizontal link circuits of the office selector switch. 70

As soon as the sender is connected to the office marker a circuit is completed from ground over conductor 1930, inner left contact of relay 1902, conductors 1910 and 1911, contacts of relay 2208, conductor 2221, conductor 756, middle right contact of register relay 705, conductor 757, contact of relay 2208, conductor 2222, winding of relay 2012 to battery. Another circuit is completed from ground in the office marker over the path traced including conductor 2221, conductor 756, middle right contact of relay 712, conductor 758, contact of relay 2208, conductor 2223, winding of relay 2006 to battery. Another circuit is traceable from ground over the conductor 1908, and thence over the conductor 2221, conductor 756, 80 through the middle right contact of relay 711, conductor 759, contact of relay 2208, conductor 2224, winding of relay 2007 to battery. Another circuit leads from ground over conductor 2221, middle right contact of relay 719, conductor 761, contact of relay 2208, conductor 2226, winding of relay 2009 to battery. Still another circuit is traceable from ground over the conductor 2221, as described, conductor 756, middle right 85 contact of register relay 721, conductor 760, contact of relay 2208, conductor 2225, winding of relay 2008 to battery. 90

Marking and testing the trunks at the office selector switch. 105

With the registers 2002, 2003 and 2004 positioned in accordance with the office designation, the translator device 2000 and 2001 is operated to select one of the group relays 110 shown at the right of Fig. 21 which identifies the group of trunks leading to the tandem office. First a circuit is traceable from ground over conductor 1930 inner left front contact of relay 1902 conductors 1910 and 1911 contact of relay 1906 conductor 1912, conductor 2010, inner right back contact of relay 2005, inner left front contact of relay 2012 winding of multi-contact of relay 2014 115 to battery. Another circuit is traceable from ground over the conductor 1912, conductor 2023, outer left contact of relay 2015, left contact of relay 2008, left back contact of relay 2016, outer left front contact of relay 2009, winding of multi-contact 120 relay 2017 to battery. With relay 2017 operated a circuit is closed from ground over conductors 1912 and 2010 inner right contact of relay 2019, inner right back contact of relay 2020, inner right front con- 125 130

tact of relay 2006, inner left front contact of relay 2007 horizontal conductor 2021 of the translator 2801, contact of relay 2017, conductor 2024, winding of multi-contact relay 2025 to battery. With relays 2025 and 2014 energized, a circuit is established from ground over conductor 1910, horizontal conductor 2026, contacts of relay 2014, horizontal conductor 2027, contact of relay 2025, conductor 2028, winding of group relay 2112 to battery.

At the time the office marker is first connected to the sender a circuit is completed from ground over conductor 1930, outer right front contact of relay 1901, outer left front contact of relay 1902, conductor 1914, outer left back contact of relay 2107, winding of slow-to-release relay 2130 to battery.

Relay 2130 operates and closes a circuit from battery through the winding of relay 2109 to ground at the left contact of relay 2130. When the relay 2112 is selected and operated it closes a circuit from ground through its lowermost contact, conductor 2113, winding of relay 2107 to battery. Relay 2107 opens the circuit of relay 2130 but this latter relay being slow holds its armatures attracted for an interval of time. During this interval a circuit is established from ground over conductor 1914 as above traced, outer left front contact of relay 2107 left contact of relay 2109, conductor 2114, contact of relay 2173, conductor 2115, middle lower contact of relay 2112, winding of multi-contact relay 2111 to battery.

It will be noted that relay 2173 is energized at this time. This relay, together with relays 2132 and 2131, is operated in a circuit from battery through their windings in parallel, conductor 2116, to ground at the contact of magnet 1813.

Relay 2112 is individual to the row 1811 of the office selector switch 1800 containing the desired group of trunks and serves to associate the upper set 2106 of testing relays in the marker with the respective trunks of said group. Another circuit is closed from ground through the inner left contact of relay 2107, right front contact of relay 2109, conductor 2117, innermost upper contact of relay 2112, conductor 2118, contact of relay 2173, conductor 2119, winding of the magnet 1816 to battery. Magnet 1816 rotates the associated bar and prepares the contacts of the trunks in the vertical row 1811 for connection with the horizontal link circuits. The magnet 1816, in operating closes a circuit from ground over its contact, conductor 1828, contact of relay 2173, conductor 2120, winding of relay 2108 to battery.

When the multi-contact relay 2111 is operated the double wound test relays 2121, 2122 and 2133 are associated respectively, with the horizontal links 1806, 1807, etc., in

the upper group 1802 and with the outgoing trunks 1829, 1823, etc., in the upper section of the row 1811. In the manner already described in connection with the testing relays of the district marker, the double wound relays 2121, 2122, 2133, etc., are operated over one winding or the other, according as the corresponding link circuits and outgoing trunks are busy. Assuming that the link 1806 or the trunk 1829 is busy, or both are busy, the testing relay 2121 is operated. Assuming that the next link 1807 and the corresponding outgoing trunk 1823 are both idle, the next successive relay 2122 remains inert. Relay 2121, in operating locks in a circuit from battery through its right hand winding and right contact, conductor 2124, to ground at the middle right contact of relay 2107. Relay 2121 closes a circuit from battery through the winding of relay 2125, left contact of relay 2121, to ground over conductor 2124. Relay 2125, at its outer left front contact, closes an energizing circuit for relay 2126.

After the necessary interval has elapsed, relay 2130 releases and a circuit may now be traced from ground over conductor 1914, inner right contact of relay 2108, right contact of relay 2130, innermost right contact of relay 2107, conductor 2127, contact of relay 2111, inner left front contact of relay 2125, inner left back contact of relay 2128, winding of relay 2129 to battery. Relay 2129 operates and a circuit may now be traced from ground through the left contact of relay 2108, conductor 2134, contact of relay 2111, right front contact of relay 2125, right back contact of relay 2128, left front contacts of relay 2129, contacts of relay 2131, conductors 2135 and 2136, windings of horizontal magnet 1822 to battery. The magnet 1822 operates the associated bar and the trunk 1028 is connected through the horizontal link 1807 to the outgoing trunk 1823 leading to the distant called office.

The instant the trunk 1028 is connected to the horizontal link 1807 and while the office marker is associated with the office switch 1800, a circuit is closed from ground at the left contact of relay 2108, and thence, as above traced, over conductor 2135, contacts of the office switch 1800 in the row 1808, sleeve conductor 1830, winding of relay 1715 to battery. Relay 1715 operates and locks through its winding and right contact to the grounded sleeve conductor 1717. At its left contact relay 1715 completes the tip and ring conductors of the trunk 1028 through the office selector switch. At its right contact relay 1715 extends the grounded sleeve conductor 1717 over the sleeve conductor 1830 to the office selector switch, whereby the horizontal magnet 1822 is held operated after the office marker is discharged. Relay 1715, at its outer left back contact, opens

the circuit of the vertical magnet 1813 and this magnet releases to restore the vertical operating bar. Magnet 1813, in releasing, opens the circuit of multi-contact relays 2131, 2132 and 2173 and these relays in turn disassociate the common office marker from the office selector switch 1800.

Release of the office marker.

10 After an interval following the release of relay 2130, the slow relay 2109 becomes de-energized and in so doing opens the circuit of multi-contact relay 2111, whereupon the testing relay set 2106 is disconnected from 15 the outgoing group of trunks. All energized relays in this set are now released. With relays 2173 and 2109 released, the circuit of magnet 1816 is opened and this magnet restores the operating rod associated 20 with the row of contacts 1811. The connection through the office selector switch 1800 is now held solely by the maintained energization of the horizontal magnet 1822.

Relay 2109, in releasing, completes a circuit from ground through the inner left contact of relay 2107, right back contact of relay 2109, conductor 2138, winding of release relay 1900 to battery. Relay 1900 operates and closes a circuit from battery 25 through the winding of relay 1903, to ground at the outer right contact of relay 1900. Relay 1903 being slow to operate and slow to release does not attract its armature until after a definite interval of time has expired. Relay 1900 locks in a circuit from battery through the winding and inner right front contact, outer left contact of relay 1901, conductor 1908, to ground at the contact of relay 2208. Relay 1900 opens the 30 circuit of relay 1902 which opens the circuits of relays 2012, 2006, 2007, 2008, 2009, 2014, 2017 and 2025. Also the circuit of relay 2112 is opened at this time resulting in the deenergization of relay 2107. After an 35 interval the relay 1903 operates and opens the circuit of relays 1901 and 2207. Relay 2207 releases and opens the circuit of relay 2208. Relay 1901 releases and opens the circuit of relay 1900. Relays 2212 and 1904 40 may also be released at this time. The relay 2208, on deenergizing, disconnects the common office marker from the recording sender and this marker may now be associated with any other of the recording 45 senders.

Prior to the disconnection of the office marker and during the interval relay 1903 is holding its armature retracted, a circuit is established from ground through the contact of relay 1903, conductor 1930, outer left contact of relay 1900, conductor 1915, contact of relay 2208, conductor 2228, winding of relay 504 to battery. Relay 504 operates and locks in a circuit from battery 50 through its winding and inner right con-

tact, to ground over conductors 506 and 507.

Transfer of the record from the recording sender in the originating office to the recording sender at the tandem office.

Immediately that the calling subscriber's line is extended over the interoffice trunk 1823 to the tandem switching center, the recording sender in the originating office is prepared to transmit code impulses representing the office designation and the numerical designation of the wanted subscriber's line over the trunk to a register sender located at the tandem office.

The energization of relay 604 is one of the first steps in preparing the sender to transmit code impulses over the interoffice trunk. This relay is operated over a circuit from battery through its winding, conductor 668, inner lower contact of relay 501, outer left front contact of relay 504, outer right front contact of relay 513, inner left contact of relay 505, conductor 512, outer left contact of relay 511, inner left back contact of relay 510 to ground over conductors 509 and 507. Relay 604 operates and locks through its left contact to the grounded conductor 507.

As hereinbefore mentioned the apparatus at the tandem office is arranged to take note of the length of the trunk over which a connection has been extended from the originating office. This is done by a proper circuit connection in the sender selector switch 2500 as will be fully explained here later. If the length of the trunks incoming to the tandem office and appearing in the sender selector switch 2500 is less than a given value, a circuit connection individual to each such trunk will cause an indication to be produced in the sender which taken in conjunction with certain class information regarding the length of the trunk outgoing from the tandem point determines the operations of the tandem sender. In the present case where the trunk is assumed to be comparatively long, this indication is omitted. Moreover, since the outgoing trunk from the tandem point to the called office is also in excess of the arbitrary value, the class information is also omitted.

Returning now to the point where relay 604 of the originating office operates, a circuit is established from battery, through the winding of relay 2304 in the tandem office, left back contacts of relay 2303, inner right back contact of relay 2302, upper back contact of relay 2300, thence over the tip conductor of trunk 1823, through the office and district switches in the calling office, uppermost front contact of relay 208, middle right contact of relay 205, conductor 353, thence through the sender selector 300, conductor 556, inner right contact of relay 604, outer right contact of relay 606, winding of relay

- 607, inner right contact of relay 606, outer right contact of relay 604, conductor 524, thence through the sender selector 300, conductor 355, outer right contact of relay 205, 5 lowermost front contact of relay 208, thence over the ring conductor of the trunk to the tandem office and through the lower back contact of relay 2300 to ground at the outer left back contact of relay 2302. Relay 607 10 at the originating office operates and a circuit is closed from battery through the winding of relay 608, left back contact of relay 661, inner front contact of relay 607, conductor 609, left contact of relay 610, conductor 658 to the grounded conductor 507. Relay 608 operates and locks to the grounded conductor 609. Relay 2304 also 15 operates and closes a circuit from ground over conductor 2306, winding of relay 2513 to battery. Relay 2513 operates and completes a circuit from battery through the winding of relay 2515, right back contact of relay 2514, left contact of relay 2513 to ground through the winding of relay 2518. 20 In a manner substantially identical to that described in connection with the apparatus shown in Figs. 1 and 3, the relays 2514, 2515, 2516, 2517, 2518, 2519, 2520, 2521, 2522 and 2523 are brought into action to control the 25 sender selector switch 2500 for establishing a connection between the incoming trunk 1823 and an idle register sender such as the one illustrated in Figs. 26 to 29, inclusive. In the manner explained, circuits are completed 30 for the vertical magnet 2529 controlling the contacts in the row 2501 and for the vertical magnet 2531 controlling the contacts of the row 2504. The magnet 2531 in operating completes a circuit from ground through its 35 outer contact, conductor 2532, winding of slow-to-release relay 2667 to battery. Relay 2667 energizes and locks in a circuit through its inner left contact and back contact of relay 2668 to ground. Relay 2667 at its 40 outer left contact closes a circuit for relay 2663.
- The vertical magnet 2531 also closes a circuit for the stepping magnet 2524 and the allotter switch 2526 is advanced whereby the 45 relay 2523 operates and a circuit is completed for the horizontal magnet 2510 of the first idle link 2507 of the selector switch 2500. The switch is operated and the incoming trunk is extended through the link 2507 to the 50 idle register sender. After an interval the slow relay 2522 releases and the vertical magnets 2529 and 2531 are deenergized and the connection is held by the continued energization of horizontal magnet 2510. The 55 circuit for holding this magnet energized may be traced from battery through its winding and the winding of relay 2509, thence through contacts of the switch, conductor 2532, left contact of relay 2667 to 60 ground.

With the sender selector switch operated, another circuit is completed from battery through the winding of relay 2302, conductor 2308, contacts of the sender selector switch to the grounded conductor 2532. Relay 2302 operates and opens the circuit of relay 2304 whereby relay 2513 releases and restores the operating relays associated with the sender selector switch. Relay 2302 also closes a circuit for slow-to-release relay 2303. Relay 2302 in disconnecting battery and ground from the tip and ring conductors of the trunk opens the circuit of relay 607 in the originating office. Relay 607 releases and a circuit is closed from battery through the winding of relay 606, inner right front contact of relay 608, inner right back contact of relay 607 to the grounded conductor 609. Relay 606 operates and locks to the grounded conductor 609. Moreover, relay 2302 extends the tip and ring conductors of the trunk 1823 through the sender selector switch 2500 to the register sender. This circuit may be followed from the tip conductor of the trunk 1823, through the upper back contact of relay 2300, inner right front contact of relay 2302, conductor 2309, through the sender selector, conductor 2534, outer right back contact of relay 2673, winding of relays 2674, 2675 and 2676, left back contact of relay 2673, conductor 2535, through the sender selector, conductor 2310, outer left front contact of relay 2302, lower back contact of relay 2300, through the ring conductor of the trunk 1823. The equipment is now in condition for transmitting code impulses over the line circuit to the tandem office for setting the registers of the sender therein. The code impulses are sent to the sender mechanism over a full metallic circuit comprising both tip and ring sides of the line in series. These impulses may be, however, positive or negative in polarity dependent upon the pole of battery that is connected to a given side of the line. They may also be weak or strong dependent upon whether a high or low resistance is included in the circuit. Relay 2676 at the tandem office is polarized in such a manner as to respond only when a current of positive polarity flows over the ring side of the line, that is, over conductor 2535. The relay 2675 is polarized in such a manner as to respond to current of the opposite polarity. Both relays 2676 and 2675 respond either to strong or weak impulses provided the polarity is in the proper direction. Relay 2674 responds to strong impulses only whether they be of positive or negative polarity. This relay being marginal does not operate on weak impulses. The relays 615 and 616 cooperate with each other to measure intervals of time during which the code impulses are produced and transmitted over the line circuit to the

distant office. Due to the characteristics of these relays they operate and release slowly. The relays 617, 618, 619 and 620 operate in a definite sequence and their function is to measure a sufficient number of periods of code impulses to represent each of the different letters and digits.

At the time relay 608 operates it closes a circuit from ground through its outer right contact, conductor 612, thence through the outer left contacts of relays 808, 818, etc., and through the outer left contacts of the corresponding relays 820, 822, etc., conductor 841, left front contact of relay 657, winding of relay 614 to battery. It will be noted that the parallel branches of the energizing circuit of relay 614 extend through the outer left back contacts of relays 820, 822, 920, etc., so that the relay 614 having operated over any one of these branches will remain energized so long as any one of them is closed. In the case of the units register 901, this circuit does not extend through a back contact of relay 922 so that when relay 927 operates the circuit of relay 614 remains closed until the sender is discharged.

Relay 614, upon operating, completes a circuit from ground through the right contact of relay 608, inner left contact of relay 614, conductor 624, inner right back contact of relay 619, conductor 625, inner right contact of relay 617, outer right back contact of relay 618, left back contact of relay 619, left hand winding of relay 620, left hand winding of relay 619 to battery. Relay 619, being marginal, does not receive sufficient current through its left hand winding in series with the winding of relay 620 to operate. Relay 620, however, attracts its armatures and closes a circuit from battery through the left hand winding of relay 619, left hand winding of relay 620, right hand winding of relay 619, inner right contact of relay 620 to ground over conductors 658 and 507. Relay 619, however, still remains deenergized since its right hand winding is shunted by the circuit previously traced to ground over conductor 624. Relay 620 completes a circuit from ground through its outer right contact, contact of relay 621, middle left front contact of relay 613, conductor 669, outer right back contact of relay 725, winding of relay 726 to battery. Relay 726 operates and closes a circuit from battery through its winding and inner lower contact, conductor 771, winding of relay 621 to ground at the contact of relay 620. Relay 621 being shunted by the circuit above traced does not operate at this time. Relay 726 at its upper contacts connects certain control conductors to the relays of the first register 700.

Relay 614 also closes a circuit from bat-

tery through the resistance 630, winding of relay 615, left back contact of relay 616, conductor 631, outer left contact of relay 614, outer left contact of relay 606 to ground. Relay 615 operates and locks through its winding, inner right front contact to ground over conductor 631 as traced. Relay 615 closes a circuit from battery through the resistance 632, winding of relay 616, inner left contact of relay 615 to the grounded conductor 631. Relay 616 operates and closes a circuit from battery through resistance 630, middle right contact of relay 616 to the grounded conductor 631. This circuit is in shunt of relay 615 and this latter relay commences to release. Relay 616 also closes a circuit from battery through the winding and normal contact of relay 633, outermost right front contact of relay 616 to the grounded conductor 631. Relay 633 operates and locks through its left hand make-before-break contact to the grounded conductor 631. Relay 615, upon releasing, closes a circuit from battery through the resistance 632, right back contact of relay 615 to the grounded conductor 631. This circuit shunts the winding of relay 616 and this latter relay thereupon commences to release. In this manner the relays 615 and 616 successively operate each in turn shunting the other and thereupon successively deenergizing.

During the period measured by the release of the relays 615 and 616 which follows the operation of relay 633, a circuit is prepared for the transmission of an impulse over the line in case the first register relay 703 of the register 700 is operated. When the relay 633 operates at the beginning of this period it closes a circuit from ground through its outer right contact, conductor 638, middle right contact of relay 614, conductor 639, outer normal contact of relay 640, outer right contact of relay 604, thence over the ring conductor 524 to the distant tandem office and returning over the tip conductor 556, through the inner right contact of relay 604, inner normal contact of relay 640, left back contact of relay 618, conductor 641, outer right contact of relay 614, outer right front contact of relay 613, conductor 670, left back contact of relay 725, thence to the outer left contact of relay 703. Since the relay 703 is not operated, the circuit is open at this point and no impulse is transmitted during the first period.

When relay 616 releases, a circuit is closed from battery, through the resistance 647, winding of relay 640, outer left contact of relay 615, inner right back contact of relay 616, inner right contact of relay 633 to the grounded conductor 631. Relay 640 operates and reverses the connection of the tip and ring conductors of the line cir-

cuit to the impulse sending mechanism. Relay 640 also closes a locking circuit for itself from battery through its winding and right contact to ground over conductor 631.

5 Relay 616 on releasing also establishes a circuit from ground over conductor 631, outer right back contact of relay 616, outer left contact of relay 633, conductor 643, left back contact of relay 617, left hand windings of 10 relays 618 and 617 to battery. Relay 617 being marginal does not receive sufficient current through its left hand winding to operate in series with relay 618. Relay 618, however, attracts its armatures and a circuit is closed from battery through the left hand winding of relay 617, left hand winding of relay 618, right hand winding of relay 617, inner right front contact of relay 618 to ground over conductor 507. Although both windings of relay 617 are included in this circuit, the relay is shunted due to the direct ground applied to the conductor 643 as above traced. Therefore, relay 617 still remains deenergized. Relay 25 618, on attracting its armatures, opens the shunt circuit which has been maintained around the right hand winding of relay 619. Relay 619 operates in series with relay 620 in the circuit already described.

30 Relay 619 establishes a circuit from ground over conductor 507, middle right contact of relay 619, conductor 645, lowermost contact of relay 726, winding of relay 725 to battery. Relay 725 operates and locks 35 through its inner right contact, conductors 736, 737 and 738 to ground. Relay 725 at its outer right contact opens the shunt around the winding of relay 621 and this latter relay operates in series with relay 40 726.

The next action to take place is the re-operation of relays 615 and 616 which measure a second interval for the transmission of an impulse over the line circuit provided the proper register relay of the register 45 700 is operated. Immediately that relay 616 releases its armatures, the above traced circuit for relay 615 is closed and this latter relay reoperates. Relay 615, in operating, closes the circuit traced for relay 616 which relay also attracts its armatures again. During the operating interval of 50 relays 615 and 616 a path may be traced from ground through the outer right contact of relay 633, conductor 638, middle right contact of relay 614, conductor 639, inner left contact of relay 640, inner right contact of relay 604, thence over the tip side of the line through the windings of relays 55 624, 2674, 2675 and 2676, returning by way of the ring side of the line to conductor 524, outer contact of relay 604, middle front contact of relay 640, conductor 646, high resistance 673, to the opposite pole of battery.

60 65 The polarity of the current flowing through this circuit is such as to cause the operation of relay 2675. Due to the inclusion of the high resistance 673, the marginal relay 2674 remains inactive. Relay 2675 completes a circuit from ground through the right contact of relay 2667, conductor 2682, conductor 2683, contact of relay 2675, left back contact of relay 2678, left hand windings of relays 2679 and 2678 to battery. Relay 2679 operates, but relay 2678 being marginal remains 70 deenergized. Relay 2679 completes a circuit from battery through the left hand windings of relays 2678 and 2679, right hand winding of relay 2678, inner right contact of relay 2679 to ground over conductors 75 2684 and 2682. Relay 2679 completes a circuit from the grounded conductor 2684, through its outer right contact, conductor 2685, lower back contact of relay 2730, winding of relay 2731 to battery. Relay 2731 80 operates and closes a circuit from battery through its winding and the winding of relay 2730, upper contact of relay 2731 to the grounded conductor 2684. Relay 2730, however, is shunted and does not operate at 85 this time. When relay 616 operates it closes a circuit from battery through the resistance 647, conductor 648, middle left contact of relay 633, outermost right front contact of relay 616 to the grounded conductor 631. 90 This circuit shunts the winding of relay 640 and said relay retracts its armatures thus interrupting the impulse of current being transmitted over the line circuit. In response to the interruption of the impulse, relay 2675 releases and removes ground from the left back contact of relay 2678. The removal of this ground permits the relay 2678 to operate in series with relay 2679. Moreover, relay 616 in operating opens its outer 95 100 right back contact and removes ground from the conductor 643. This removes the shunt from around the right hand winding of relay 617 and said relay operates in series with relay 618. Relay 616, in operating, 105 shunts relay 615 and this latter relay becomes deenergized, in turn, shunting and releasing relay 617. During the releasing period of relays 615 and 616, with relay 640 deenergized, a path may be traced from 110 ground over conductor 639 as above explained, left normal contact of relay 640, thence over the ring side of the line through the polarized and marginal relays at the tandem office and returning over the tip side 115 of the line through the inner normal contacts of relay 640, left front contact of relay 618, conductor 649, middle upper contact of relay 726, outer left contact of relay 705, conductor 646, resistance 763 to the opposite 120 pole of battery. The polarity of this impulse is such that relay 2676 responds, while due to the high resistance 763, the marginal relay 2674 remains deenergized. Relay 2676 completes a circuit from the grounded con- 125 130

ductor 2683, through the contact of said relay, left front contact of relay 2679, conductor 2686, inner lower front contact of relay 2731, inner lower back contact of relay 2732, conductor 2733, winding of relay 2734 to battery. Relay 2734 operates and locks to the grounded conductor 2684.

When relay 616 releases it completes a circuit from battery through the winding of relay 640, outer left back contact of relay 615, innermost right contact of relay 616, inner right contact of relay 633 to the grounded conductor 631. Relay 640 operates and locks as above described and opens the line circuit to interrupt the impulse being transmitted thereover. In addition, relay 616 completes a circuit from ground through the conductor 631, outermost right back contact of said relay, outer left contact of relay 633, conductor 643, left front contact and left hand winding of relay 617 to battery. Relay 617 is held in this circuit and relay 618 is shunted and becomes released. Relay 640 in interrupting the impulse over the line circuit causes the release of relay 2676.

The next period is measured by the energization of relays 615 and 616 which takes place in the manner already described. During this period, the circuit hereinbefore traced is closed from ground over conductors 638 and 639, thence over the tip side of the line through the relays 2674, 2675 and 2676 and returning over the ring side of the line through the resistance 763 to battery. In response to this impulse, relay 2675 energizes in the tandem office. Relay 2675 closes a circuit from the grounded conductor 2683, through its contact, left front contact of relay 2678, left hand winding of said relay to battery. This circuit holds relay 2678 operated and shunts relay 2679. Relay 2679, in releasing, opens the shunt around relay 2730, but this shunt is now maintained over a path through the inner right contact of relay 2678 to the grounded conductor 2683. Consequently, relay 2730 remains deenergized. When relay 616 operates it closes the above traced shunt circuit through the resistance 647, around the winding of relay 640, and this latter relay releases its armatures. Furthermore, relay 616 at its outer right back contact opens the holding circuit of relay 617 which thereupon becomes deenergized. With relays 617 and 618 released, a circuit may be traced from battery through the left hand winding and left front contact of relay 619, outer right contact of relay 618, inner right contact of relay 617, conductor 625, inner right front contact of relay 619, inner right contact of relay 620 to the grounded conductor 507. Relay 620 is shunted by this circuit and releases its armatures. Relay 620 at its outer right contact opens the holding circuit

of relays 621 and 726. Relay 726 releases and disconnects the impulse circuit from the register 700. Relay 620 at its inner right contact opens the circuit of relay 619, whereupon this relay retracts its armatures. When relay 640 releases and opens the impulse circuit, the relay 2675 at the tandem point becomes deenergized. Relay 2675 removes ground from the left front contact of relay 2678 and this latter relay becomes deenergized. Relay 2678 opens the shunt around the winding of relay 2730 which thereupon operates in series with relay 2731. With relays 2731 and 2730 operated, the impulse circuit incoming to the tandem office is associated with the next register 2701 of the tandem sender. The code impulses representing the second letter of the office designation will now be transmitted. With relays 617, 618, 619 and 620 all released, the energizing circuit of relay 620 is immediately closed as above traced and this relay operates. Relay 620 completes a circuit from ground through its outer right contact, back contact of relay 621, middle left front contact of relay 613, conductor 669, outer right front contact of relay 725, outer right back contact of relay 727, winding of relay 728 to battery. Relay 728 operates and locks through its inner lower contact, conductor 771 and the winding of relay 621. Relay 621, however, is shunted and remains deenergized. Relay 728 connects the impulse circuit to the second register 701.

During the interval measured by the deenergization of relays 615 and 616, a circuit is completed from ground, over conductor 639, thence over the ring side of the line through the polarized relays of the tandem office and returning over the tip side of the line through the inner normal contact of relay 640, left back contact of relay 618, conductor 641, outer right contact of relay 614, outer right front contact of relay 613, conductor 670, left front contact of relay 725, left back contact of relay 727, middle left contact of relay 711, high resistance 763 to the opposite pole of battery. An impulse is transmitted in this circuit of the proper polarity to cause the operation of relay 2676 at the tandem office. Relay 2676 closes a circuit from ground over conductor 2683, through the contact of said relay, left back contact of relay 2679, conductor 2687, lower front contact of relay 2731, lower back contact of relay 2732, winding of relay 2735 to battery. Relay 2735 operates and locks to the grounded conductor 2684.

After an interval relays 615 and 616 become deenergized and relays 640, 619 and 618 become energized in the manner above described. Relay 619 closes a circuit from the grounded conductor 507, through its outer right contact, conductor 645, lowermost contact of relay 728, winding of relay

727 to battery. Relay 727 operates and locks to the grounded conductor 737. Relay 727 opens the shunt around relay 621 which operates in series with relay 728. Relay 640, in operating, discontinues the impulse being transmitted and locks to ground through its right contact. Upon the discontinuance of the impulse, the polarized relay 2676 at the tandem office becomes deenergized. Following the regular order relays 615 and 616 are energized in succession. During the interval measured by these relays for energizing, a circuit is traceable from ground over conductors 638 and 639, through the inner front contact of relay 604, thence over the tip side of the line and returning over the ring side of the line through the middle front contact of relay 640, thence through the outermost contact of relay 640, conductor 680, outer right back contact of relay 617, conductor 652, innermost upper contact of relay 728, middle left contact of relay 712, low resistance 764 to the opposite pole of battery. The current from this circuit is of the proper polarity to operate polarized relay 2675 and due to the low resistance 764, the marginal relay 2674 operates. Relay 2675 closes a circuit from the grounded conductor 2683, through the contact of said relay and thence through the windings of relays 2678 and 2679, in the manner described, whereupon relay 2679 is energized. A circuit is now closed from the grounded conductor 2684, through the outer right contact of relay 2679, conductor 2685, lower front contact of relay 2730, lower back contact of relay 2736, winding of relay 2732. Relay 2732 operates and prepares a circuit for relay 2736, the latter relay remaining deenergized due to the shunt around its winding closed by the relay 2679. Another circuit is closed from the conductor 2683 to the contact of relay 2674, outer right back contact of relay 2678, thence through the upper front contact of relay 2730, outermost back contact of relay 2736, winding of relay 2737 to battery. Relay 2737 operates and locks to the grounded conductor 2684. When relays 616 and 615 have operated, ground is removed from the conductor 643 and relay 617 operates in series with relay 618. Moreover, relay 616 closes the shunt around relay 640 which becomes deenergized and interrupts the impulse being sent over the line. The interruption of the impulse circuit causes the release of relays 2674 and 2675. Relay 2675, in releasing, permits relay 2678 to operate in series with relay 2679. Relay 2675 releases ground from the left back contact of relay 2678 and this relay operates in series with relay 2679.

Relays 615 and 616 again become deenergized in succession causing the release of relay 618 and the operation of relay 640 in

the manner explained. During this interval, however, no impulse is transmitted over the circuit.

Next relays 615 and 616 operate successively and during the interval required for this purpose, an impulse circuit is closed from the positive pole of battery over conductors 638 and 639 as traced, thence over the tip side of the line and returning over the ring side through the middle front contact of relay 640, thence over conductor 646, through the high resistance 763 to the opposite pole of battery. Due to this impulse, relay 2675 operates and a circuit is closed from the grounded conductor 2683, through the contacts of said relay to the left front contact of relay 2678. Relay 2678 remains energized while relay 2679 being shunted becomes released. Relay 616, in operating, removes ground from conductor 643 and relay 617 deenergizes. With relays 617 and 618 released the above traced circuit is closed for shunting relay 620. Relay 620, in releasing, opens the circuit of relay 619. Moreover, relay 616, in operating, closes the shunt around relay 640 and this latter relay becomes deenergized. Relay 620, in releasing, opens the circuit of relays 621 and 728. With relay 640 deenergized, the impulse circuit is opened and relay 2675 releases to, in turn, cause the release of relay 2678. Relay 2678 removes the shunt around the winding of relay 2736 and this relay operates in series with relay 2732. With relays 617, 618 and 619 released, the relay 620 is immediately energized in the manner above described. The apparatus is now in condition to transmit codes of impulses representing the third letter of the office designation. Relay 620, in operating, completes a circuit from ground through its outer right contact, contact of relay 621, thence as above traced over conductor 669, through the outer right front contacts of relays 725 and 727, outer right back contact of relay 729, winding of relay 730 to battery. Relay 730 operates and closes a holding circuit through its winding and lower contact, over conductor 771, through the winding of relay 621. Relay 621, however, remains deenergized for the time being.

After relays 615 and 616 have become released, relays 618, 619 and 640 are operated as above explained. When relay 619 operates it closes the circuit traced over conductor 645, thence through the lower contact of relay 730, winding of relay 729 to battery. Relay 729 operates and removing the shunt permits relay 621 to energize in series with relay 730.

During the succeeding period, while relays 615 and 616 are energizing in succession and while the reversing relay 640 is operated, a circuit is traceable from ground over conductors 638 and 639, front contact of relay 640 in

640, over the tip side of the line and returning over the ring side of the line, through the middle front contact of relay 640, thence through the outer left contact 5 of relay 640, conductor 680, outer right back contact of relay 617, conductor 652, inner upper contact of relay 730, middle left contact of register relay 719, low resistance 764 to the opposite pole of battery. The im- 10 pulse transmitted over this circuit causes the operation of relay 2675 and being heavy in character also operates the relay 2674. Relay 2675 causes the operation of relay 2679 in the manner described. Relay 2674 com- 15 pletes a circuit from the grounded conductor 2683, through its contact and thence through the outer right back contact of relay 2678, upper front contact of relay 2730, upper front contact of relay 2736, inner lower back 20 contact of relay 2738, winding of relay 2739 to battery. Relay 2739 operates and locks to the grounded conductor 2684. Relay 2679 completes a circuit through its right contact, from the grounded conductor 2684, 25 thence over conductor 2685, lower front contacts of relays 2730 and 2736, lower back contact of relay 2738, winding of relay 2740 to battery. Relay 2740 operates and prepares a locking circuit in series with the winding 30 of relay 2738, this latter relay, however, remaining deenergized due to the shunt around its winding. When relays 615 and 616 have operated, relay 617 operates as explained and relay 640 releases. Relay 640 inter- 35 rupts the impulse circuit causing the deener- gization of relays 2674 and 2675. Relay 2675 removing the shunt, permits relay 2678 to energize in series with relay 2679.

During the next interval, relays 615 and 40 616 again release, at the end of which time, relay 618 releases and relay 640 again operates all in the manner as above explained.

Next relays 615 and 616 become energized 45 in succession and during the period required for this purpose a circuit is completed from ground, over conductors 638 and 639 as traced, thence through a front contact of relay 640, over the tip side of the line and returning over the ring side of the line 50 through the middle left front contact of relay 640, thence through the outer left contact of said relay, conductor 680, outer right front contact of relay 617, conductor 654, uppermost contact of relay 730, middle left 55 contact of relay 721, low resistance 764 to the opposite pole of battery. The impulse in this circuit causes the operation of relays 2674 and 2675. Relay 2675 shunts the relay 2679 which becomes deenergized, the relay 60 2678 remaining energized and maintaining the shunt around the winding of relay 2738. Relay 2674 completes a circuit from the grounded conductor 2683, through the contact of said relay, outer right front contact 65 of relay 2678, thence through the inner

lower contact of relay 2730, inner lower contact of relay 2736, upper contact of relay 2738, winding of relay 2741 to battery. Relay 2741 operates and locks to the grounded conductor 2684. 70

When relays 615 and 616 have completely energized, relays 617, 620, 619 and 640 become deenergized. Relay 640, in releasing, opens the impulse circuit and causes the release of relays 2674 and 2675. Relay 2675 75 opens the holding circuit of relay 2678 which releases and opens the shunt around relay 2738. Relay 2738 operates in series with relay 2740 and a circuit leading to the grounded conductor 2684. Relay 2738 closes 80 a circuit for relay 2743.

Thus the office code consisting of three digits representing the abbreviation letters has been transmitted from the sender in the originating office to the corresponding reg- 85 istrars of the sender at the tandem point. Inasmuch as the call being considered involves the full transmission of the record from the originating office to the tandem office, the impulse mechanism continues to function to send out code impulses cor- 90 responding to the numerical portion of the designation.

With relays 617, 618, 619 and 620 released, a circuit is again prepared for relay 620 95 which operates and closes the above traced circuit from ground, over conductor 669, through the outer right front contacts of relays 725, 727 and 729, thence over conductor 765, outer right front contact of relay 657, conductor 626, inner left back contact of relay 603, outer right back contact of relay 623, conductor 651, outer right back contact of relay 820, winding of relay 821 to battery. Relay 821 operates and closes a 105 locking circuit through its winding and inner lower contact, thence over conductor 771 as herebefore traced, through the winding of relay 621 to ground. Relay 621 being shunted by the circuit previously traced does 110 not operate. Relay 821 connects the impulse circuit to the thousands register 800.

While relays 615 and 616 are deenergizing, a circuit is completed from the positive pole of battery, over conductors 638 and 639, 115 thence over the ring side of the line and returning over the tip side of the line through the inner normal contact of relay 640, left back contact of relay 618, conductor 641, outer right contact of relay 614, outer right 120 front contact of relay 613, conductor 670, left front contacts of relays 725, 727 and 729 right back contact of relay 603, inner left back contact of relay 820, inner left contact of relay 803, conductor 842, high 125 resistance 763 to the opposite pole of battery. The impulse flowing in this circuit causes the operation of relay 2676 at the tandem office, which in turn, closes a circuit from the grounded conductor 2683, through 130

its contact, left back contact of relay 2679, conductor 2687, thence through the lower front contacts of relays 2731, 2732 and 2740, lower back contact of relay 2810, winding of 5 relay 2811 to battery. Relay 2811 operates and locks to the grounded conductor 2684.

Relays 615 and 616, in releasing, also cause the operation of relays 618, 619 and 640. Relay 619, in operating, closes the circuit above traced over conductor 645, through the inner lower contact of relay 821, winding of relay 820 to battery. Relay 820 operates and locks to the grounded conductor 737. Relay 640 interrupts the 10 impulse circuit causing the release of relay 2676.

During the next interval relays 615 and 616 operate successively and a circuit is closed from the grounded conductor 639, 20 through the inner left contact of relay 640, over the tip side of the line and returning over the ring side of the line through the middle front contact of relay 640, conductor 646, high resistance 763 to battery. The 25 impulse in this circuit causes the energization of relay 2675, which in the manner explained, causes the operation of relay 2679. Relay 2679 closes a circuit from the grounded conductor 2684 through its outer right 30 contact, conductor 2685, lower front contacts of relays 2730, 2736, and 2738, lower back contact of relay 2812, winding of relay 2810 to battery. Relay 2810 operates and closes a holding circuit for itself and relay 35 2812, but relay 2812 being shunted for the time being remains deenergized. When relays 615 and 616 operate, relay 617 energizes and relay 640 releases. Relay 640 interrupts the impulse circuit causing the release 40 of relay 2675. The release of relay 2675 permits relay 2678 to operate in series with relay 2679.

Next the relays 615 and 616 release, whereupon relay 618 becomes deenergized and relay 640 operates.

Following this relays 615 and 616 operate in succession, during which period, a circuit is closed from ground or the positive pole of battery, over conductor 639, thence over 50 the tip side of the line and returning over the ring side of the line, conductor 646, through the high resistance 763 to the opposite pole of battery. The impulse in this circuit causes the operation of relay 2675 which shunts the relay 2679. When relays 615 and 616 have operated, relays 617, 620, 619 and 640 all become released. Relay 640, in releasing, opens the circuit of relay 2675 which releases and opens the circuit of relay 65 2678. Relay 620, in releasing, opens the holding circuit of relays 621 and 821. Relay 821 releases and disconnects the impulse circuit from the thousands register 800. In the manner above explained, relay 620 again 60 operates and a circuit is closed from ground 65 through the outer right contact of this relay, thence over conductor 669, through the outer right front contacts of relays 745, 727, and 729, conductor 765, outer right front contact of relay 657, conductor 626, inner left back of 70 contact of relay 603, outer right back contact of relay 623, thence over conductor 651, outer right front contact of relay 820, outer right back contact of relay 822, winding of relay 823 to battery. Relay 823 operates and 75 closes a locking circuit through its winding and inner lower contact, over conductor 771, through the winding of relay 621 to ground. Relay 621 being shunted does not operate for the time being. During the time relays 80 615 and 616 are releasing, a circuit is closed from the positive pole of battery, over conductor 639, thence over the ring side of the line and returning over the tip side of the line, through the inner normal contact of 85 relay 640, left back contact of relay 618, conductor 641, outer right contact of relay 614, outer right front contact of relay 613, conductor 670, left front contacts of relays 725, 727, 729, right outer armature and back 90 contact of relay 603, left front contact of relay 820, inner left back contact of relay 822, inner right contact of relay 810, conductor 842, high resistance 763 to the opposite pole of battery. In response to this impulse relay 2676 operates and closes a circuit from the grounded conductor 2683, through the contact of said relay, left back contact of relay 2679, conductor 2687, lower front contacts of relays 2731, 2732, 2740 and 2810, 100 lower back contact of relay 2813, winding of relay 2814 to battery. Relay 2814 locks through its left contact to the grounded conductor 2684.

With relays 615 and 616 deenergized, relays 618, 619 and 640 become operated. Relay 619, in operating, closes the circuit heretofore traced from ground over conductor 645, thence through the lower contact of relay 823, winding of relay 822, to battery. Relay 822 operates and locks through its inner right contact to the grounded conductor 737. Relay 823 opening the shunt, permits relay 621 to operate in series with relay 823. Relay 640 opens the impulse circuit and relay 2676 releases. During the next interval, while relays 615 and 616 are operating, a circuit is closed from the positive pole of battery, over conductor 639, thence over the tip side of the line and returning over the ring side of the line, through the middle left front contact of relay 640, through the outer left contact of said relay, conductor 680, outer right back contact of relay 617, conductor 652, thence through the inner upper contact of relay 823, inner right contact of relay 811, conductor 843, low resistance 764 to battery. This impulse being heavy causes the operation of relay 2674 and is of the proper 115 120 125 130

150

polarity to energize relay 2675. Relay 2675 operates relay 2679 which closes a circuit from the grounded conductor 2684, through the outer right contact of relay 2679, conductor 2685, thence through the lower front contacts of relays 2730, 2736, 2738 and 2810, lower back contact of relay 2815, winding of relay 2813 to battery. Relay 2813 operates and in the manner explained prepares a holding circuit for itself and relay 2815, the latter relay remaining shunted for the time being. Another circuit is closed from the grounded conductor 2683, the contact of the relay 2674, outer right back contact of relay 2678, thence through the upper front contacts of relays 2730 and 2736, inner lower front contact of relay 2738, upper front contact of relay 2812, upper back contact of relay 2815, winding of relay 2816 to battery. Relay 2816 operates and locks to the grounded conductor 2684.

After relays 615 and 616 have operated, relay 617 operates and relay 640 releases. Relay 640, in releasing, interrupts the impulse circuit causing the deenergization of relays 2674 and 2675. Relay 2675 permits the operation of relay 2678 as explained.

Next the relays 615 and 616 release, at which time, relay 618 becomes deenergized and relay 640 operates.

Following this, relays 615 and 616 again energize in succession and during this period a circuit is closed from ground over conductor 639, thence over the tip side of the line and returning over the ring side of the line, over conductor 646, through the high resistance 763 to battery. The impulse in this circuit causes the operation of relay 2675, which in turn shunts the relay 2679.

After relays 615 and 616 have operated, relays 617, 619, 620 and 640 become deenergized. Relay 640 opens the impulse circuit whereupon relay 2675 releases and opens the holding circuit of relay 2678.

This latter relay, in releasing, removes the shunt around the winding of relay 2815 which relay operates in series with relay 2830. Relay 620, in releasing, opens the holding circuit of relays 621 and 823.

Next the relay 620 which operates in the manner explained, closes a circuit from ground through its outer right contact and thence as previously traced to conductor 669, through the outer front contacts of relays 820 and 822, outer right back contact of relay 920, winding of relay 921 to battery. Relay 921 operates, connects the impulse circuit to the register 900, closes a locking circuit for itself over conductor 771

and as traced through the winding of relay 621 to ground. Relays 615 and 616 undergo release at the end of which time relays 618, 619 and 640 operate. Relay 619, in operating, closes a circuit from the grounded conductor 507, through its outer right contact and thence as traced over conductor 645, through the lower contact of relay 921, winding of relay 920 to battery. Relay 920 operates, locks through its inner right contact to the grounded conductor 737 and 70 opens the shunt around the winding of relay 621, permitting this relay to operate in series with relay 921.

Next relays 615 and 616 energize and during this time a circuit is closed from ground over conductor 639, thence over the tip side of the line and returning over the ring side of the line through the middle right left contact of relay 640, outer left contact of said relay, conductor 680, outer right back contact of relay 617, conductor 652, thence through the inner upper contact of relay 921, inner right contact of relay 903, conductor 843, low resistance 764 to battery.

In response to this impulse relays 2674 and 2675 operate. Relay 2675 causes the operation of relay 2679. Relay 2679 closes the circuit previously traced from ground through its outer right contact, thence over conductor 2685, through the lower front contacts of relays 2730, 2736, 2738, 2812 and 2815, lower back contact of relay 2820, winding of relay 2821 to battery.

Relay 2821 operates and in the manner explained prepares a holding circuit for itself and relay 2820. Another circuit is closed from the grounded conductor 2683, through the contact of relay 2674, outer right back contact of relay 2678, upper front contacts of relays 2730 and 2736, inner lower front contact of relay 2638, upper front contacts of relays 2812 and 2815, upper back contact of relay 2820, winding of relay 2822 to battery.

Relay 2822 operates and locks to grounded conductor 2684. When relays 615 and 616 have operated, relay 617 operates and relay 640 becomes deenergized. Relay 640 opens the circuit of relays 2674 and 2675. Relay 2678 now operates in series with relay 2679.

Next the relays 615 and 616 become deenergized at the end of which period relay 618 releases and relay 640 operates.

Next relays 615 and 616 operate and during this period a circuit is closed from ground, over conductor 639, thence over the tip side of the line and returning over the ring side through conductor 646 and the high resistance 763 to battery. In response to this impulse relay 2675 operates and shunts the relay 2679. After relays 615 and 616 have energized, relays 617, 620, 619 and 640 become deenergized. Relay 640 opens the circuit for relay 2675, which in turn, opens the circuit of relay 2678. Relay 2678 opens the shunt around relay 2820, and this latter relay operates. Relay 620, in releasing, opens the holding circuit of relays 621 and 921.

Relay 620 again operates and closes a circuit from the grounded conductor 507, through its outer right contact and thence as traced over conductor 645, through the lower contact of relay 921, winding of relay 920 to battery. Relay 920 operates, locks through its inner right contact to the grounded conductor 737 and 75 opens the shunt around the winding of relay 621, permitting this relay to operate in series with relay 921.

Relay 620 again operates and closes a circuit from the grounded conductor 507, through its outer right contact and thence as traced over conductor 645, through the lower contact of relay 921, winding of relay 920 to battery. Relay 920 operates, locks through its inner right contact to the grounded conductor 737 and 80 opens the shunt around the winding of relay 621, permitting this relay to operate in series with relay 921.

circuit from ground through its outer right contact and thence as traced to the conductor 651, thence through the outer right front contacts of relays 820, 822 and 920, 5 outer right back contact of relay 922, winding of relay 923 to battery. Relay 923 operates, connects the impulse circuit to the units register 901 and closes a holding circuit for itself over conductor 771, through 10 the winding of relay 621 to ground as previously explained.

Next relays 615 and 616 become deenergized, during which time, a circuit is closed from positive pole of battery, over conductor 639, thence over the ring side of the line and returning over the tip side of the line, through the inner normal contact of relay 640, left back contact of relay 618, conductor 641, thence as traced to conductor 670, through the left front contacts of relays 725, 727, 729, 820, 822 and 920, 15 left back contact of relay 922, inner right contact of relay 912, conductor 842, high resistance 763 to battery. In response to this impulse, relay 2676 operates and a circuit is closed from ground as traced, through the left back contact of relay 2679, conductor 2687, thence through the lower front contacts of relays 2731, 2732, 2740, 20 2810, 2813 and 2821, inner lower back contact of relay 2912, winding of relay 2913 to battery. Relay 2913 operates and locks to the grounded conductor 2684. When relays 615 and 616 again deenergize, relays 35 618, 619 and 640 operate. Relay 640 opens the circuit of relay 2676. Relay 619, in operating, closes the circuit above traced over conductor 645, through the middle lower contact of relay 923, winding of relay 922 to battery. Relay 922 operates and 40 locks to the grounded conductor 737 and also opens the shunt around the winding of relay 621. Relay 621 operates in series with relay 923.

Next the relays 615 and 616 operate and during this period a circuit is closed from the positive pole of battery, over conductor 639, thence over the tip side of the line and returning over the ring side of the line through the high resistance 763 to the opposite pole of battery. In response to this impulse, relay 2675 operates and causes the operation of relay 2679. Relay 2679 closes the circuit above traced from ground 50 over conductor 2685, thence through the lower front contacts of relays 2730, 2736, 2738, 2812, 2815 and 2820, inner lower left contact of relay 2914, winding of relay 2912 to battery. Relay 2912 operates and prepares a circuit for itself and relay 2914. After relays 615 and 616 have operated, relay 617 operates and relay 640 releases. Relay 640 opens the circuit of relay 2675 whereupon relay 2678 becomes energized. 55 Next the relays 615 and 616 become deen-

ergized following which relay 618 releases and relay 640 operates.

Next relays 615 and 616 operate and during this interval a circuit is closed from the positive pole of battery, over conductor 639, thence over the tip side of the line and returning over the ring side of the line, through the middle left contact of relay 640, through the outer left contact of said relay, conductor 680, outer right front contact of relay 617, conductor 654, thence through the uppermost contact of relay 921, inner right contact of relay 905, conductor 843, low resistance 764 to the opposite pole of battery. In response to this impulse, relays 2674 and 2675 operate. Relay 2675 shunts the relay 2679. Relay 2674 closes a circuit from grounded conductor 2683 to the contact of said relay, outer right front contact of relay 2678, thence through the inner lower contacts of relays 2730 and 2736, upper contact of relay 2743, inner lower contact of relay 2812, inner lower contact of relay 2815, inner lower contact of relay 2820, inner upper contact of relay 2914, winding 85 of register relay 2915 to ground. Relay 2915 operates and locks to the grounded conductor 2684. After relays 615 and 616 have operated, relays 617, 620, 619 and 640 become deenergized. Relay 640 opens the circuit of relays 2674 and 2675, whereupon relay 2678 releases. Relay 2678 removes the shunt and permits the operation of relay 2914 in series with relay 2912. Relay 2914 closes an obvious circuit for relay 2920. Relay 620, 90 in releasing, opens the circuit of relays 621 and 923.

Release of the recording sender at the originating office.

Since the complete record has been transferred from the sender in the originating office, this sender is no longer required and may be released immediately to the common use of other subscribers' lines. In the manner already explained the relay 620 again operates and a circuit is closed from ground through its outer right contact, left contact of relay 621, outer left front contact of relay 613, conductor 669, thence as traced to conductor 651, through the outer right front contacts of relays 820, 822, 920 and 922, lowermost back contact of relay 923, conductor 932, outer right back contact of relay 602, conductor 655, left back contact of relay 520, conductor 557, outer left back contact of relay 940, conductor 933, conductor 525, winding of relay 412 to battery. The sender release relay 412 operates and locks temporarily through its inner right contact to the grounded conductor 343. Relay 412 opens the circuit of the impulse relay 400 which is included in series with the subscriber's line. Relay 400 releases and opens the circuit of relay 401 which after an in- 125

interval releases and opens the circuit of relay 402. Relay 402 removes ground from the several holding conductors whereby the energized relays in the sender and register circuits are released. The removal of ground from conductor 343 also releases the magnet 310 and relay 309 and the sender selector switch 300 releases to disconnect the sender from the trunk 114.

10 The removal of ground from the test conductor 343 also opens the holding circuit of relay 201. Relay 201 releases and disconnects the tip and ring conductors to the subscriber's line from conductors 211 and 213 and extends them through to the left-hand windings of repeating coil 227. Relay 201 also opens the circuit of relay 204. Relay 204 being slow to release maintains its armatures attracted for an interval. During this 15 interval the subscriber's line is connected in series with the left-hand windings of the repeating coil 227 including battery and the winding of supervisory relay 203. Relay 203, therefore, operates and closes a substitute circuit for relay 204 before the latter can release. Relay 201 at its outer right contact opens the holding circuits of relays 208 and 205 and these relays become deenergized. Relay 208 completes the tip and 20 ring conductors of the trunk 114 through to the right-hand windings of the repeating coil 227.

Attachment of the tandem marker and
35 transfer of office record from tandem
sender to tandem marker.

The marker in the tandem office is attached to the recording sender as soon as the full 40 office code has been received on the registers 2700, 2701 and 2702 without waiting the receipt of the numerical part of the designation. It will be recalled that following the receipt of the third digit of the office 45 code, namely, the digit recorded on the register 2702, the relay 2743 is operated. Relay 2743 closes a circuit from ground through its lower contact, thence over conductor 2745, outer right back contact of relay 2665, conductor 2688, winding of relay 3309 to battery. Relay 3309 which is individual to the sender shown operates and closes an obvious circuit for the relay 3311. Relay 3311 completes a circuit from battery 50 through the right-hand winding of relay 3305, left contact of relay 3309, left back contact of relay 3310, left front contact of relay 3311, left back contact of relay 3312, thence through the outer right back contact 55 of relay 3001, conductor 3008, contact of slow relay 3004 to ground. Relay 3305 operates and closes an obvious circuit for relay 3313. Relay 3313 completes a circuit from battery 60 through the left winding and contact of relay 3305, left back contact of relay 3306,

outer left contact of relay 3313, outer left back contact of relay 3314, thence through the winding of relay 3001 to the grounded conductor 3008. A circuit may now be traced from battery through the winding of 70 the multicontact relay 3301, outer right contact of relay 3305, thence through the inner left contact of relay 3001 to the grounded conductor 3008. Relay 3301 operates and connects the recording sender with the tandem marker. Relay 3301 at its right-hand contact completes a circuit from ground over the conductor 3315, outer left contact of relay 3001, inner right back contact of relay 3000, winding of relay 3006 to battery. 75 With relays 3001 and 3313 operated the relay 3311 becomes deenergized.

With relays 3011 and 3006 energized a circuit may be traced from the grounded conductor 3008 to the outer right front contact of relay 3001, outer left front contact of relay 3006, conductor 3010, contact of relay 3001, conductor 3316, inner right contact of relay 2665, conductor 2689, through the sender selector 2500, conductor 2312, outer 85 right contact of relay 2305, conductor 2313, winding of the vertical magnet 2415 to battery. The magnet 2415 rotates the associated rod and prepares the contacts of the incoming trunk 1823 in the row 2403 of the 90 tandem district selector switch 2400. Magnet 2415 also closes a circuit from ground through its contact, conductor 2416, windings of the multicontact relays 3207, 3208, and 3309 to battery. These relays are individual to the particular switch shown and serve to associate the tandem marker therewith. Still another circuit may be traced from the grounded conductor 3008, through the outer right front contact of relay 3001, 105 outer left front contact of relay 3006, conductor 3011, outer left back contact of relay 3210, winding of slow-to-release relay 3212 to battery. Relay 3212 operates and closes an obvious circuit for slow-to-release 110 relay 3211.

The transfer of the three portions of the office designation from the sender to the marker registers 3101, 3102 and 3103 will now be described. First a circuit may be 115 traced from the grounded conductor 3008, inner left contact of relay 3006, conductor 3012, contact of relay 3301, conductor 3317, outer right contact of relay 2734, conductor 2746, contact of relay 3301, conductor 3318, winding of relay 3121 to battery. Another circuit may be traced from the grounded conductor 3317, thence through the outer right contacts of relays 2735 and 2737, conductors 2747 and 2748, contacts of relay 3301, conductors 3319 and 3320, windings of relays 3122 and 3123, to battery. Still another circuit may be followed from the grounded conductor 3317, through the outer 125 right contacts of relays 2739 and 2741, con- 130

ductors 2749 and 2750, windings of relays 3124 and 3125 to battery.

The three registers 3101, 3102 and 3103 in conjunction with the translator 3100 and 5 3120 determine the selection of the group of trunks outgoing from the switch 2400 to the called office. With register 3101 positioned a circuit may be traced from the grounded conductor 3008, through the inner 10 left contact of relay 3006, conductor 3012, contact of relay 3005, conductor 3013, inner right contact of relay 3126, inner right front contact of relay 3121, winding of multicontact relay 3110 to battery. Another circuit 15 may be traced over the grounded conductor 3013, outer left contact of relay 3130, left front contact of relay 3125, left back contact of relay 3131, outer left front contact of relay 3124, winding of multicontact relay 20 3119 to battery. When these relays operate, a circuit is completed from the grounded conductor 3013, through the inner right back contacts of relays 3128 and 3129, inner right front contact of relay 3123, inner left front contact of relay 3122, thence through a contact of relay 3119, over conductor 3132, winding of multicontact relay 3105 to battery. With relays 3105 and 3109 energized 25 a circuit is traceable over conductors 3013 and 3133, through contacts of relay 3110, to the horizontal conductor 3134, thence through a contact of relay 3105, conductor 3135, winding of the group relay 3214, conductor 3215, left back contact of relay 3216 30 to battery.

Another circuit is traceable from ground through the right contact of relay 3006, conductor 3015, horizontal conductor 3136, contacts of relay 3110, conductor 3137, contact 40 of relay 3105, conductor 3138, contact of relay 3301, conductor 3322, winding of the class relay 2917 to battery. Relay 2917 operates and locks through its upper contact to the grounded conductor 2684. Relay 45 3214 is individual to the group of trunks occurring in the section 2402 of the vertical row 2413 in the switch 2400 which lead to the called office and operates to select this group of trunks for testing.

50 *Testing the trunks of the selected group.*

The apparatus is now in condition for 55 making a test of the selected group of trunks outgoing from the switch 2400 to the distant office to select an idle one thereof. The testing operation involving the common test relays 3200 and 3203 in the marker takes place in substantially the same manner as that already explained in connection with 60 the mechanism in the originating office. When relay 3214 operates it closes a circuit from ground through its lowermost contact, conductor 3220, winding of relay 3210 to battery. Relay 3210 operates and opens the 65 circuit of relay 3212. Relay 3212 being slow

to release requires an interval before it de-energizes. Relay 3210 completes a circuit from ground, through its inner left contact, right front contact of relay 3211, conductor 3221, inner upper contact of relay 3214, conductor 3222, contact of relay 3209, conductor 3223, winding of the vertical operating magnet 2419 to battery. Magnet 2419 operates, prepares the contacts in the vertical row 70 2413 and closes a circuit from ground through its contact, over conductor 2421, contact of relay 3209, winding of relay 3213 to battery. Relay 3214 also completes a circuit from battery through the winding of relay 3240, middle lower contact of relay 75 3214, conductor 3242, contact of relay 3209, left front contact of relay 3211, outer left front contact of relay 3210 to ground over conductor 3011. Relay 3240 is individual to the selected group of trunks and serves 80 to connect the testing relay set 3200 with the individual trunks of that group.

Assuming that the first trunk 2420 in the group is busy, a circuit is closed from battery through the right-hand winding of test relay 3217, right contact of relay 3219, contact of relay 3240, conductor 3243 to the test conductor of the busy trunk 2420. Test relay 3217 operates in this circuit and locks 90 through its right-hand winding and right contact, conductor 3244, outer right contact of relay 3210, outer right back, contact of relay 3216 to the grounded conductor 3011. Relay 3217 closes a circuit for relay 3218 to ground over conductor 3244. Relay 3218, in 95 turn, closes an obvious circuit for relay 3219. On the other hand, had the associated idle link 2409 been busy instead of the trunk 2420, a circuit is completed through the left-hand winding of relay 3217, outer left back contact of relay 3219, through the contact of the relay 3207 to the grounded sleeve conductor of the link 2409. In either event, the relay 3217 operates as explained. However, if the next trunk 2428 and the associated link 2410 are simultaneously idle, the 100 corresponding test relay 3206 remains de-energized.

After the necessary interval has elapsed 105 following the operation of relay 3210, slow relay 3212 becomes deenergized and opens the circuit of relay 3211. Relay 3211, however, remains energized for an interval thereafter. A circuit is now completed from the grounded conductor 3011, right contact 110 of relay 3213, right contact of relay 3212, inner right contact of relay 3210, thence over conductor 3245, contact of relay 3240, inner left front contact of relay 3218, inner left back contact of relay 3205, winding of relay 3204 to battery. A circuit is now traceable 115 from ground through the left contact of relay 3213, conductor 3246, contact of relay 3240, right front contact of relay 3218, right back contact of relay 3205, left front 120 conductor 3247, contact of relay 3219, right back contact of relay 3217, right contact of relay 3213, conductor 3248, contact of relay 3240, right front contact of relay 3218, right back contact of relay 3205, left front 125 conductor 3249, contact of relay 3219, right back contact of relay 3217, right contact of relay 3213, conductor 3248, contact of relay 3240, right front contact of relay 3218, right back contact of relay 3205, left front 130 conductor 3247, contact of relay 3219, right back contact of relay 3217, right contact of relay 3213, conductor 3248, contact of relay 3240, right front contact of relay 3218, right back contact of relay 3205, left front conductor 3249.

contacts of relay 3204, contacts of relay 3207, thence through the windings of the horizontal operating magnet 2423 to battery. The magnet 2423 operates and establishes a connection between the incoming trunk 1823 and the selected outgoing trunk 2428, through the medium of the horizontal link 2410. Immediately, that the connection is effected, a locking circuit is closed 10 from battery, through the right-hand winding of magnet 2423, contacts of the switch 2400, thence over the sleeve conductor 2315 to ground at the contact of relay 2303.

After another interval has expired slow 15 relay 3211 releases and opens the circuit of relay 3240 which becomes deenergized and disconnects the testing relays from the sleeve conductors of the outgoing trunks. Relay 3211 also opens the circuit of the vertical 20 magnet 2419 which releases and restores the associated rod and also opens the circuit of relay 3213. Relay 3211 establishes a circuit from ground through the inner left contact of relay 3210, right back contact of relay 3211, conductor 3247, winding of release relay 3000 to battery. Relay 3000 closes a circuit for the slow operating and slow release relay 3004 which requires an appreciable interval before it attracts its 25 armature. During this time a circuit is established from the grounded conductor 3008, through the left contact of relay 3000, conductor 3017, contact of relay 3301, conductor 3323, winding of relay 2665 to battery. Relay 35 3004 operates and locks through its inner left contact to the grounded conductor 2682.

After an interval relay 3004 operates and removes ground from conductor 3008 whereby 40 all energized relays in the tandem marker are restored to normal. Moreover the multi-contact relay 3301 is released to disconnect the marker from the register sender.

45 *Transfer of numerical record from the tandem switching center to the register sender in the terminating office.*

The connection has now been extended to 50 the distant terminating mechanical office and the equipment in the tandem office is ready to transfer the numerical part of the designation representing the called line number from the register sender in the tandem office to the register sender in the terminating office. This transfer will take place as soon as the register sender in the terminating office has been associated with the incoming trunk 2428 by means of the 55 sender selector switch 4700. As soon as relay 2665 operates a circuit is completed from battery through the winding of relay 2604, outer right back contact of relay 2661, outer left contact of relay 2665 lower back contact of relay 2695, conductor 2624, inner

lower front contact of relay 2917 lower front contact of relay 2920 to ground. Relay 2604 operates and locks through its left contact to the grounded conductors 2697 and 2684. Relay 2604 at its right contacts connects the winding of relay 2607 to the tip and ring conductors of the trunk 1823, thence through the switch 2400 to the tip and ring conductors of the trunk 2428 extending from the tandem office and terminating on 70 the incoming selector switch 4600 at the final office. The circuit thus prepared by the relay 2604 may be traced from battery through the left-hand winding of relay 4504, left normal contact of relay 4503, upper 80 left winding of repeating coil 4500, inner right back contact of relay 4501, thence over the tip conductor of trunk 2428, through the tandem district switch 2400 to the tip conductor of trunk 1823, left back contact 85 of relay 2305, conductor 2317, through the sender selector 2500, conductor 2536, right front contact of relay 2663, upper back contact of relay 2695, conductor 2650, outer right contact of relay 2604, outer right contact of relay 2606, winding of relay 2607, inner right contact of relay 2606, inner right contact of relay 2604, conductor 2651, inner upper contact of relay 2695, conductor 2537, through the sender selector switch 2500, conductor 2318, inner right back contact of relay 2305, thence over the ring side of the trunk to the terminating office through the outer right back contact of relay 4501, lower left winding of repeating coil 4500, right 90 normal contact of relay 4503, right-hand winding of relay 4504 to ground. Relay 2607 operates and closes a circuit from battery through the winding of relay 2608, front contact of relay 2607, contact of relay 100 2610 to the grounded conductor 2684. Relay 2608 operates and locks through its inner right contact to the grounded conductor 2633.

Relay 4504 at the called office operates 110 and closes a circuit from ground through its contact, conductor 4509, winding of slow-to-release relay 4502 to battery. Another circuit may be traced from the grounded conductor 4509, thence through the winding of relay 4703 to battery. Relay 4703 operates and locks in a circuit from battery through its winding and inner left contact, conductor 4725, outer left contact of relay 4501, left back contact of relay 4506, conductor 4510 to ground at the contact of relay 4502. Relay 4703 in a manner substantially similar to that already explained in connection with the other sender selectors brings about the operation of the several relays 4710, 4711, 4712, 4713, 4714, 4715, 4716, 4717, 4718 and 4719. For the purpose of operating the sender selector switch 4700 to connect the incoming trunk 2428 to the idle register sender shown in Figs. 48, 49 125 130

and 50, the vertical operating magnet 4723 is operated to prepare the contacts in the vertical row 4708 containing the set of contacts representing the incoming trunks 2428. 5 At the same time the vertical operating magnet 4724 is energized to prepare the contacts in the row, representing the idle register sender allotted by the allotter switch 4722. When magnet 4724 operates it completes a circuit from ground through its outer right contact, thence over conductor 4726, outer right back contact of relay 4801, winding of slow-to-release relay 4800 to battery. Relay 4800 operates and closes a circuit from battery through the winding of relay 4801 to ground at the right contact of relay 4800. Relay 4801 operates in this circuit. With relay 4801 operated, relay 4800 is locked in a circuit through its left contact, conductor 4821, right back contact of relay 4815, conductor 4842 inner left contact of relay 4803, inner left contact of relay 4801 to ground at the right contact of relay 4800. With relay 4801 operated a circuit is closed from battery through the winding of slow-to-release relay 4813, conductor 4829, inner right back contact of relay 5005, conductor 5009, thence to conductor 4822 to ground at the inner right contact of relay 4801. Relay 4813 closes a circuit from battery through the winding of relay 4805, left contact of relay 4813 to ground at the outer right contact of relay 4801.

Magnet 4724, in operating, also closes a circuit in the manner previously traced through the windings of the stepping magnet 4721 and the relay 4720. The stepping magnet 4721 advances the allotter switch 4722 to allot a new sender for use. Following this, the horizontal magnet 4707 associated with the idle link 4701 is operated to complete the connection from the trunk to the selected register sender. The magnet 4707 is locked in a circuit from battery through its winding and the winding of relay 4706, thence through the sender selector switch 4700, conductor 4726, outer left front contact of relay 4801, inner left front contact of said relay, right front contact of relay 4800 to ground. Moreover, a circuit is established from battery through the winding of relay 4501, conductor 4511, through contacts of the selector switch 4700 to the grounded conductor 4726. Relay 4501 operates and opens the circuit of relay 4703 which brings about a restoration of the energized relays associated with the sender selector 4700.

60 Relay 4501, in operating, opens the circuit of relay 4504 which releases and opens the circuit of slow relay 4502. Relay 4502, however, remains energized in a substitute circuit closed at the inner left contact of relay 4501. The tip and ring conductors of 65 the trunk 2428 are now extended through

the sender selector switch to the control relays of the sender ready to receive the code impulses from the distant tandem office. The extended circuit may be traced from the tip conductor of trunk 2428, through the 70 inner right front contact of relay 4501, conductor 4507, through the sender selector switch 4700, conductor 4728, right normal contact of relay 4808, conductor 4823, windings of relays 4816, 4817 and 4818, conductor 4824, left normal contact of relay 4808, conductor 4729, through the selector switch 4700, conductor 4508, outer right front contact of relay 4501 to the ring conductor of the trunk 2428. The relays 4816 80 and 4817 are polarized in such a manner that the first of these relays responds to impulses of the polarity in which the positive pole of battery is connected to the tip side of the line, whereas the relay 4817 responds to impulses of the opposite polarity, both relays operating on either strong or weak impulses. The relay 4818 is marginal, however, and operates only on strong impulses of either polarity. The relays 4819 85 and 4820 cooperate with the polarized relays and marginal relays to receive the code impulses and record the digits represented on the registers 4900, 4901, 5000 and 5001 of the incoming register sender. 95

At the time relay 4501 operates to disconnect the battery supply through the windings of relay 4504 from the trunk 2428, the relay 2607 at the tandem office releases. This results in a circuit from battery through the winding of relay 2606, right contact of relay 2608, back contact of relay 2607 to ground over conductor 2633. Relay 2606 operates and locks through its inner left contact to the grounded conductor 2633. At the time relay 2608 operates a circuit is completed from battery through the winding of relay 2614 right back contact of relay 2622, conductor 2631, thence through parallel branches, closed at the front contacts of relays 2812, 2815, 2820, etc. and at the outer left back contacts of the corresponding relays 2808, 2818, 2824, etc., conductor 2825, outer right contact of relay 2608 to ground. By means of this circuit the relay 2614 is held operated so long as any one of the numerical registers has been positioned and until such register has served its function in connection with transmission of code impulses. In the case of the units register 2900 the circuit does not extend through a break contact on relay 2910 so that when relay 2914 closes its front contact, relay 2614 remains energized until the sender is released. Relay 2614 closes a circuit from ground through the outer right contact of relay 2608, inner left contact of relay 2614, inner right back contact of relay 2619, inner right contact of relay 2617, outer right contact of relay 2618, left back contact of 100 105 110 115 120 125 130

- relay 2619, left-hand windings of relays 2620 and 2619 to battery. Relay 2619 being marginal does not operate, but relay 2620 attracts its armatures. Relay 2620 completes a circuit from ground through its outer right contact, back contact of relay 2621, right back contact of relay 2613, conductor 2636, inner left back contact of relay 2808, winding of relay 2809 to battery. Relay 2809 operates and locks through its inner upper contact, over conductor 2827, winding of relay 2621 to ground at the contact of relay 2620. Relay 2621 being shunted does not operate at this time. With relays 2606 and 2614 operated, the slow operating and releasing relays 2615 and 2616 are brought into operation to create and transmit code of impulses according to the settings of the registers 2800, 2801, 2803 and 2900 to the distant terminating office.
- A circuit may be traced from ground through the outer left contact of relay 2606, conductor 2635, outer left contact of relay 2614, conductor 2626, left back contact of relay 2616, winding of relay 2615, resistance 2630 to battery. Relay 2615 operates and at its inner left contact closes a circuit from battery through the resistance 2632; winding of relay 2616 to the grounded conductor 2626. Relays 2616 and 2615 operate measuring an interval in so doing. Relay 2616 at its middle right contact closes a shunt circuit around the winding of relay 2615. Relay 2615 releases and at its right back contact closes a shunt circuit around the winding of relay 2616 which also becomes released. When relay 2616 operates a circuit is closed from battery through the winding and normal contact of relay 2633, outer right front contact of relay 2616 to ground over conductor 2626. Relay 2633 operates and through its make-before-break contact locks to the grounded conductor 2626.
- While relays 2615 and 2616 are undergoing deenergization as explained, a circuit is closed from the positive pole of battery, through the outer right contact of relay 2633, middle right contact of relay 2614, conductor 2653, outer normal contact of relay 2640, inner right contact of relay 2604, conductor 2651, thence over the ring side of the line as above traced to the distant office through the outer right front contact of relay 4501, thence to conductor 4729, left normal contact of relay 4808, conductor 4824, windings of relays 4818, 4817 and 4816, conductor 4823 and returning thence over the tip side of the line to conductor 2650, through the outer right contact of relay 2604, inner normal contact of relay 2640, left back contact of relay 2618, conductor 2641, outer right contact of relay 2614, outer left back contact of relay 2613, conductor 2636, outer right back contact of relay 2808, inner right contact of relay 2811, conductor 2751, high resistance 2753 to the opposite pole of battery. Due to the impulse transmitted in this circuit, relay 4817 at the terminating office is operated. Relay 4817 closes a circuit from ground through the inner right contact of relay 4801, conductor 4822, contact of relay 4817, outer right back contact of relay 4819, conductor 4826, left back contact of relay 4904, winding of register relay 4910 to battery. Relay 4910 operates and locks through its inner right contact to the grounded conductor 4822.
- Following the release of relays 2615 and 2616, a circuit is closed from the grounded conductor 2626, through the outer right back contact of relay 2616, outer left contact of relay 2633, conductor 2643, left back contact of relay 2617, left-hand windings of relays 2618 and 2617 to battery. Relay 2617 being marginal does not operate, but the relay 2618 attracts its armatures. Relay 2618, in operating, removes the shunt from around the right-hand winding of relay 2619 and this relay operates in series with relay 2620 in the manner already explained. Relay 2619 completes a circuit from ground over conductors 2684 and 2690, outer right contact of relay 2619, conductor 2691, uppermost contact of relay 2809, winding of relay 2808 to battery. Relay 2808 operates and locks to the grounded conductor 2684. It opens the shunt around the winding of relay 2621 which operates in series with relay 2809. Relay 2640 is also operated in a circuit from battery through its winding, outer left contact of relay 2615, inner right back contact of relay 2616, inner right contact of relay 2633 to the grounded conductor 2626. Relay 2640 operates and it opens the impulse circuit at its right contacts, whereby the relay 4817 at the terminating office becomes released. Next the relays 2615 and 2616 energize in succession and during this period a circuit is closed from the positive pole of battery, over conductor 2653 as traced, through the inner right front contact of relay 2640, thence over the tip side of the line through the control relays at the terminating office and returning over the ring side of the line through the outer right front contact of relay 2640, conductor 2654, high resistance 2753 to the opposite pole of battery. Due to this impulse, relay 4816 operates and a circuit is closed from grounded conductor 4822, through the contact of relay 4816, right back contact of relay 4820, right-hand winding of relay 4819, left-hand winding of relay 4820 to battery. Relay 4819 operates but relay 4820 being marginal does not become energized. Relay 4819, in operating, closes a circuit from battery through the left-hand winding of relay 4820, right-hand winding of relay 130

4819, right-hand winding of relay 4820, left contact of relay 4819 to the grounded conductor 4822. Relay 4820 being shunted, however, remains deenergized. Relay 4819, 5 in operating, closes a circuit from the grounded conductor 4822, through the inner right contact of said relay, conductor 4827, outer left back contact of relay 4903, winding of relay 4904 to battery. Relay 4904 10 operates and prepares a circuit through its windings and the winding of relay 4903, inner right front contact of relay 4904 to the grounded conductor 4822. Relay 4903, however, is shunted and does not operate at 15 this time.

Following the operation of relays 2615 and 2616, ground is removed from conductor 2643 whereby relay 2617 operates in series with relay 2618. Also a circuit is closed 20 from battery through the resistance 2647, middle left contact of relay 2633, outermost right front contact of relay 2616 to the grounded conductor 2626. This circuit shunts the relay 2640 which becomes deenergized. Relay 2640, in releasing, interrupts the impulse circuit and causes the deenergization of relay 4816. Relay 4816 removes the shunt from around the winding of relay 4820; and this relay operates in series 25 with relay 4819. Next the relays 2615 and 2616 become released whereupon ground is connected to conductor 2643 and the relay 2618 is shunted and released. Moreover, the shunt around the winding of relay 2640 is 30 opened and this relay again becomes operated. Next the relays 2615 and 2616 operate in succession. During the interval a circuit is completed from the positive pole of battery over conductor 2653, thence over the 35 tip side of the line and returning over the ring side of the line to the high resistance 2753 to the opposite pole of battery. Due to this impulse, relay 4816 reoperates and in so doing shunts relay 4819 which becomes released. Relay 4903 still remains deenergized by reason of a shunt maintained by the relay 4820. After relays 2615 and 40 2616 have operated, relay 2617 has its circuit opened and releases. The release of 45 this relay completes a circuit from battery through the left-hand winding and left front contact of relay 2619, outer right contact of relay 2618, inner right contact of relay 2617, inner right front contacts of 50 relays 2619 and 2620 to the grounded conductor 2684. Relay 2620 is shunted in this circuit and releasing, opens the circuit of relay 2619 which also in turn releases. Relay 2640 is also shunted in the manner above 55 explained and becomes deenergized. Relay 2640 opens the circuit of relay 4816 which releases and opens the circuit of relay 4820. Relay 4820 removes the shunt around the winding of relay 4903 and this latter relay 60 operates in series with relay 4904. Relay 65

2620, in releasing, opens the circuit of relays 2621 and 2809.

With relays 2617, 2618, 2619 and 2620 released the above traced circuit is again established through the windings of relays 2619 and 2620 and relay 2620 operates. Relay 2620 closes a circuit above traced from ground through the contact of relay 2621, thence over conductor 2636 to the left front contact of relay 2808, left back contact of relay 2818, winding of relay 2819 to battery. Relay 2819 operates and closes a circuit for itself over conductor 2827 including the winding of relay 2621.

While relays 2615 and 2616 are releasing 80 a circuit is closed from ground over conductor 2653, thence over the ring side of the line and returning over the tip side of the line through the high resistance 2753 to battery. In response to this impulse relay 4817 85 operates and a circuit is closed from ground through the contact of said relay, outer right back contact of relay 4819, conductor 4826, left front contact of relay 4904, left back contact of relay 4906, winding of relay 4911, to battery. Relay 4911 operates and locks to the grounded conductor 4822. After relays 2615 and 2616 have released, relays 2618, 2619, and 2640 become energized. Relay 2640 opens the impulse circuit and releases the relay 4817. Relay 2619 closes a 90 circuit for relay 2818, as above explained, whereupon relay 2621 operates in series with relay 2819.

Next relays 2615 and 2616 operate in succession and during this period a circuit may be traced from the positive pole of battery over the tip side of the line and returning over the ring side of the line through contacts of relay 2640, thence through the outer right back contact of relay 2617, conductor 2692, contact of relay 2819, inner right contact of relay 2816, conductor 2752, low resistance 2754 to battery. In response to this impulse relays 4818 and 4816 operate. Relay 4816 causes the operation of relay 4819, which in turn, closes a circuit from the grounded conductor 4822, through its inner right contact, conductor 4827, outer left front contact of relay 4903, outer left back contact of relay 4905, winding of relay 4906 to battery. Relay 4906 operates and prepares a circuit for itself and relay 4905. Relay 4818 establishes a circuit from ground through its contact. Outer right back contact of relay 4820, outer right front contact of relay 4903, inner right back contact of relay 4905, winding of register relay 4912 to battery. Relay 4912 operates and locks to the grounded conductor 4822. Following the operation of relays 2615 and 2616, relay 2617 operates and relay 2640 releases. Relay 2640 opens the circuit of relays 4818 and 4816, whereupon relay 4820 becomes operated. Next relays 2615 and 2616 become re- 100 105 110 115 120 125 130

leased, at the end of which time, relay 2618 deenergizes and relay 2640 operates.

Following this, relays 2615 and 2616 operate and during this period a circuit is closed from ground over the tip side of the line and returning over the ring side of the line through the high resistance 2753 to battery. Responsive to this impulse, relay 4816 operates and shunts the relay 4819. With relay 2616 operated, relays 2617, 2620, 2619 and 2640 become deenergized. Relay 2640 opens the circuit of relay 4816, which in turn, opens the circuit of relay 4820. The shunt being removed, relay 4905 now operates in series with relay 4906. Relay 2620, in releasing, opens the circuit of relays 2621 and 2819.

A circuit is again closed from the operation of relay 2620 in the manner above described and this relay prepares a circuit as traced over conductor 2636, through the left front contacts of relays 2808 and 2819, left back contact of relay 2824, winding of relay 2829 to battery. Relay 2829 operates and closes a circuit for itself in series with relay 2621. Relays 2615 and 2616 release in succession, and in so doing, cause the operation of relays 2618, 2619 and 2640. Relay 2619 completes a circuit as above described for relay 2824, which in operating locks to conductor 2684 and opens the shunt around the winding of relay 2621. Relay 2621 operates in series with relay 2829. Next the relays 2615 and 2616 operate, during which period, a circuit is closed from ground over the tip side of the line and returning over the ring side of the line, as above traced, through a contact of relay 2822 and the low resistance 2754 to battery. In response to this impulse, relays 4818 and 4816 operate. Relay 4816 operates the relay 4819. Relay 4818 extends ground through its contact, through the outer right back contact of relay 4820, through the outer right front contact of relay 4903, inner right front contact of relay 4905, inner right back contact of relay 5003, winding of relay 5008 to battery. Relay 5008 operates and locks over conductor 5009 to the grounded conductor 4822. Relay 4819, in operating, closes a circuit similar to that above traced for the operation of relay 5004. Relay 5004 prepares a circuit for itself and relay 5003. After relays 2615 and 2616 have operated, relay 2618 operates and relay 2640 releases. Relay 2640 opens the circuit of relays 4818 and 4816, whereupon relay 4820 becomes energized.

Next relays 2615 and 2616 release, following which, relay 2618 releases and relay 2640 operates.

Thereupon relays 2615 and 2616 operate and during this interval a weak impulse is sent over the line of the proper polarity to operate relay 4816. Relay 4816 shunts relay 4819. After relay 2616 operates, relays 2617,

2620, 2619 and 2640 become deenergized. Relay 2640 opens the circuit of relay 4816 and thereupon relay 4820 releases. With relay 4820 released the shunt is removed and relay 5003 operates in series with relay 5004 to the grounded conductor 4822. With relay 2620 released, it opens the circuit of relays 2621 and 2829. With relays 2617, 1819, and 2620 released, relay 2620 is again operated as explained to establish a circuit through the inner left front contacts of relays 2808, 2818 and 2824, left back contact of relay 2910, winding of relay 2911 to battery. Relay 2911 operates and closes a circuit for itself in series with relay 2621. While relays 2615 and 2616 release, a circuit is completed for sending a positive impulse over the line causing the operation of relay 4817. Relay 4817 extends ground through its contact, outer right back contact of relay 4819, conductor 4826, thence through the front contacts of relays 4904, 4906, and 5004, left back contact of relay 5006, winding of relay 5010 to battery. Relay 5010 operates and locks to the grounded conductor 5009. As soon as relay 2616 releases, relays 2618, 2619 and 2640 operate. Relay 2640 opens the impulse circuit and relay 4817 releases. Relay 2619, in operating, closes a circuit for relay 2910 which removes the shunt and permits relay 2621 to operate in series with relay 2911.

While relays 2615 and 2616 are energizing in succession, a light negative impulse is sent over the line to operate the relay 4816, to in turn, operate the relay 4819. Relay 4819 in the manner explained brings about the operation of relay 5006. After relay 2616 is operated, relay 2617 operates and relay 2640 releases. Relay 4816 now releases and relay 4820, consequently, operates.

Thereafter, relays 2615, 2616 become released, at the end of which time, relay 2618 releases and relay 2640 operates. Next, the timing relays 2615 and 2616 operate and during this interval a heavy negative impulse is transmitted over the line causing the operation of relays 4818 and 4816. Relay 4816 shunts the relay 4819. Relay 4818 extends ground through its contact, over the outer right front contact of relay 4820, thence through contacts of relays 4903, 4905 and 5003, outer right contact of relay 5005, winding of relay 5011 to battery. Relay 5011 operates and locks. After relays 2615 and 2616 have operated, relays 2617, 2620, 2619 and 2640 become deenergized. Relay 2640 opens the circuit of relays 4818 and 4816 and relay 4820 releases. Relay 4820 removes the shunt and permits relay 5005 to operate. Relay 5005, in operating, opens the holding circuit of relay 4813 which commences to release. A circuit is also closed while relay 4813 is holding its armature attracted from battery through the winding of relay 4815, right front contact of relay 130

4813, conductor 4830, inner right front contact of relay 5005 to the grounded conductor 5009. Relay 4815 operates and locks to the grounded conductor 4822. After an interval 5 relay 4813 releases and a circuit is closed from battery through the winding of relay 4808, outer left contact of relay 4815, right back contact of relay 4813, conductor 4830, thence through contact of relay 5005 to the 10 grounded conductor 5009. Relay 4808 at its make-before-break contacts, extends the conductors 4728 and 4729 through the windings of the battery feed relay 4806. Relay 2620, in releasing, opens the circuit of relays 2621 15 and 2911. It will be noted that the relays 2808, 2818, 2824 and 2910 have locked as they became energized successively.

Release of the sender in the tandem office.

20 In the aforesaid manner the numerical record consisting of the thousands, tens, hundreds and units digits of the called number has been transferred from the sender in the tandem office over the trunk to the sender 25 at the incoming or terminating mechanical office. The tandem sender is no longer required and may be released immediately to the common use of other calls. Following the release of relays 2617, 2619 and 2620, the 30 circuit previously traced is closed for the operation of relay 2620. A circuit is now established from ground, through the outer right contact of relay 2620, contact of relay 2621, thence as above traced over conductor 35 2636, through the inner left front contacts of relays 2808, 2818, 2824 and 2910, left back contact of relay 2940, lower front contact of relay 2917, conductor 2918, winding of the sender release relay 2668 to battery. 40 Relay 2668 operates and unlocks the relay 2667. After an interval relay 2667 releases and removes ground from conductors 2682 and 2532 and also opens the circuit of relay 2663. The removal of ground from these 45 conductors brings about a release of all operated relays in the sender and register circuits and also opens the holding circuit of the magnet 2510 of the sender selector 50 2500. The sender selector releases to disconnect the sender from the trunk 1823.

The release of the sender at the tandem office also causes the release of relay 2302. Relay 2302 opens the original circuit of relay 2303, but being slow, this relay holds its 55 armatures for an interval. A circuit is immediately closed from battery through the windings of relays 2300 and 2305, in parallel, thence through the inner left back contact of relay 2302 to ground at the contact of relay 2303. Relay 2300 disconnects the conductors of trunk 1823 from relay 2304 to prevent its reoperation. With relay 2305 operated a circuit may be traced from ground through the right-hand winding of relay 4806 at the terminating office, inner

normal contact of relay 4807, inner left front contact of relay 4808, conductor 4729, thence through the sender selector switch and through the outer right front contact of relay 4501 to the ring conductor of trunk 70 2428, through the tandem district selector switch to the ring conductor of trunk 1823, left front contact of relay 2305, left-hand winding of relay 2301, thence over the ring conductor of trunk 1823 to the originating 75 office, thence over the ring conductor of trunk 114, lower back contact of relay 208, uppermost contact of relay 207, lower right-hand winding of repeating coil 227, inner lower front contact of relay 206, inner lower 80 front contact of relay 207, windings of the polarized relay 233, inner upper front contact of relay 207, upper front contact of relay 206, upper right-hand winding of repeating coil 227, uppermost back contact of 85 relay 208 and returning over the tip side of the trunk through the right hand winding of relay 2301 to the terminating office, through the inner right front contact of relay 4501, thence through the sender selector 90 switch to conductor 4728, right front contact of relay 4808, outer normal contact of relay 4807, left-hand winding of relay 4806 to battery. Relay 4806 operates in this circuit but the polarity of current is such that the polarized relay 233 remains inert. Relay 2301 also operates in the circuit above traced and provides a substitute holding circuit for the slow relay 2303 before the latter can become released. 100

Returning to the point where the complete record was received at the terminating office and relay 5005 operates it will be recalled that relay 4815 becomes energized as a result thereof. Relay 4815 opens the above 105 traced holding circuit of relay 4800. Relay 4800, however, remains energized in a substitute circuit from battery through its winding and left contact, conductor 4821, front contact of relay 4805 to ground. An interval following the operation of relay 4815, relay 4813 releases and opens the circuit of relay 4805, which in turn, releases and opens the circuit just traced for relay 4800. Relay 4800 is now held in a circuit through its 110 winding, over conductor 4832, inner contact of relay 4804 to ground at the contact of relay 4806. Since both relays 4813 and 4805 are slow to release, the latter does not become finally deenergized following the receipt of the last impulses until after the trunk circuit has been cut through the contacts of relay 4808 to operate the relay 4806 as above explained. 115

Association of the incoming sender with the incoming marker and operation of the incoming selector switch.

With the full numerical record having been received on the registers 4900, 4901, 5000 130

and 5001, it is now necessary to associate the sender with the incoming marker illustrated in Figs. 51 and 52, for the purpose of operating the incoming selector switch 4600 to 5 select a group of trunks leading to the proper line terminal group of switch apparatus. Inasmuch as the operation of the incoming switch 4600 depends particularly upon the first or thousands digit, the marker may be 10 associated with the sender as soon as this digit is received and recorded on the register 4900. Accordingly, when relay 4906 operates during the receipt of the hundreds digit, a circuit is established from ground 15 over conductor 4822, through the inner left contact of relay 4906, conductor 4914, outer right contact of relay 4812, conductor 4834, winding of relay 5204 to battery. Relay 5204 operates and closes an obvious circuit 20 for relay 5213. Relay 5213 operates and a circuit is closed from battery through the right winding of relay 5202, left contact of relays 5204 and 5205, right front contact of relay 5213, outer right back contact of 25 relay 5207, conductor 5214, contact of slow operating and slow releasing relay 5208 to ground. Relay 5202 operates and closes an obvious circuit for relay 5206. Relay 5206 completes a circuit from battery through 30 the left winding and left contact of relay 5202, left back contact of relay 5203, outer right contact of relay 5206, winding of relay 5207 to the grounded conductor 5214. Relay 5202 locks and relay 5207 operates in 35 this circuit. With relays 5206 and 5207 operated, relay 5213 releases. A circuit may next be traced from battery through the winding of multicontact relay 5201, outer right contact of relay 5202, conductor 5215, 40 inner left contact of relay 5207 to the grounded conductor 5214. The multicontact relay 5201 is individual to the incoming sender shown and operates to associate such sender with the incoming marker illustrated in Figs. 51 and 52. Relay 5201, in 45 operating, also closes a circuit from ground over conductor 5216, outer left contact of relay 5207, inner left back contact of relay 5210, winding of relay 5209 to battery. 50 The sender connecting device 5200 and the associated relays operate in substantially the same manner as that described in connection with the equipment shown in Fig. 14 to associate the several incoming senders with the incoming marker which is common to these 55 senders. A further detailed description is not considered necessary. As soon as the sender is associated with the marker a circuit is established from the grounded conductor 5214, outer right front contact of relay 5207, outer left contact of relay 5209, conductor 5218, contacts of relay 5201, conductor 5219, inner left back contact of relay 4812, outer left contact of relay 4811, conductor 4835, through the sender selector 60 switch 4700, conductor 4730, winding of the vertical operating magnet 4603 to battery. The magnet 4603 operates the associated rod and prepares the contacts in the row 4601 in which appears the incoming trunk 2428 in 70 the incoming selector 4600. Magnet 4603 also closes a circuit from ground over conductor 4610, through the windings of relays 5103, 5104 and 5105 to battery. These multicontact relays are individual to the particular incoming selector switch 4600 shown in the drawing and serve to connect the common incoming marker with this particular switch. Similarly, the other multicontact relays illustrated are individual to other incoming selector switches. 75

Another circuit may be traced from grounded conductor 5214, right contact of relay 5209, conductor 5220, middle left contact of relay 5115, winding of slow-to-release relay 5114 to battery. Relay 5114 operates and closes a circuit for the slow-to-release relay 5113. 80

Still another circuit is established from ground through the inner left contact of relay 5209, conductor 5221, contact of relay 5201, conductor 5222, innermost back contact of relay 4916, left back contact of relay 4917, outer right back contact of relay 4918, inner left back contact of relay 4919, outer left back contact of relay 4920, conductor 4921, contact of relay 5201, conductor 5223, winding of the group relay 5117 to battery. Relay 5117 is individual to the particular group of trunks occurring in the vertical row 4607 of the switch 4600 which extends to the desired terminal line group of switching apparatus. Relay 5117 is selected due to the fact that only the register relay 4910 of the register 4900 is energized. Other group relays such as relays 5118 and 5119 are individual to still other groups of trunks on the incoming switch 4600 and may be operated by reason of the corresponding settings of the register 4900. 90

Relay 5117, in operating, closes a circuit from ground through its lowermost contact, conductor 5120, winding of relay 5115 to battery. Relay 5115 opens the circuit of relay 5114 which commences to release. Relay 5115 closes a circuit from ground through its inner left contact, right front contact of relay 5113, upper contact of relay 5117, conductor 5121, contact of relay 5105, conductor 5122, winding of the vertical operating magnet 4604 to battery. Magnet 4604 operates the associated rod and prepares the contacts in the vertical row 4607 in which appear the trunks leading to the desired terminal line group of switches. Magnet 4604 closes a circuit from ground through its contact, common conductor 4608, contact of relay 5105, conductor 5123, winding of relay 5116 to battery. Relay 5115 also closes a circuit from ground over conductor 5124 to battery. 100

Relay 5115, in operating, closes a circuit from ground through its inner left contact, right front contact of relay 5113, upper contact of relay 5117, conductor 5121, contact of relay 5105, conductor 5122, winding of the vertical operating magnet 4604 to battery. Magnet 4604 operates the associated rod and prepares the contacts in the vertical row 4607 in which appear the trunks leading to the desired terminal line group of switches. Magnet 4604 closes a circuit from ground through its contact, common conductor 4608, contact of relay 5105, conductor 5123, winding of relay 5116 to battery. Relay 5115 also closes a circuit from ground over conductor 5124 to battery. 110

Relay 5115, in operating, closes a circuit from ground through its inner left contact, right front contact of relay 5113, upper contact of relay 5117, conductor 5121, contact of relay 5105, conductor 5122, winding of the vertical operating magnet 4604 to battery. Magnet 4604 operates the associated rod and prepares the contacts in the vertical row 4607 in which appear the trunks leading to the desired terminal line group of switches. Magnet 4604 closes a circuit from ground through its contact, common conductor 4608, contact of relay 5105, conductor 5123, winding of relay 5116 to battery. Relay 5115 also closes a circuit from ground over conductor 5124 to battery. 120

Relay 5115, in operating, closes a circuit from ground through its inner left contact, right front contact of relay 5113, upper contact of relay 5117, conductor 5121, contact of relay 5105, conductor 5122, winding of the vertical operating magnet 4604 to battery. Magnet 4604 operates the associated rod and prepares the contacts in the vertical row 4607 in which appear the trunks leading to the desired terminal line group of switches. Magnet 4604 closes a circuit from ground through its contact, common conductor 4608, contact of relay 5105, conductor 5123, winding of relay 5116 to battery. Relay 5115 also closes a circuit from ground over conductor 5124 to battery. 130

ductor 5220, through the middle left front contact of said relay, left contact of relay 5113, conductor 5124, contact of relay 5105, conductor 5125, middle lower contact of relay 5117, winding of multicontact relay 5112 to battery.

The relay 5112 is individual to the selected group of trunks. If it be assumed that the vertical row 4607 in the switch 4600 accommodates two separate groups of trunks as explained in connection with switches previously described, the multicontact relay 5112 is individual to the group occurring in the upper part of the row 4607, whereas the multicontact relay 5126 is individual to the other group in the same row. The other multicontact relays illustrated may likewise be individual to other groups in other vertical rows of contacts on the same switch 4600. Relay 5112 when operated associates a group of testing relays 5100 with the test conductors of the respective trunks of the selected group. Relay 5126 serves a similar purpose with respect to the group of testing relays 5102 and associates these relays with the respective trunks of the other group occurring in the row 4607. Similarly, the other multicontact relays associate the groups of testing relays 5100 and 5102 with the corresponding groups of trunks in other vertical rows of the switches. It may be desirable to have a full vertical row of contacts in the incoming selectors accommodate a single group of trunks, in which case, two of the multicontact relays are operated simultaneously to associate both groups of testing relays 5100 and 5102 with the trunks of such a group.

40 *Testing the outgoing trunks and horizontal links on the incoming selector switch.*

The outgoing trunks and the horizontal links will now be tested to ascertain an idle pair for extending the connection beyond the incoming switch. The testing operations are substantially the same as those already fully explained in connection with other switches in the system. If the first trunk 4611 in the selected group which appears in the upper section of the vertical row 4607, is busy, a circuit is closed from battery through the right-hand winding of corresponding test relay 5106, right contact of relay 5108, contact of relay 5112, conductor 5127 to the grounded sleeve conductor of the busy trunk 4611. Relay 5107 operates and looks through its right-hand winding and contact, conductor 5128 to ground at the outer left contact of relay 5115. Relay 5106 at its left contact closes a circuit for relay 5107 to the grounded conductor 5128. Relay 5107, in turn, closes the circuit for relay 5108. If the associated horizontal link 4612 is busy a circuit is closed from bat-

tery through the left-hand winding of relay 5106, outer left front contact of relay 5108, contact of relay 5103, conductor 5129 to the grounded third conductor of the link 4612. The relay 5106 will operate when either of its windings alone is energized or when both are energized.

Assuming, however, that the next trunk in the group 4606 is idle and that the associated link 4602 is simultaneously idle, the corresponding test relay 5109 remains de-energized. When after an interval slow relay 5114 releases, a circuit is completed from the grounded conductor 5220, right contact of relay 5116, right contact of relay 5114, right contact of relay 5115, conductor 5130, contact of relay 5112, left front contact of relay 5107, left back contact of relay 5110, winding of relay 5111 to battery. With relay 5111 operated, a circuit is closed from ground, through the left contact of relay 5116, conductor 5131, contact of relay 5112, right front contact of relay 5107, right back contact of relay 5110, left contacts of relay 5111, contacts of relay 5103, thence over conductors 5132 and 5133, windings of horizontal magnet 4605 to battery. Magnet 4505 operates and the trunk 2428 is connected to the trunk 4606 through the idle link 4602. Immediately that this happens the magnet 4605 is locked in a circuit through its right winding, contacts of the switch 4600, sleeve conductor 4510 to ground at the contact of slow relay 4502.

After an interval following the release of relay 5114, slow relay 5113 releases and opens the circuit of relay 5112. Relay 5113 also opens the circuit of the vertical magnet 4604 which releases and opens the circuit of relay 5116. Relay 5113 closes a circuit from ground through the inner left contact of relay 5115, right back contact of relay 5113, conductor 5134, winding of release relay 5210 to battery.

Relay 5210 locks temporarily through its inner left contact, outer left contact of relay 5207, conductor 5216 to ground at the contact of relay 5201. Relay 5210 at its outer left contact closes an obvious circuit for relay 5208 which, being slow to operate, requires an interval in which to attract its armature. During this interval, a circuit is established from the grounded conductor 5214, outer right contact of relay 5210, conductor 5224, contact of relay 5201, conductor 5225, winding of relay 4812 to battery. Relay 4812 operates and locks through its inner right contact, conductor 4836, to ground at the outer right contact of relay 4801. After an interval following the operation of relay 5210, relay 5208 operates and disconnects ground from the holding conductor 5214, whereupon relays 5202, 5204, 5206, 5207 and the multi-contact relay 5201 become released. Relay 5201 disconnects the

incoming marker from the register sender inasmuch as the incoming marker is no longer required for this particular call. At the time relay 5210 operates, it opens the 5 circuit of relay 5209, whereupon ground is removed from conductor 5220. The release of the marker brings about a release of the group relay 5117 and the release of the vertical magnet 4603. With the vertical magnets 4603 and 4604 released, the connection 10 through the incoming switch 4600 is maintained solely by the continued energization of the horizontal magnet 4605. Thus, the incoming marker is fully released and may 15 be seized by other senders in connection with subsequent calls.

Association of the incoming sender with the line marker.

20 The apparatus is now in condition for associating the register sender containing the numerical record with a line marker mechanism whose function it is to control a group selector and connector switches such as those 25 shown in Figs. 53 and 54 to complete the establishment of the connection to the called subscriber's line. Before proceeding with the outline of the operation of these last two switches in the train, a brief explanation 30 will be given of one method in which the subscribers' lines may be grouped as regards the establishment of connections through the group selector and connector switches.

Assuming for the purpose of illustration 35 that the terminating office has a capacity of ten thousand subscribers' lines, these lines may be divided in five terminal groups of two thousand lines each. Each terminal group of two thousand lines is served by 40 a number of group selector switches and connector switches such as those shown in Figs. 53 and 54. The incoming selector switches 4600 have access to trunk groups which lead directly to the switches of the 45 terminal line groups. Hence, the several incoming selector switches are each provided with five groups of trunks leading to the five different terminal line groups.

For the particular terminal line group illustrated, one group selector 5300 and one connector switch 5400 are shown in the drawing. For the purpose of explanation, it will be assumed that each of the connector switches 5400 has a capacity for two hundred 55 and fifty called subscribers' lines. These two hundred and fifty lines may be divided into twenty-five groups of ten lines, each group occupying a vertical row on the connector switch. The group to which the line 5416 60 belongs occupies the vertical row 5427. Another row 5420 which accommodates a ten line group is shown. Likewise, there may be other vertical rows for the other groups of subscribers' lines.

65 Consider also that the connector switch

5400 has a vertical capacity for seventy horizontal links, the same as the district selector switch in Fig. 10. With seventy links in the structure and ten lines per vertical group, each line may, therefore, be 70 accessible to seven different links. Of these seven links, six are used for the establishment of talking connections while the remaining link is employed for testing purposes. Referring to the figure, two of the 75 ten groups of horizontal links are illustrated, only a portion of these being shown. The line 5416 appearing in the vertical row 5427 is served by the group of horizontal links containing the links 5401 and 5402 and the test link 5403. Connections may be established to this line over any one of the six horizontal links, while the line is tested over the common test link 5403. This particular group of horizontal links also serves 80 corresponding lines in each of the remaining twenty-four vertical rows 5420 etc. The second group of horizontal links shown serves similarly a line in each of the twenty-five, ten line groups, the connecting links 90 5404, 5405, etc. being used for establishing talking connections and the testing link 5406 being used for testing purposes.

Since each connector switch 5400 accommodates two hundred and fifty subscribers' lines, there will be a total of eight of these switches for each two thousand lines. Connections are extended from the group selector switch 5300 to any one of the eight different connector switches 5400 over interconnecting trunk circuits. A group of trunks is provided between the group selector 100 5300 and each of the eight connector switches whereby a connection incoming to a group selector may be extended to any one 105 of the eight connector switches each serving two hundred and fifty lines. Before describing the arrangement of these trunk groups between the connector and selector switches, it will be necessary to first explain 110 the construction of the switches themselves.

There will be a suitable number of the group selector switches 5300 for serving the terminal line group and the trunks incoming from the incoming switches 4600 are 115 distributed among the several group selectors. The trunk 4606 illustrated in the drawing appears in the group selector switch 5300 and occupies the vertical row 5323 having access to all horizontal links 120 in the switch. Other trunks of the incoming group would occupy other vertical rows in the switch 5300. Still other trunks of the incoming group will be allotted to the incoming vertical rows of the remaining group selector switches not shown in the drawing.

A convenient arrangement is to allot each trunk group extended from the group selector 125 5300 to a different connector switch to a full row of contacts in the group se- 130

lector. There being eight different connector switches in the terminal line group which must be reached from the group selector switch, the terminal bank of said group selector must be provided for eight groups of outgoing trunk circuits. Where several group selector switches similar to the switch 5300 are provided, all having access to all of the eight connector switches, it is necessary to multiple the interconnecting trunk groups to appear in all of the group selectors serving these eight connector switches. Considering the trunk group assigned to the vertical row 5326, this group would have a similar appearance in each of the group selectors serving the same group of connector switches; in other words, the trunk 5322 would be multiplied to appear in the row corresponding to row 5326 and to be accessible to the link corresponding to the link 5305 in each of the group selector switches serving the same group of connector switches. The same would be true of all other trunks in all other groups. The details of the terminal line group mechanism will now be considered. At the time relay 4812 operates a circuit is closed from ground through the contact of relay 4800, inner contact of relay 4801 inner left back contact of relay 4803, conductor 4842, right front contact of relay 4815, outer left contact of relay 4812, inner right back contact of relay 4810, conductor 4837, thence in parallel through the windings of relays 4907, 4920 and 4916 to battery. Next a circuit is closed from ground over conductor 4837, through the inner contact of relay 4916, left back contact of relay 4917, outer right back contact of relay 4918, inner left back contact of relay 4919, outer front contact of relay 4920, conductor 4923, winding of relay 5512 to battery. Thus the setting of the thousands register 4900 determines the selection of the relay 5512 which is individual to the register sender in the terminal line group of apparatus having access to the group of two thousand lines containing the called line. Had the called line been in some other group of two thousand lines, the register 4900 would have a different setting and the circuit above traced would have been led over some other front contact of the relay 4921 or the relay 4916 to a relay corresponding to relay 5512 in such other terminal line group of apparatus. Relay 5512 closes an obvious circuit for relay 5516, thereupon a circuit is closed from battery through the right winding of relay 5510, left contact of relay 5512, left back contact of relay 5513, left contact of relay 5516, outer right back contact of relay 5514, conductor 5540, contact of the slow operating and slow releasing relay 5517 to ground. Relay 5510 operates and closes an obvious circuit for relay 5515 thereupon a circuit is completed from

battery through the left winding and contact of relay 5510, inner back contact of relay 5511, winding of relay 5514 to the grounded conductor 5540. Relay 5514 operates and as soon as the relay 5515 is operated, relay 5516 releases. A circuit is now established from battery through the winding of multicontact relay 5508, outer right contact of relay 5510, inner left contact of relay 5514 to ground over conductor 5540. Relay 5508 operates and associates the incoming register sender with the line marker illustrated in Figs. 55 and 56. Relay 5508 also closes a circuit from ground through its contact, outer left contact of relay 5514, outer left back contact of relay 5519, winding of relay 5518 to battery. As soon as the sender is connected to the marker a circuit is closed from ground over conductor 5540, inner right front contact of relay 5514, contact of relay 5518, conductor 5541, contact of relay 5508, conductor 5542, lower contact of relay 4907, conductor 4924, outer left contact of relay 4810, outer right contact of relay 4811, conductor 4839, through the sender selector switch 4700, conductor 4731, inner right back contact of relay 4506, thence over the tip conductor of trunk 2428, through the switch 4600 to the tip conductor of trunk 4606, outer left contact of relay 5340, right back contact of relay 5344, through the winding of the vertical operating magnet 5306, controlling the row of contacts in which appears the selected incoming trunk 4606. Magnet 5306 prepares contacts and also closes an obvious circuit for multicontact relay 5312. Relay 5312 operates and being individual to the switch 5300 associates the line marker with the horizontal links of said switch.

The record of the thousands, hundreds, tens and units digits is now transferred from the registers of the sender to the line marker. The relays 5618 and 5619 serve to determine whether the thousands digit is even or odd according to the combination in which they are operated. In the present case the digit being 1 and odd, the relay 4910 alone in the register 4900 is operated. Also the relay 4922 is energized in parallel with relay 4910. Therefore, a circuit is established from ground, as above traced, over the conductor 5542, thence through the outermost contact of relay 4922, conductor 4925, contact of relay 5508, conductor 5543, winding of relay 5619 to battery. Since the terminal line group contains only two thousand lines, a thousand digit is needed only for the purpose of determining which one of the two thousand is involved. If the thousands digit represents the even thousand of the group, the multicontact relay 5627 of the translator device 5604 will be operated to connect the conductors from the tens register 5602 to the horizontal conductors in

the lower section of the selector 5604. On the other hand, if the thousands digit represents the odd thousand in the group, the multicontact relay 5628 should be operated to connect the tens register with the horizontal conductors in the upper section of the translator bank 5604. In the present case the digit being odd and relay 5619 being operated, as explained, a circuit 5 is closed from battery through the winding of relay 5628, thence through the right back contact of relay 5618, front contact of relay 5619 to the grounded conductor 5541.

Another circuit may be traced from 15 ground over conductor 5542, through the outermost contact of relay 4911, conductor 4926, contact of relay 5508, conductor 5544, winding of relay 5614 to battery. Still another circuit may be traced over the ground- 20 ed conductor 5542, through the outermost contact of relay 4912, conductor 4927, contact of relay 5508, conductor 5545, winding of relay 5615 to battery. Another circuit is traceable over conductor 5542, through the 25 outermost contact of relay 5008, conductor 5013, contact of relay 5508, conductor 5546, winding of relay 5607 to battery. Lastly, a circuit is closed over the grounded conductor 5542, through the outermost contacts of re- 30 lays 5010 and 5011, conductors 5014 and 5015, contacts of relay 5508, conductors 5547 and 5548, windings of the register re-lays 5610 and 5613 to battery.

With register relays 5614 and 5615 operated a circuit may be traced from the 35 grounded conductor 5541, thence over conductors 5631 and 5632, inner right back contacts of relays 5617 and 5616, inner right front contact of relay 5615, inner left front 40 contact of relay 5614, winding of the multicontact relay 5626 to battery. A circuit is thereupon closed from battery through the winding of relay 5630, contact of relay 5628, contact of relay 5626, conductor 5631 to the 45 grounded conductor 5541. Relay 5630 operates and a circuit is established from ground over conductors 5541 and 5631, through the contact of said relay, thence through the inner right back contacts of relays 5609 and 5608, inner right front contact of relay 5607, inner left back contact of relay 5606, conductor 5634, contact of relay 5628, contact of relay 5626, conductor 5635, winding of the 50 vertical operating magnet 5415 to battery. The magnet 5415 controls the vertical row of contacts 5427 in which appear the subscribers' lines of the group of ten containing the called line 5416. The magnet 5415 at its 55 contact, closes a circuit from ground over conductor 5422, thence in parallel through the windings of multicontact relays 5316 and 5620 to battery. Relay 5316 connects the common test relays of the marker with the 60 group of trunks leading from the switch 5300 to the connector switch 5400. It also

closes a circuit for the vertical operating magnet 5308 controlling the vertical row of contacts 5326 on the group selector switch 5300 in which appear these trunks. Magnet 5308 prepares the contacts in this row and 70 closes a circuit from ground through its contact, contacts of relays 5312, conductor 5313, winding of slow-to-release relay 5521 to battery. Relay 5521 closes a circuit from battery through the winding of relay 5538, back 75 contact of relay 5537, conductor 5551, outer contact of relay 5521 to the grounded conductor 5541. Relay 5538 closes a circuit from ground over conductor 5541, through the inner contact of relay 5538, conductor 80 5552, winding of slow-to-release relay 5523 to battery. Relay 5523 closes a circuit from battery through the winding of slow-to-release relay 5524, right front contact of relay 5523 to the grounded conductor 5541. 85 Relay 5524, in turn, closes a circuit from battery, through the winding of relay 5525, front contact of relay 5524, conductor 5553, outer right front contact of relay 5514 to the grounded conductor 5540. Relay 5525 operates and locks to the grounded conductor 5553.

The multicontact relay 5620 operates and connects the register 5601 to the connecting device 5410. Relay 5620 also closes a circuit 95 from battery through the winding of relay 5636 to ground over conductor 5631. Relay 5636 completes a circuit from the grounded conductor 5541, conductors 5631 and 5632, contact of relay 5636, thence 100 through the outer right contact of relay 5610, outer right contact of relay 5613, outer right back contacts of relays 5612 and 5611, conductor 5637, contact of relay 5620, winding of the multicontact relay 5411 to battery. 105 Relay 5411 associates the test relays 5622, 5624, etc. of the marker with the respective horizontal links of the group in the connector switch 5400 having access to the called subscriber's line 5416.

Testing the trunks and links in the terminal line group.

The testing operation will now be explained. If the first trunk 5320 in the selected group is busy, a circuit is closed from battery through the right-hand winding of test relay 5534, innermost right contact of relay 5536, thence through contacts of the relay 5316 to the grounded sleeve conductor 115 of the trunk 5320. If the link 5303 associated with the trunk 5320 is busy, a circuit is closed from battery through the left-hand winding of relay 5534, outer left back contact of relay 5536, thence through contacts of relay 5312, conductor 5527 to the grounded third conductor of the busy link 5303. Either winding of the relay 5534 is sufficient to operate the same. If the next trunk 120 5321 or its associated link is busy or both 125

are busy, the corresponding test relay 5531 is operated in the same manner. Relays 5534 and 5531, in operating, lock through their right-hand windings and right contacts, conductor 5554, conductor 5551, through the contact of relay 5521 to the grounded conductor 5541. Relay 5534, in operating, closes a circuit from its left contact for relay 5535, to ground over conductor 5554. Likewise, relay 5531 closes a circuit for relay 5532.

Assuming, however, that the next trunk 5322 and the link 5305 are idle, the test relay 5528 remains deenergized.

15 Another circuit may be traced from ground over conductor 5541, through the inner contact of relay 5521, conductor 5556, inner left front contacts of relays 5535 and 5534, inner left back contact of relay 5529, winding of relay 5530 to battery. Relay 5530 operates and a circuit may be traced for operating the vertical magnet 5413 at the connector switch which controls the row of contacts in which appears the selected 20 idle trunk 5322 interconnecting the group selector 5300 and connector switch 5400. This circuit may be traced from ground over conductor 5541, through the outer contact of relay 5521, conductor 5551, outer 25 right contact of relay 5530, middle right contact of relay 5529, conductor 5557, contact of relay 5316, conductor 5329, winding of the vertical operating magnet 5413 to battery. Magnet 5413 prepares the associated 30 contacts and also closes a circuit from ground through its contact, conductor 5418, contact of relay 5316, conductor 5330, winding of relay 5537 to battery. Relay 5537 operates and opens the circuit of the slow 35 release relay 5538. Relay 5537 also closes a circuit from battery, through the winding of the horizontal test magnet 5409, contacts of relay 5411, conductor 5428, front contact of relay 5537 to ground over conductor 5551. 40 The magnet 5409 operates the test link 5403 connecting the third conductor 5325 of the incoming trunk 5322 with the sleeve conductor of the line 5416.

45 While the foregoing operations are taking place a test is made of the links 5401 and 5402 and the others of the same group to determine an idle one. Assuming that link 5401 is busy, a circuit is completed from battery through the right-hand winding of relay 5622, left contact of relay 5621, contact of relay 5411 to the grounded third conductor of the busy link 5401. Relay 5622 operates and locks through its left winding and contact to the grounded conductor 5541. If the next link is idle, the corresponding test relay 5624 remains inert. Similarly, a test is made of all other horizontal links in this particular group.

50 After the necessary interval relay 5538 becomes deenergized and opens the holding

55 circuit of relay 5523. While relay 5523 is holding its armatures attracted, a test circuit is closed from battery through the winding of test relay 5522, left contact of relay 5523, outer contact of relay 5538, middle 60 right contact of relay 5530, outer right contact of relay 5529, through contacts of relay 5316, sleeve conductor 5325 of the trunk 5322, over the test link 5403 to the sleeve 65 conductor 5423 of the called subscriber's line. Assuming the line 5416 be idle, no potential is found on the test conductor 5423 and, consequently, test relay 5522 fails to operate. After an interval relay 5523 releases and opens the circuit of relay 5524. 70 While relay 5524 which is slow to release is deenergizing, a circuit is closed from ground over conductor 5541, right back contact of relay 5523, right contact of relay 5522, outer left contact of relay 5525, conductor 5558, innermost right front contact of relays 5535 and 5532, innermost right 75 back contact of relay 5529, left front contacts of relay 5530, thence over conductors 5559 and 5560, through contacts of relay 5312, conductors 5331 and 5322, respectively, windings of the horizontal operating magnet 5311 to battery. Magnet 5311 operates the selector switch 5300 and immediately 80 that the connection is completed, a circuit is closed from battery through the winding of relay 5344, contacts of the switch 5300, thence over conductor 5331, as above traced to the grounded conductor 5541. Relay 5344 85 operates and locks in a circuit through its winding and the right normal contact of relay 5343, outer left contact of relay 5344 to the grounded sleeve conductor 5348 of the trunk 4606. The connection 90 through the switch is now held by the horizontal magnet 5311 which is locked in a circuit through its right winding contacts of the switch 5300, conductor 5347, right normal contact of relay 5343, outer left contact 95 of relay 5344 to ground over the sleeve conductor 5348. 100

105 Another branch of the above traced circuit leads through the inner left contact of relay 5525, conductor 5561, right front contact of relay 5622, right back contact of relay 5624, winding of relay 5623 to battery. Relay 5623 operates and the grounded conductor 5561 is thereby extended through its right contact, thence over conductor 5639, through 110 the left-hand winding of the horizontal operating magnet 5408 to battery. Magnet 5408 operates the connector switch 5400 and locks through its right winding and contacts of the switch to the grounded sleeve conductor 5325. 115

The release of the line marker.

120 The apparatus is now in condition for applying ringing current to the called subscriber's line; before proceeding with this 125

- phase of the connection a description will be given of the restoration of the line marker. At the end of the required interval following the release of relay 5523, relay 5524 retracts its armature and a circuit is closed from grounded conductor 5553, through the back contact of relay 5524, outer left contact of relay 5525, winding of release relay 5519 to battery. Relay 5519 operates and 5 closes a momentary locking circuit for itself through its outer left front contact to ground at the contact of the relay 5508. Relay 5519 closes a circuit for the slow operating and slow releasing relay 5517 which requires an interval before its armature is attracted. During this interval a circuit is closed from ground through the contact of relay 5517, right contact of relay 5519, conductor 5562, contact of relay 5508, conductor 5563, winding of relay 4810 to battery. Relay 4810 operates and locks to the grounded conductor 4836. After an interval has expired relay 5517 attracts its armature and disconnects ground from conductor 5540. Relays 5519, 5518, 5514, 5510 and 5508 are thereupon restored to normal and the line marker is disconnected from the recording sender. Relay 5517, in operating, removes ground from conductor 5541, 30 whereupon the various operated relays in the marker are restored to normal.

- The removal of ground from conductor 5541 causes the release of the horizontal magnet 5409 and the horizontal test link 5403 is thereby restored. Moreover, the holding circuits of the vertical operating magnets 5413, 5415, 5308 and 5306 have been opened and these magnets release to restore the associated rods. With the vertical magnets of the switches 5300 and 5400 restored the connection is maintained by the continued energization of the horizontal magnets 5311 and 5408.

45 *Release of the incoming sender.*

- When the relay 4810 operates at the time the line marker is releasing, it closes a circuit from ground through its outer right contact, inner right contact of relay 4811, conductor 4840, through the sender selector switch 4700, conductor 4733, winding of relay 4506 to battery. Relay 4506 operates and locks to ground at the contact of the slow relay 4502. Relay 4810 also completes a circuit from battery through the winding of relay 4802, inner right front contact of relay 4810, outer left contact of relay 4812, right front contact of relay 4815, conductor 4842, left contact of relay 4803, 55 outer right contact of relay 4804 to ground. Relay 4802 operates and locks through its left contact to ground at the outer right contact of relay 4804. Relay 4802 closes a circuit from battery through the winding of slow release relay 4804, inner right con-

tact of relay 4802, conductor 4836 to ground at the outer right contact of relay 4801. Relay 4804 operates and opens the locking circuit of relay 4802. Relay 4802, however, is held in a circuit from battery 70 through its winding and left contact, conductor 4842, inner left contact of relay 4801 to ground at the right contact of relay 4800. Relay 4804 at its inner right contact, opens the circuit of relay 4800. Relay 4800 after 75 an interval releases and opens the holding circuit of relay 4801.

Relay 4801, in releasing, removes ground from conductors 4836 and 4822, whereupon all energized relays in the sender and register circuits are restored to their normal condition. The release of relay 4801 also removes ground from conductor 4726, whereupon the horizontal magnet 4707 and relay 4706 of the sender selector become 80 deenergized and the sender is released from the trunk 2428. At the time ground is removed from the conductor 4726, the holding circuit of relay 4501 is also opened and this relay releases to disconnect the 85 tip and ring conductors of the trunk 2428 from the conductors leading to the sender selector and to connect them through to the left-hand windings of the repeating coil 4500. Relay 4501 opens the circuit of relay 4502, but this latter relay being 90 slow, retains its armature for an interval until another circuit is closed therefor. When the tip and ring conductors of the 95 trunk 2428 are extended through to the repeating coil 4500, the circuit hereinbefore traced is again completed including the windings of relay 4504 in series with the trunk circuit and including the right-hand 100 windings of the repeating coil 227 and the windings of the polarized relay 233 in the trunk circuit 114 at the originating office. Relay 4504 operates but the direction of the 105 flow of current is such that the relay 233 at the originating office remains deenergized. Relay 4504 at its contact completes a holding circuit for the slow relay 4502 before the latter has time to release.

45 *Application of ringing current to the called line.* 115

At the time group selector 5300 is operated a circuit is closed for relay 5344 in the manner above explained and this relay operates and locks to the grounded conductor 120 5348. Another branch of the circuit extends from ground in the marker as explained over the conductor 5347, outer right contact of relay 5342, contact of relay 5345, winding of relay 5341 to battery. Still another 125 branch of this circuit may be traced over the conductor 5347, through the right-hand winding of relay 5342, inner normal contact of said relay, winding of relay 5341 to battery. Relay 5341 operates, but relay 5342 130

being shunted by the relay 5345 remains deenergized at this time. Relay 5341 completes a circuit from battery through the winding of relay 5340, outermost left contact of relay 5341 to the grounded sleeve conductor 5348. Relay 5340 operates and locks directly to the conductor 5348. Relay 5340 at its left back contacts disconnects the trunk conductors from the armatures of relay 5344 and this occurs prior to the time relay 4506 operates to extend the circuit including the right-hand windings of repeating coils 4500, through to the contacts of relay 5340. Relay 5340, moreover, establishes, a circuit from ground through its inner left contact, inner right front contact of relay 5344, left-hand winding of relay 5343 to battery. Relay 5343 energizes and at its right-hand make-before-break contact, applies ground to conductor 5347, in substitution of the ground potential momentarily applied by the line marker during the operation of the group selector 5300. The horizontal magnets 5311 and 5408 are held under the control of the relay 5343 after the line marker is disconnected. Relay 5344 is now held in a circuit closed at the right front contact of relay 5343.

Relay 5341 in operating closes the ringing circuit which may be traced as follows: from the source of ringing current 5346, through the winding of the marginal relay 5345, inner left front contact of relay 5341, over the ring conductor of the talking circuit, through the switch 5300, thence through the switch 5400, over the subscriber's line 5416 and returning over the tip side of the line through the middle left front contact of relay 5341 to ground. Relay 5345 being marginal does not operate while the subscriber's receiver is on the switchhook. The calling subscriber in removing his receiver responsive to the ringing of his call bell reduces the resistance in the circuit sufficiently to permit the operation of relay 5345. Relay 5345 opens the shunt around the right-hand winding of relay 5342. Relay 5342 operates and locks in a circuit from battery through its inner right-hand front contact and right-hand winding to ground at the right front contact of relay 5343. Relay 5342 at its contact opens the circuit of relay 5341 which releases and disconnects ringing current from the subscriber's line.

Upon the release of relay 5341 the talking circuit for supplying current to the called subscriber's line is complete. This circuit may be traced from battery through the lower right winding of repeating coil 4500, winding of supervisory relay 4513, outer right contact of relay 4506, over the ring side of the line, through the switch 4600, thence through the inner left back contact of relay 5341, through the contacts of switches 5300 and 5400, over the called sub-

scriber's line and returning over the tip side of the line through switches 5400 and 5300, middle left back contact of relay 5341, through contacts of the switch 4600, inner right front contact of relay 4506, upper right winding of coil 4500 to ground. As above traced the talking connection extending between the originating office and the terminating office includes battery and ground potentials supplied through the windings of the relay 4504, left-hand winding of repeating coil 4500, winding of the relay 2301 in the tandem office, right-hand windings of the repeating coil 227 and the polarized relay 233 at the originating office. The talking current for the calling subscriber's line is supplied through the left-hand windings of the repeating coil 227 at the originating office.

Release of the established connection.

After the conversation is finished the calling and called subscribers replace their receivers upon their switchhooks and the connection is automatically restored. When the calling subscriber hangs up his receiver he opens the circuit through the left-hand windings of the repeating coil 227, permitting the release of relay 203. After an interval the relay 204 becomes deenergized and in so doing removes ground potential from the sleeve conductor 150. The removal of ground from the sleeve conductor results in the deenergization of the horizontal magnet 124, relay 126, cut-off relay 120 and the trunk relay 146. Magnet 124, in releasing, restores the line switch 100 and the calling subscriber's line is hereby disconnected from the trunk 114. The removal of ground from the holding conductor 150 also results in the deenergization of the horizontal magnet 1026 of the district selector switch 1000. The district selector restores and disconnects the trunk 114 from the trunk 1028. The holding circuit of the horizontal magnet 1822 of the office selector 1800 is also broken and this switch is restored to disconnect the trunk 1028 from the outgoing trunk 1823.

Relay 204, in releasing, also opens the circuits of relays 206 and 207. Relay 207, in releasing, opens the bridge across the tip and ring conductors of the outgoing trunk, whereupon relay 2301 in the tandem office and relay 4504 at the terminating office become deenergized. Relay 2301, in releasing, opens the circuit of slow relay 2303 which after an interval retracts its armature and opens the circuits of relays 2300 and 2305. Relay 2303, in releasing, removes ground potential from conductor 2315 resulting in the deenergization of the horizontal operating magnet 2423. Magnet 2423 releases the tandem district selector 2400 thereby disconnecting the incoming trunk 1823 from the outgoing trunk 2428.

Relay 4504 at the terminating office, in releasing, opens the circuit of relay 4502. Relay 4502 after an interval deenergizes and removes ground from conductor 4510, 5 whereupon relay 4506 and horizontal magnet 4605 become released. Magnet 4605 releases the switch 4600 disconnecting the trunk 2428 from the trunk 4606. The removal of ground from the sleeve conductor 10 4510 opens the holding circuit of relay 5340. Relay 5340 releases and opens the circuit of relay 5343. Relay 5343 becomes deenergized and opens the circuits of relay 5344 and 5342 and removes ground from the conductor 15 5347. The removal of ground from the conductor 5347 opens the holding circuits of the horizontal magnets 5311 and 5408, whereupon the group selector 5300 and the connector switch 5400 are restored to 20 normal.

Called subscriber's line test busy.

It was first assumed that the called subscriber's line 5416 was found to be idle when a test was made by the line marker through the common horizontal test trunk 5403. It will now be considered that the line is busy when the test is made. Returning to the 25 point where the slow relay 5538 in the line marker releases following the operation of relay 5537, a circuit may now be traced from battery through the winding of the test relay 5522, left contact of relay 5523, thence 30 as above traced to the sleeve conductor 5423 of the busy line 5416 which sleeve conductor presents ground potential. The test relay 5522, consequently, operates and locks through its inner left contact to the grounded conductor 5541. After the necessary interval relay 5523 releases. Relay 5523 at 35 its right back contact completes one break in the circuits previously traced for the horizontal operating magnet 5311 associated with the selected idle link 5305 and the idle trunk 5322 and for the horizontal magnet 5408 associated with the selected idle link 5402 of the connector switch 5400. These 40 circuits, however, are now held open at the right contact of relay 5522 and, therefore, 45 neither the switch 5300 nor the switch 5400 can be operated to extend the incoming connection to the busy subscriber's line 5416. Following the release of relay 5523, relay 5524 releases and closes a circuit for relay 5519, whereupon the line marker is disconnected in the manner heretofore explained. Prior to the release of the line marker, however, the circuit traced is completed for operating relay 4810 in the sender. Another 55 circuit is also closed from the grounded conductor 5541, outer left contact of relay 5522, conductor 5555, contact of relay 5508, conductor 5565, windings of relays 4803 and 4809, in parallel to battery. Relays 4803 and 4809 operate and lock to the outer right contact of relay 4801.

Although relay 4810 is operated the circuit previously traced for relay 4802 following the release of the line marker after the 70 called line had been found idle, is held open at the contact of relay 4803. Therefore, relay 4802 remains inert and does not operate the relay 4804 to, in turn, cause the release of relays 4800 and 4801 to bring about a release of the incoming sender. With relay 4809 operated the right-hand winding of the induction coil 4844 is connected through the condensers 4846 and 4847 across the tip and ring conductors of the trunk 2428. A tone 75 producing source 4845 connected to the left-hand winding of the coil 4844 induces current in the right-hand winding which is transmitted over the trunk through the tandem office to the originating office in a circuit including the right-hand windings of the repeating coil 227. This induces current, in turn, inducing a current in the left-hand windings of the coil 227 to produce a 80 characteristic tone in the receiver at the 85 calling subscriber's station to notify the calling party that the line is busy. This tone obtains until the calling party hangs up his receiver. When he hangs up the receiver the connection in the originating and tandem offices is released in the manner already described in detail. The release of the connection at the originating and tandem office opens the circuit of relay 4806 in the incoming sender. This relay at its contact, opens 90 the holding circuit of relay 4800 which releases and opens the circuit of relay 4801. In the manner already described the release of relay 4800 and 4801 brings about a 95 restoration of the incoming sender, the 100 sender selector 4700 and also the operated switches in the terminating office. The release of the incoming selector switch 4600 and the removal of ground from the holding conductor of trunk 4606 results in the restoration of the relays 5344 and 5341, no ringing current having been applied to the called line since the group selector and connector switches were not operated.

Message registration.

If the subscriber's lines in the originating office are provided with message registers for measuring the service rendered, these registers must be operated on successful calls and prevented from operating when the called line is found busy or when the called subscriber fails to answer. Assuming that the subscriber's line 101 is equipped with the message register 172, this line will 110 have access through the line switch to trunks equipped with the necessary apparatus, as in the case of trunk 114, for controlling the message register operation. Consider that the subscriber of line 101 has succeeded in 115 120 125 130

building up a connection in the manner hereinbefore discussed to the called subscriber's line 5416 which was tested and found idle. In response to the ringing, the 5 called subscriber removes his receiver from the switchhook and in so doing relay 5341 is caused to operate to remove ringing current and to connect the called subscriber's line through to the left-hand windings of 10 repeating coil 4500. Relay 4513 being included in this circuit operates and closes a circuit for the reversing relay 4503. Relay 4503 reverses the connections of the relay 4504 to the tip and ring conductors of the 15 trunk, thereby causing the reversal of current through the polarized relay 233 at the originating office. Relay 233 operates and closes a circuit from battery through the winding of relay 229, outer right contact of 20 relay 228 to ground at the contact of relay 233. Relay 229 energizes and locks in a circuit from battery through its winding and right contact, right back contact of slow-to-release relay 228 to ground at the 25 left contact of relay 204. The relay 229 is thus operated in response to the removal of the called subscriber's receiver to record the fact that the call proved to be successful.

At the end of conversation when the calling subscriber hangs up his receiver the circuit of relay 203 is opened and this relay releases to close the following circuit: battery through the winding of relay 228, left contact of relay 229, back contact of relay 30 203 to ground. Relay 228 operates and at its right contacts, opens both the operating and locking circuits of relay 229. Relay 229 releases and opens the circuit of relay 228 which commences to deenergize. During 35 the time that relay 228 is holding its armatures attracted a circuit is closed from battery through the winding of relay 204, inner right front contact of relay 228 to ground at the left contact of relay 204. Relay 204, therefore, remains operated to prevent release of the connection following the release of relay 203. During the period measured by the slow release relay 228, a 40 circuit is completed for operating the subscriber's message register 172. This circuit is traceable from ground through the left contact of relay 228, conductor 152, through contacts of the switch 100, winding of message register 172 to battery.

55 *The establishment of connection through a single tandem office involving partial transfer of record to the tandem office.*

60 The case will now be considered in which the subscriber whose line terminates in an office lying at a relatively short distance from the tandem point wishes to converse with the subscriber of a line in a called office 65 similarly situated with respect to the tan-

dem office. Referring to Fig. 59, such a call corresponds to one from one of the lines 5918 in the office 5903, through the tandem office 5900 to the called line 5912 terminating in the office 5905. The total trunking 70 distance from the originating office to the called office being comparatively short, code impulses representing the designation may be transmitted directly from the calling office through the tandem point to the called office 75 without the necessity of making an intermediate registration at the tandem office. Therefore, as soon as the originating office obtains a trunk leading to the tandem point, the office code designation and that 80 only is transferred to the tandem office to determine the selection of a trunk to the final office, whereupon the numerical portion of the designation is transmitted directly from the originating to the called office. 85 This method of procedure calls for different action on the part of the equipment in the originating office and also on the part of the apparatus in the tandem office. In the case first mentioned where the full record 90 was sent from the calling office, the sender was permitted to release as soon as this had been accomplished. In the present case, however, only part of the record is transmitted and following this the sender must 95 wait until conditions have been prepared for the transfer of the remaining part of the designation. With respect to the tandem office in the case first assumed where 100 the complete record was received from the calling office, the tandem sender had to prepare itself to transfer a portion of this record on to the terminating office, whereas in the present case, the tandem sender is not required to perform this duty.

105 It was pointed out hereinbefore that a tandem sender in order to prepare itself for the particular type of a call now being considered depends upon two different factors. One is the length of the trunk incoming from a calling office and the other is the character of the office code which determines the class of the trunk outgoing from the tandem office to the terminating office. Referring to Fig. 25 one test condition is obtained by strapping the terminals of a connecting block 2540; these terminals are individual to the incoming trunk. In the previous call it was considered that the trunk 1823 led into the tandem office from the distant calling office; in that case, the terminals of block 2540 were disconnected. For the purpose of the call now being considered, however, it will be assumed that the trunk 115 1823 is one which comes from a nearby calling office and hence the strap is connected to the terminals of block 2540 as illustrated by the dotted line. Since the trunk outgoing from the tandem office, which in this case will be considered as the trunk 2428, 120

leads to a nearby terminal office, the office code which represents this trunk when received at the tandem point affects the tandem sender accordingly. In other words this 5 office code through the medium of the translator in the tandem marker, in conjunction with the relay 2662, which records the fact that the terminals 2540 were grounded will bring about the operation of class relay 10 2673.

Assume that the name of the called office is one having the abbreviation LER which corresponds to a series of five, three and seven impulses and also assume that the 15 number of the called line is 1 3 2 6. It will be noted that the office code LER differs from the one first assumed only in the first letter, while the numerical part of the designation is identical with that of the called 20 line first discussed. Inasmuch as the equipment in calling and called offices is substantially the same regardless of their location with respect to the tandem point, the apparatus used for describing the present call is 25 the same as that previously considered except that it is assumed to be located in a different calling and a different called office respectively.

30 *Initiation of call and attachment of an idle sender.*

When the calling subscriber of the line 101 initiates the call the operations involved 35 in the extension of his line through a line switch 100 to an idle trunk 114, the association of an idle register sender with the selected trunk and the association of the equipment for receiving impulses all take 40 place in substantially the same manner as hereinbefore described.

When the sender has been attached and the subscriber has received the customary dialling tone, he manipulates his transmitter 45 171 to send the first series of five impulses representing the first letter L in the first abbreviation. In response to this series of impulses the counting relays in Fig. 4 are operated until upon the receipt of the last 50 impulse, relay 417 is energized and locked and the preceding counting relays are all deenergized. After an interval has expired following the last impulse, the slow relay 405 releases and a circuit is closed from the 55 grounded conductor 425 as hereinbefore explained through the contact of relay 405, right front contact of relay 404, inner left contact of relay 403, conductor 434, right back contact of relay 710, winding of relay 60 709 to battery. Relay 709 operates and closes a holding circuit for itself in series with the winding of relay 403 as previously described. With the counting relay 417 operated, a circuit is closed from ground over 65 conductors 432 and 431, through the inner

left contact of relay 417, inner left contact of relay 413, conductor 441, lowermost contact of relay 709, winding of register relay 706, winding of relay 708 to battery. Relays 708 and 706 operate, relay 707 locking to the grounded conductor 736. From this point on, the operation of the apparatus and the receipt of the impulses from the calling subscriber's line takes place in identically the same manner as previously described. The last two series of impulses in the office designation being 3 and 7 in number respectively, the register relays 711, 712, 719 and 721 are operated as above explained. Similarly, the numerical designation consisting of digits 1, 3, 2 and 6, the corresponding series of impulses cause the operation of register relays 803, 810, 811, 903, 912 and 915.

85 *Attachment of district marker, transfer of record from sender to marker and selection of outgoing trunk.*

Following the operation of the thousands register 800, the district marker is associated 90 with the register sender through the sender connector 1400 ready for transferring the office record from the sender to the marker. As soon as the relays 1101 and 1106 have 95 operated following the association of the marker, a circuit is closed from ground through the contact of relay 1104, conductor 1116, thence through the inner left contact of relay 1106, conductor 1123, contact of relay 1401, conductor 1434, conductor 747, 100 outermost right contact of register relay 706, conductor 754, contact of relay 1401, conductor 1463, winding of relay 1224 of the register 1201 to battery. The other two registers 701 and 702 being positioned the 105 same as above described, the registers 1202 and 1203 in the marker likewise take up similar settings and hence no further description of this operation is necessary. From this point on, the operation of the translator 1200, 110 1220 for the purpose of selecting one of the group relays 1306, 1307, 1308 and 1309, the selection of the proper group of trunks on the district selector switch 1000, the testing and selection of an idle one of these trunks 115 and an idle link, and finally the operation of the district switch to extend the connection through to the office selector takes place in substantially the same manner as that previously related. Since the relay 1224 in 120 the register 1201 is operated, a different one of the multicontact relays 1209, 1210, 1211, etc. in the translator will be operated. This means that instead of operating the group relay 1309 in Fig. 13, a different one of 125 these relays may be chosen relating to a different group of trunks on the district switch 1000, inasmuch as the call is destined for an office different from the one previously discussed. If desirable, the same group relay 130

1309 may be selected to select the same group of trunks leading to the office selector with the different setting of the register 1201 inasmuch as the connection must first be routed to the tandem office. It is only necessary that the office code control the tandem equipment in such a way that the proper called office will be selected.

10 *Class indications.*

The district marker is released as soon as the outgoing trunk has been chosen, but before this is done and while selection is taking place, the district marker in accordance with the office code determines the necessary class indications in the recording sender. The present call is one which requires the originating sender to transfer the numerical part of the record from the originating office to the terminating office, and to identify this particular type of a call, the class relay 657 in the sender must remain deenergized, whereas relays 613, 501 and 502 are operated as in the previous instance. In the manner above explained, relay 207 in Fig. 2 is operated, but relay 206 in this case will remain deenergized. The reason for leaving relay 206 deenergized is to include only a part of the right-hand windings of the repeating coil 227 in the talking circuit inasmuch as the length of the trunk is comparatively short and only a minimum amount of loading is required.

35 Considering the translator in the district marker, due to the fact that the register relay 1224 is operated, a circuit is traceable over the grounded conductor 1125, outer left contact of relay 1227, left contact of relay 40 1224, left back contact of relay 1225, outer left contact of relay 1226, winding of the multicontact relay 1209 to battery. With relay 1209 operated a circuit is closed from ground at the outer right contact of relay 45 1106, conductor 1132, through contacts of relay 1209 to the horizontal conductor 1255, contact of relay 1205, conductor 1256, winding of relay 1464 to battery. Relay 1464 closes a circuit from ground through its 50 outer right contact, conductor 1454, contact of relay 1401, conductor 1457, winding of relay 501 to battery. Another circuit is closed from ground through the inner right contact of relay 1464, conductor 1455, thence over conductor 1459, through the winding of relay 55 60 613 to battery. A third circuit is closed from ground through the left contact of relay 1464, conductor 1453, thence over conductor 1458, through the winding of relay 60 613 to battery. Relays 501, 502 and 613 operate and lock in the manner previously described. Relay 1464 closes another circuit from ground through its outer left contact, thence over conductor 1460, through the district selector switch 1000, conductor 1032,

winding of relay 207 to battery. Relay 207 operates and locks to conductor 150.

Operation of the office selector.

Following the operation of the district switch, the recording sender is associated with the office marker, the office code is transferred from the register sender to the office marker registers 2002 and 2004 in the manner already described and the office switch is operated to extend the connection over an idle trunk leading to the tandem switching office. Following this, the office marker is released from the recording sender.

Transfer of the office record from the originating office to the sender at the tandem office.

At the time the subscriber's line is extended over the interoffice trunk 1823 to the tandem switching point, relay 604 is operated in the manner hereinbefore described. Relay 604 connects the winding of relay 607 across the tip and ring conductors of the outgoing trunk, whereupon relay 608 operates and locks. Also in the manner fully explained, sender selector switch 2500 at the tandem point operates in response to the connection to associate an idle sender with the incoming trunk 1823.

When the trunk 1823 has been extended through contacts of relay 2302 to the sender selector, relay 607 releases and relay 606 is operated.

At this time provided the thousands digit has been received and recorded on the register 800, relay 614 is operated in a circuit from battery through its winding, left back contact of relay 657, conductor 672, outer left contact of relay 729, conductor 673, inner right front contact of relay 613, conductor 841, outer left back contact of relay 820, outer left contact of relay 808, conductor 612, outer right contact of relay 608 to ground. Relay 614 as above explained will remain energized until each of the numerical registers has served in connection with the transmission of outgoing impulses.

With relay 614 operated the relays 615 and 616 are set in operation and relay 620 is energized as previously described. Relay 620 closes a circuit for relay 726 which operates and prepares a holding circuit for itself and relay 621. While relays 615 and 616 are undergoing their first deenergization, an inspection of the circuits will show that no impulse is transmitted over the line to the tandem office. Following the release of relays 615 and 616, relays 618, 619 and 640 operate. The relays 615 and 616 then energize successively and during this period, the negative pole of battery is connected to the ring side of the line, through the high

resistance 763, whereby a light negative impulse is transmitted to the tandem office. In response to this impulse, relay 2675 operates causing the operation of relay 2679. Relay 5 2679 closes a circuit for relay 2731. Relay 619, in operating, closes a circuit for relay 725 whereupon relay 621 operates in series with relay 726. Following the operation of relays 615 and 616, relay 617 operates 10 and relay 640 releases. Relay 640 opens the circuit of relay 2675 which permits the operation of relay 2678.

During the next period, relays 615 and 616 release successively, but no impulse is transmitted 15 over the line circuit. Upon the release of these relays relay 618 deenergizes and relay 640 operates. Lastly, relays 615 and 616 operate and during the interval required for this purpose, a circuit is closed 20 from the positive pole of battery over conductor 639, as previously traced, inner left front contact of relay 640, thence over the tip side of the line and returning over the ring side of the line through the middle 25 left front contact of relay 640, outer left contact of said relay, conductor 680, outer right front contact of relay 617, conductor 654, thence through the uppermost contact of relay 726, outermost left contact of relay 30 706, through the low resistance 764 to the opposite pole of battery. In response to this impulse relays 2674 and 2675 operate. Relay 2675 shunts relay 2679, which in turn, is released. Relay 2674 closes a circuit from 35 ground over conductor 2683, contact of said relay, outer right front contact of relay 2678, inner upper back contact of relay 2730, winding of relay 2761 to battery. Relay 2761 operates and locks to the grounded conductor 2684. At the end of the period when 40 relays 615 and 616 have operated, relays 617, 620, 619 and 640 become deenergized. Relay 640 interrupts the impulse circuit causing the release of relays 2674, 2675 and 45 2678. Relay 2630 now operates in series with relay 2631. At the originating office relay 620, in releasing, opens the circuit of relays 621 and 726.

Thus, the first digit representing the letter L is transmitted from the originating office to the tandem office. Following this and in the manner precisely as hereinbefore explained, the next two digits E and R are transmitted and recorded on the registers 50 2701 and 2702 in the tandem office sender.

When the third digit has been transferred relays 617, 620, 619 and 640 are released and when relay 620 again operates a circuit is closed from ground through its 55 outer right back contact of relay 621, middle left contact of relay 613, conductor 669, outer right front contacts of relays 725, 727 and 729, conductor 765, outer right back contact of relay 657, right contact of slow relay 610, inner left back contact of relay 660, 60 winding of relay 661 to battery. Relay 661 operates and at its inner right contact closes a holding circuit for itself and relay 660 to ground over conductors 658 and 507. Relay 660, however, being shunted does not 65 operate. A circuit is closed for relay 610 traceable through the right back contact of relay 660, outer right front contact of relay 661 to ground over conductor 658. Relay 610 operates and at its left contact opens the 70 holding circuits of relays 606 and 608. Relay 606 releases relay 633, opens the circuit of relay 618 and the time counting relays 615 and 616 are rendered inoperative. Relay 608 opens the shunt circuit of relay 619 75 which operates. Relay 619 in operating causes the release of relays 620 and 619. Relay 610, in operating, opens its right contact and removes the shunt from around the winding of relay 660 which thereupon energizes in series with relay 661. Relay 660 opens the circuit of relay 610 which proceeds to release. Thus at the end of the transmission of the office code, the impulse mechanism in the originating sender is rendered 80 inoperative in order that the numerical part of the designation may be held up until the equipment in the tandem and final offices is in readiness to receive the same. It will be 85 noted that when relay 606 releases, the winding of relay 607 is again connected across the tip and ring conductors of the trunk outgoing to the terminal office. This relay does not operate, however, since at the tandem office the trunk encounters the dry bridge afforded by the polarized relays 2675 and 2676 and the marginal relay 2674 in the 90 sender. The relay 607 must wait until battery connection is provided at the distant end, at which time, it will operate and start the impulse mechanisms sending the numerical part of the designation.

Selection at the tandem office.

In the same manner as hereinbefore explained following the receipt of the office code in the tandem sender, the sender is associated with the tandem marker through the connecting device 3300. When relay 3006 is operated a circuit is closed from ground over conductor 3008 to the inner left contact of relay 3006, conductor 3012, relay 3301, conductor 3317, outer right contact of register relay 2761, conductor 2756, contact of relay 3301, conductor 3325, winding of register relay 3126 to battery. Similarly, circuits are closed as hereinbefore described for the register relays 3122, 3123, 3124 and 3125. With the registers 3101, 3102 and 3103 positioned, a circuit is first closed from ground over conductor 3013, through the outer left contact of relay 3139, left contact of relay 3126, left back contact of relay 3121, outer left back contact of relay 3140, winding of multicontact relay 3109 to battery.

Due to the settings of register 3103, as above explained, the multicontact relay 3119 is operated. Next, a circuit is traced over the grounded conductor 3013, inner right back contacts of relays 3128 and 3129, inner right front contact of relay 3123, inner left front contact of relay 3122, contact of relay 3119, conductor 3132, winding of relay 3105 to battery. Thereupon, a circuit is traceable from ground over conductor 3013, conductor 3133, contacts of relay 3109, horizontal conductor 3142, contact of relay 3105, conductor 3144, winding of the group relay 3249, conductor 3215, left back contact of relay 3216 to battery. Relay 3249 is individual to the particular group of trunks on the district selector 2400 which leads to the called office. This relay operates and in the manner explained causes the district switch 2400 to operate and select this group of trunks to choose an idle one therein leading to the called office. As a matter of fact the group of trunks to which the relay 3249 is individual and which lead to the called office, in the present case, differs from the group previously considered, namely, the group containing the trunk 2428. For instance, the group of trunks being considered in the present call, might appear in the vertical row 2414, or in any other vertical row other than the upper section of the vertical row 2413. Inasmuch as only the trunk 2428 is shown in full, it will be assumed, merely for the purpose of description, that this trunk leads to the office desired for the present connection.

Class indications.

Due to the character of the office code, the translator 3100, 3120 determines the operation of certain class relays in the sender. As hereinbefore noted, one of these class relays 2673 is operated by the translator in conjunction with the individual connection at the connecting block 2540 pertaining to the incoming trunk 1823. These class indications are recorded prior to the time the tandem marker is released following the operation of the tandem district switch 2400. Recalling the operation of the sender selector 2500, it will be remembered that when the magnet 2531 operates, a circuit is closed from ground through the outer right contact of said magnet, conductor 2532, winding of slow release relay 2667 to battery. Relay 2667 operates and locks through the contact of relay 2668. Relay 2867 also closes a circuit for slow operating relay 2663. Following this, the selector horizontal magnet is operated and thereupon a circuit is completed from ground through the connecting block 2540, outer right contact of relay 2513, through contacts of the selector 2500, conductor 2536, right back contact of relay 2663, winding

of slow release relay 2662 to battery. Relay 2662 operates and locks to the grounded conductor 2684. An instant later the magnet 2531 releases and removes ground from conductor 2532 so that now a circuit may be traced from battery through the winding of magnet 2510, relay 2509, through contacts of the selector 2500, conductor 2532, to ground at the inner left contact of relay 2667.

When, subsequently, the translator of the tandem marker is positioned, a circuit may be traced from battery through the windings of relays 2673 and 2695 in parallel, right contact of relay 2662, outer left contact of relay 2670, conductor 2693, contact of relay 3301, conductor 3326, contact of relay 3105, contact of relay 3109, conductor 3015 to ground at the right contact of relay 3006. Relays 2673 and 2695 operate and lock through the outer left contact of relay 2673 to the grounded conductor 2684.

It may be noted in the present case where the connection involves only one office beyond the tandem point and where the thousands register 2800 is not positioned, since no numerical pulses are received, that another circuit is traceable for the class relay 2673 and the relay 2695. This path may be followed from battery through the relays, conductor 2694, outer left back contact of relay 2808 which is deenergized at the time the marker is associated since no thousands impulses are incoming, thence over conductor 2830, back contact of the class relay 2660, outermost left contact of relay 2661, outer right front contact of relay 2665, conductor 2745 to ground at the inner lower contact of relay 2743. It is possible that the connection may involve a number of offices succeeding the tandem office under discussion and hence the tandem sender must be arranged to take this fact into account, as will be explained more fully hereinafter. Where a succeeding tandem office is involved the class relay 2660 will be operated and hence the circuit just traced for the relays 2673 and 2695 will be broken but the relays will be operated notwithstanding the fact that the thousands register 2800 had not received any impulses. Therefore, the operation of the class relay 2673 which notifies the tandem sender that the numerical portion of the designation is going to be transmitted directly from the originating office, through the tandem office to the office beyond, must depend upon the operation of relay 2662 and upon the translator of the tandem marker.

Another class circuit is completed from ground through the translator 3120, as hereinbefore described, thence over conductor 3138, through the winding of the class relay 2917 to battery. Relay 2917 operates and locks to the grounded conductor 2684.

As soon as the connection is extended through the tandem district switch 2400 over the trunk 2428, to the terminating office, a circuit is completed from battery 5 through the left-hand winding of relay 4504, left normal contact of relay 4503, upper left winding of repeating coil 4500, inner right back contact of relay 4501, thence over the tip side of the line through 10 the district selector switch 2400 in the tandem office, through the tip side of the trunk 1823, left back contact of relay 2305, thence over conductor 2317, through the sender selector to conductor 2536, right front contact 15 of relay 2663 winding of the polarized relay 2672, outer right front contact of relay 2673, conductor 2534, thence through the sender selector 2500 to conductor 2309, inner right front contact of relay 2302, upper back 20 contact of relay 2300, thence over the tip side of the trunk 1823 to the originating office and as traced through the winding of relay 607 and returning over the ring side of the trunk to the tandem office through 25 the lower back contact of relay 2300, outer left front contact of relay 2302, conductor 2310, through the sender selector switch 2500 to the conductor 2535, left front contact of relay 2673, conductor 2537, through the 30 sender selector switch to conductor 2318, inner right back contact of relay 2305, thence over the ring side of the trunk to the tandem district switch 2400 to the terminating office, through the outer right back contact of relay 4501, lower left winding of repeating coil 4500, right normal contact of relay 4503, right-hand winding of relay 4504 to ground. Relays 4504 and 607 operate in this circuit. The direction of the flow of current in this 35 circuit is such that the polarized relay 2672 in the tandem office sender also becomes operated.

The purpose of the polarized relay 2672 is to make an account of the number of 45 digits as they are transmitted from the originating office through the tandem office to the final office. The reason for this is to give a signal to the tandem office sender at the proper time and only then to release. 50 It must wait until the four numerical digits have been sent through to the final office before it releases since the impulse circuit over which the code impulses are transmitted extends through the tandem sender. 55 The polarized relay 2672 is brought into the impulse circuit by means of the relay 2673 which is operated on this class of the call. The relay 2672 in conjunction with relays 2678 and 2679 makes an account for each 60 digit transmitted. While there are four digits to be sent, it is obvious that the relay 2672 should be provided to make five separate counts before releasing the tandem sender. The first of these counts is due to the 65 closure of the impulse circuit as just traced

and the other four each pertain to one of the numerical digits. Relay 2672 is polarized in such a manner that it responds to code impulses of a negative character; that is, the impulse flowing when the negative pole 70 of battery is connected to the ring side of the line. From an examination of the code impulses thoroughly explained hereinbefore, it will be found that for each digit transmitted there are two negative impulses regardless of what the digit may be. One of these negative impulses occurs during the second quarter or during the period when relays 615 and 616 are undergoing their first energization and the second negative 75 impulse occurs in the last quarter or while the relays 615 and 616 are undergoing their second energization. Therefore, the relay 2672 in the tandem office operates twice for each of the digits transmitted. As will be seen from the detail description following, the relays 2678 and 2679 respond to the two negative impulses occurring with respect to each digit to make a single count. The polarized relay 2672, in operating, closes a 80 circuit from the grounded conductor 2684, contact of said relay, right back contact of counting relay 2681, winding of relay 2680 to battery. Relay 2680 operates and closes a series circuit for itself and relay 2681. 85 Relay 2681 being shunted, however, remains deenergized.

At the originating office the relay 607 in operating closes a circuit from battery through the winding of relay 608, left front 100 contact of relay 661, outer left contact of relay 660, outer contact of relay 607 to ground over conductor 609 as hereinbefore traced. Relay 608 operates and locks to conductor 609. With relay 608 operated, 105 the relay 614 again becomes energized.

At the terminating office the relay 4504 in operating causes in the manner explained, the operation of the sender selector switch 4700 to associate an idle register sender 110 with the incoming trunk 2428, the preparation of said sender and the operation of relay 4501 to extend the tip and ring conductors to the associated sender ready for receiving the incoming impulses.

Transfer of numerical record from the originating office to the terminating office.

When the sender selector 4700 operates to attach the sender, relay 4501 energizes and disconnects the battery supply from the trunk 2428, whereupon relay 607 at the originating office releases and relay 2681 at the tandem office operates. With relay 607 down, the relay 606 is operated in the manner hereinbefore described and the mechanism is ready to commence the transmission of impulses. When relay 620 operates, it closes the circuit traced from ground through its outer right contact, thence over 120

conductor 669, outer right front contacts of relays 725, 727 and 729, conductor 765, outer right back contact of relay 657, right contact of relay 610, inner right front contact of relay 660, conductor 626, and thence as traced over conductor 651, through the outer right back contact of relay 820, winding of relay 821 to battery. From this point on the apparatus functions in the same manner 10 as that already explained for transmitting code impulses representing the thousands, hundreds, tens and units digits. These impulses are received as fully explained by the control relay 4816, 4817 and 4818 at the 15 terminating office and result in the operation of the registers 4900, 4901, 5000 and 5001.

Considering the tandem office, the polarized relay 2672 is operated and releases eight different times during the transmission of 20 the four digits by reason of the negative impulses. On the operation of relay 2672 in the transmission of the first digit, a circuit is closed from ground over conductor 2684, contact of said relay, front contact of 25 relay 2681, left back contact of relay 2678, left-hand windings of relays 2679 and 2678 to battery. Relay 2679 operates, but relay 2678 remains deenergized. Relay 2679 closes a circuit from ground over conductor 2684, 30 outer right contact of said relay, conductor 2685, lower front contact of relays 2730, 2736 and 2738 lower back contact of relay 2812, winding of relay 2810 to battery. Relay 2810 operates and prepares a circuit for 35 relay 2812. When relay 2672 releases relay 2678 operates. At the next negative impulse relay 2672 operates, whereupon relay 2679 releases. At the end of this second negative impulse relay 2678 releases permitting relay 2812 to operate in series with relay 2810. Similarly in response to the transmission of the next three digits, relays 2813, 2815, 2821, 2820, 2912, 2914 and 2920 are 40 operated.

45 *Release of the sender in the tandem office.*

After the last digit has passed through the tandem office and relay 2920 is operated, as explained, a circuit is prepared for the 50 release relay 2668 to cause the release of the tandem sender. This circuit may be traced from battery through the winding of said relay, conductor 2918, lower front contact of relay 2695, conductor 2624, inner lower 55 front contact of relay 2917 to ground at the lower contact of relay 2920. Relay 2668 operates and in the manner above explained brings about a release of the sender, sender selector and register circuits in the tandem 60 office.

Release of the sender in the originating office.

Following the transmission of the units 65 digit, relay 620 again operates and closes a

circuit as hereinbefore traced for the sender release relay 412. Relay 412 brings about a release of the sender selector switch 300 and the associated sender and register circuit. The release of the sender causes the 70 release of relay 201 together with the release of relays 205 and 206. The polarized relay 233 is connected through the upper and lower halves respectively of the upper and lower right-hand windings of repeating coil 227, to the tip and ring conductors of the outgoing trunk circuit 114 which extend through the district and office selectors in the originating office, through the windings of relay 2301 in the tandem office, 75 thence through the district selector switch 2400 in the tandem office to the sender associated with the trunk 2428 at the final terminating office.

It will be recalled that following the receipt of the units digit at the sender of the terminating office, relay 4808 is operated in the manner above explained to include the windings of the battery feed relay 4806 across the tip and ring conductors of the 80 trunk. The performance of these several operations, namely, the release of the senders at the originating and tandem offices and the connection of battery and ground across the tip and ring conductors at the 85 terminating office all take place in such a manner that relay 2301 in the tandem office is energized to maintain the operation of slow relay 2303 before it has time to release following the opening of its circuit by the 90 release of relay 2302.

Completion of the connection at the final office.

After the numerical record has been received on the registers 4900, 4901, 5000 and 5001 at the terminating office, the incoming sender is associated with the incoming marker for controlling the operation of the incoming switch 4600 and, thereafter, is associated with the line marker to control the operation of the group selector and connector switches 5300 and 5400. The connection is established and ringing current is applied to the called subscriber's line all in substantially the same manner as fully explained heretofore. Following the completion of the connection the line marker and the incoming sender are disassociated and the trunk circuit is converted into condition 110 for conversation.

Release of established connection.

After conversation has been completed the subscribers replace their receivers on the switchhook and the entire connection is released in the manner already fully explained.

Establishment of a connection through two tandem offices involving transfer of record to each tandem office.

- 5 The next type of a call to be treated in the present system is one which involves an originating office more than one tandem office as, for example, two tandem offices and a final terminating office. It is assumed too
 10 that the distances between the several offices are such that it is necessary to transfer the complete record from the originating office into the first tandem to transfer the complete record from the first tandem into the
 15 second tandem office and, thereafter, to transfer the numerical record from the second tandem office, to the called office. Referring to Fig. 59 a call of this class may be represented by a connection extended from
 20 the subscriber's line 5920 in the originating office 5904 through the tandem office 5900, thence over an interconnecting trunk to the second tandem office 5901, thence to the subscriber's line 5922 in the called office 5909.
 25 For this call it will be assumed that the abbreviation of the office name is FER corresponding to a series of 3, 3, and 7 impulses, while the numerical part of the designation will for simplicity be kept the same
 30 as before, namely, 1 3 2 6.

Initiation of a call and operation of the apparatus in the originating office.

- 35 As heretofore explained the initiation of the call results in the operation of the line switch 100 and the sender selector 300 and an idle register sender is associated with the calling subscriber's line. In response to the
 40 first series of impulses, the counting relays in Fig. 4 operate and the register 700 is positioned by the operation of relays 703 and 704. The next two registers 701 and 702 take the same settings as previously de-
 45 scribed. Also the four numerical registers succeeding take up their settings as is now well understood.

After the district marker has been associated with the register sender through the connector 1400 and relay 1106 is operated, the ground is applied to conductor 1434 as above explained and a circuit is traceable from this conductor over conductor 747, thence through the outer right contacts of register relays 703 and 704, conductors 774 and 775, respectively, contacts of relay 1401, conductors 1466 and 1467, respectively, windings of register relays 1227, and 1226 to battery. The registers 1202 and 1203 take the same settings as before. With relays 1227 and 1226 operated, it will be found from inspection that the multicontact relay 1211 of the translator 1220 is energized.

65 Following the setting of the translator

and the district marker, one of the group relays in Fig. 13 is operated and district selector switch 1000 is actuated to extend the connection over an idle trunk to the office selector. Thereafter, the office switch 70 is operated to extend the connection over an idle outgoing trunk such as the trunk 1823 leading to the first tandem office.

Before the district marker is released, the necessary class indications are transmitted 75 to the sender for this particular class of call. With the translator operated a circuit is closed over the grounded conductor 1132, through the horizontal conductor 1244 of the translator, contacts of relay 1211, horizontal conductors 1258 and 1259, contacts of relay 1205, thence over conductors 1240 and 1241, through the winding of relays 1450 and 1451 to battery. Relays 1450 and 1451 operate and in the manner herein- 80 before explained cause the operation of relays 207 and 206 and the class relays 502, 501, 613 and 657.

Transfer of the full record from the originating office to the first tandem office. 90

When the connection has been extended to the tandem office, the impulse mechanism in the originating sender is set in operation to transmit the full record consisting of the office abbreviation code and the numerical designation from the originating office to the corresponding registers in the sender of the first tandem office. The manner in which the sender is associated with the incoming trunk 1823, respectively, of the connection in the tandem office has already been fully discussed. Where the first digit representing the letter F corresponds to the numerical digit 3, the code impulses received on the tandem office cause the operation of the register relays 2758 and 2759 of the register 2700. The remaining registers take the same settings as previously described. 100 105 110

Operation of apparatus in the first tandem office.

After the record has been received in the tandem office, the tandem district marker is 115 associated with the sender and due to the fact that the register relays 2758 and 2759 are operated, an inspection of the circuits will show that the register relays 3139 and 3140 of the register 3101 are energized, whereas the registers 3102 and 3103 take the same settings as before. With relays 3139 and 3140 operated the multicontact relay 3146 is energized. The multicontact relays 3105 and 3119 are also operated as 120 previously explained. After the translator is positioned, one of the group relays in Fig. 32 is operated causing thereby the operation of the tandem district selector 2400 to select an idle one of the group of trunks 130

outgoing to the second tandem office, illustrated in Figs. 34 to 44, inclusive. It will be assumed that the idle trunk selected interconnecting the tandem office is the trunk 5 2428.

Class indications.

Before the marker of the first tandem office is released, the class indications are 10 set up in the tandem sender. For this purpose a circuit may be traced from ground over conductor 3015, horizontal conductor 3136, contacts of relay 3146, horizontal conductor 3149, contact of relay 3105, winding 15 of relay 3148 to battery. Relay 3148 operates and closes a circuit from ground through its inner contact, conductor 3150, contact of relay 3301, conductor 3328, winding of relay 2657 to battery. Relay 2657 20 operates and locks to the grounded conductor 2684. Another circuit is closed from ground through the middle contact of relay 3148, conductor 3151, contact of relay 3301, conductor 3329, winding of relay 2660 to 25 battery. Relay 2660 operates and locks to the grounded conductor 2684. Still another circuit is closed from ground through the outer contact of relay 3148, conductor 3188, thence as previously traced over conductor 3322, through the winding of relay 2917 to battery. Relay 2917 operates and locks to the grounded conductor 2684. Still another circuit is closed from ground through the right contacts of relay 3148, 30 conductor 3152, contact of relay 3301, conductor 3330, winding of relay 2613 to battery. Relay 2613 operates and locks to the grounded conductor 2684.

Inasmuch as the complete record is to be 40 received at the first tandem office, the connecting block 2540 for the incoming trunk is disconnected from ground, and consequently, the relay 2662 remains deenergized. Moreover, since the call is one involving a tandem 45 office beyond the first tandem office, relay 2660 is operated as explained. The relay 2673 has both of its operating paths open. One of these is held open at the right contact of relay 2662 and the other is open at 50 the right back contact of relay 2660.

Association of sender at second tandem office with the incoming trunk.

The connection has been extended from 55 the first tandem office to the second tandem office and the next operation to take place is the transfer of the full record consisting of the office and numerical parts from the sender at the first tandem to the sender at 60 the second tandem office as soon as the equipment at the second tandem office is ready to receive the same. With the class relay 2660 operated and with the relay 2665 operated at the time the tandem district marker is 65 discharged, a circuit is closed from battery

through the winding of relay 2604, right front contact of relay 2660, outermost left contact of relay 2661, outer right front contact of relay 2665, conductor 2745 to ground at the inner lower contact of relay 2743. Relay 2604 operates and locks to ground over conductors 2697 and 2684. 70

An idle register sender in the second tandem office is associated with the incoming trunk 2428 through the operation of the 75 sender selector switch 3600 in substantially the same manner as that explained in connection with the association of the sender at the first tandem office. Upon the extension of the connection to the second tandem 80 office, a circuit is completed from battery through the winding of relay 3400 left contact of relay 3403 inner right contact of relay 3401, upper back contact of relay 3402, thence over the tip side of the trunk 2428, 85 through the tandem district switch 2400 at the first tandem office, over the tip side of the trunk 1823, thence through the inner left back contact of relay 2305, thence over conductor 2317, through the 90 sender selector switch 2500 to the conductor 2536, right front contact of relay 2663, upper back contact of relay 2695, conductor 2650 outer right contacts of relays 2604 and 2606, winding of relay 2607, 95 thence through the inner right contacts of relays 2606 and 2604, conductor 2651 inner upper contact of relay 2695, over conductor 2537, through the sender selector 2500 conductor 2318 inner right back contact of relay 2305 and returning over the ring side of the trunk to the second tandem office, thence through the lower back contact of relay 3402, outer left back contact of relay 3401 to ground. Relays 2607 and 3400 105 operate in this circuit. Relay 3400 operates and closes a circuit for relay 3602, which in the manner already explained, operates and brings the various relays associated with the sender selector switch 3600 into operation. These relays cause the operation of the sender selector to associate an idle register sender with the incoming trunk 2428. Inasmuch as the register sender in the second tandem office is substantially the same as that fully 110 described at the first tandem office, a repetition of the description already given will be avoided as far as possible. 115

When the sender selector switch 3600 is 120 in operation the vertical magnet 3607 at its outer right contact applies ground to conductor 3610 causing the operation of the sender holding relay 3700. Relay 3700 energizes and applies ground potential to the holding conductors 3701, 3702 and 3703. 125 Following the operation of the sender selector switch 3600, ground potential is extended from the sender over the conductor 3610, through contacts of the sender selector to hold the magnet 3604 and relay 3605 for 130

example, energized, and to operate relay 3401. Relay 3401 closes a circuit for the slow relay 3403 and opens the circuit of relay 3400. Moreover, relay 3401 extends the tip and ring conductors of the incoming trunk 2428 into the associated sender. The circuit completed by this extension may be traced from the tip conductor of the trunk 2428, through the upper back contact of relay 3402, inner right front contact of relay 3401, conductor 3404, through contacts of the switch 3600, conductor 3611, outer right back contact of relay 3704, winding of marginal relay 3705, through the polarized relays 3706 and 3707, inner left back contact of relay 3704, conductor 3612, contacts of the switch 3600, conductor 3405, outer left front contact of relay 3401, lower back contact of relay 3402 to the ring side of the trunk 2428.

²⁰ Transfer of record from the first tandem office to the second tandem office.

At the time relay 2607 is operated in series with relay 3400 at the second tandem office, it closes a circuit for relay 2608 which operates and locks to the grounded conductor 2633. Shortly thereafter relay 3400 is disconnected from the trunk by the operation of relay 3401, whereupon relay 2607 at the first tandem office releases and relay 2606 is operated and locked in the manner hereinbefore described. With relay 2608 operated relay 2614 is energized and relays 2615 and 2616 commence to operate for the purpose of measuring and transmitting code impulses over the interoffice trunk to the second tandem office sender.

When relay 2620 operates it completes a circuit from ground through its outer right contact, contact of relay 2621, right front contact of relay 2613, conductor 2698, left back contact of relay 2710, winding of relay 2709 to battery. Relay 2709 operates and closes a circuit for itself over conductor 2827, through the winding of relay 2621 to ground, relay 2621 remaining deenergized by reason of a shunt around its winding. Relay 2709 operates and connects the impulse sending mechanisms with the first office register 2700. In the manner already described in detail code impulses are transmitted over the connection in accordance with settings of the registers 2700, 2701 and 2702 to the receiving relays 3705, 3706 and 55 3707 at the second tandem office. These receiving relays operate in conjunction with the relays 3710 and 3711 to position the corresponding office registers 3800, 3801 and 3802. Therefore, the register relays 3803, 3804, 3805, 3806, 3807 and 3808 are energized and locked to the grounded conductor 60 3702.

Following the transmission of the third digit corresponding to the setting of register 2702, the relay 2620 again operates and

the grounded circuit through its outer right contact extends over conductor 2698, through the left front contacts of relays 2710, 2716 and 2723, thence over conductor 2760, outer right front contact of relay 2657, conductor 2636, inner left back contact of relay 2808, winding of relay 2809 to battery. From this point on the impulse mechanism operates to transmit impulses representing the numerical part of the designation to the second tandem office in substantially the same manner as heretofore described. The numerical impulses are received at the second tandem office and cause the setting of the thousands, hundreds, units and tens registers 3900, 3901, 3902 and 4000. Of these registers the relays 3903, 3904, 3905, 3906, 4002 and 4003 are operated and locked to the grounded conductor 3702.

Release of the register sender in the first tandem office.

Immediately following the transmission of the units digit from the sender in the first tandem office, a circuit is closed from ground through the outer right contact of relay 2620, thence as traced over conductor 2698, through the contacts of relays 2710, 2716 and 2723, and thence to conductor 2636 95 as traced through the contacts of relays 2808, 2818, etc., left back contact of relay 2940, lower front contact of relay 2917, conductor 2918, through the winding of the sender release relay 2668 to battery. Relay 2668 operates and in the manner above explained causes the release of the register sender and the release of the sender selector switch 2500. At the time the sender selector 100 2500 releases, relay 2302 deenergizes and opens the circuit of the selector relay 2303. Relays 2300 and 2305 are also operated to extend the trunk 1823 through the windings of relay 2301, through to the second tandem office. Relay 2303 being slow holds its armatures attracted for an appreciable interval. During this interval a battery supply 110 is furnished at the second tandem office to maintain the relay 2301 operated in the manner about to be described.

Operation of the apparatus at the second tandem office.

As soon as the office record has been received on the sender at the second tandem office and register 3802 is positioned, the sender is associated with the tandem marker through the connector device 4400 and the office code is transferred from the registers of the sender to the registers 4201, 4202 and 4203 of the marker. Following this the translator 4200, 4220 is positioned and the proper one of the group relays 4310, 4311, 4312, etc. is operated to select the proper group of trunks on the tandem district 130

switch 3500 which leads to the called or terminating office. The test relays 4300 and 4303 may be brought into play in the manner heretofore explained for testing the 5 horizontal links either in the upper or lower sections 3502 or 3501 of the district switch 3500 and also for testing the corresponding trunks of the outgoing group. Thereupon the tandem district switch 3500 is operated 10 and the incoming trunk 2428 at the first tandem office is extended over an idle outgoing trunk 3508 leading to the terminating office. With the connection established through the switch 3500, the tandem marker 15 is disassociated from the tandem sender by release of the marker connector 4400.

Class indications.

During the time the marker in the second 20 tandem office is associated with the sender, the necessary class indications are set up in the tandem sender through the agency of the translator of the marker. A circuit may be traced for this purpose from ground 25 through the right contact of relay 4100, conductor 4102, through contacts of relay 4221, which is operated at this time, contact of relay 4222, conductor 4223, contact of relay 4401, conductor 4402, winding of relay 4005 30 to battery. Relay 4005 operates and locks to the grounded conductor 3702. It will be remembered that since the second tandem office is the last tandem in the series for this 35 particular call, the numerical record is to be transferred from the second tandem office to the final office rather than being transferred from a calling office through the second tandem office to the terminating office. Hence the distributing block 3613 associated with 40 the incoming trunk 2428 at the sender selector switch 3600 is disconnected from ground. This prevents the relay 3712 from becoming 45 operated. With relay 3712 deenergized, relays 3704 and 3713 remain inert, and their operating circuit is broken at the right-hand contact of relay 3712 and also at the back contact of relay 3907. This latter relay operates upon the receipt of the thousands digit prior to the time relay 3714 is operated 50 from the marker.

When relay 4005 operates immediately following the association of the marker with the sender, a circuit is closed from battery through the winding of relay 3715, conductor 55 3809, lowermost front contact of relay 4005, uppermost contact of relay 4006 to ground. Relay 3715 connects battery and ground through its front contacts to conductors 3611 and 3612, which in effect, 60 amount to connecting battery and ground across the tip and ring conductors of the trunk interconnecting the first and second tandem offices. This act establishes a circuit over the tip and ring conductors of the 65 trunk, through the windings of relay 2301

at the first tandem office, thence over the trunk leading to the originating office, through the office and district selector switches to the tip and ring conductors of trunk 114, thence through the winding of 70 the polarized relay 233. The flow of current in this circuit is not in the proper direction to cause the operation of relay 233. It does, however, hold the relay 2301 at the first tandem office operated in order to maintain the relay 2303 operated to hold ground on conductor 2315 to hold the switch 2400 in its operated condition. The closure of this circuit just described takes place immediately following the transmission of the 80 record from the first to the second tandem office before the slow relay 2303 has time to release following the energization of relay 2302.

Transfer of numerical record from the second tandem office to the terminating office.

As soon as the numerical impulses are received and relay 3714 operates the relay 90 3716 operates in the manner already explained and prepares to extend the tip and ring conductors of the outgoing trunk through the winding of relay 3718. When a little later, the tandem district switch is 95 operated to extend the trunk to the terminating office, relay 3718 operates in series with the windings of relay 4504 and causes the operation thereby of relay 3719. Relay 4504, in operating, initiates the operation of 100 the sender selector 4700 to attach an idle sender to the incoming trunk at the final office. Upon the attachment of the sender the relay 4501 operates to disconnect battery and ground from the trunk, whereupon 105 relay 3718 in the sender of the second tandem office releases and causes the operation of relay 3717. In the manner already fully explained, the relays 3720 and 3721 are brought into play to generate and transmit 110 code impulses to the second tandem office in accordance with the setting of registers 3900, 3901, 3902 and 4000, to in turn, position the corresponding numerical registers 4900, 4901, 5000 and 5001 at the terminating 115 office.

Release of the sender in the second tandem office.

After the last digit has been transmitted 120 from the second tandem office a circuit is closed from ground through the outer right contact of relay 3722, contact of relay 3723, right back contact of relay 3724, conductor 3725, left front contacts of relays 3907, 125 3908, etc., left back contact of relay 3810, middle lower front contact of relay 4005, conductor 4007, winding of release relay 3726 to battery. Relay 3726 brings about the release of the sender and registers and 130

sender selector circuits in the manner substantially the same as described hereinbefore in connection with other parts of the system. Upon the release of the sender in the 5 second tandem office, relays 3402 and 3406 are operated and relay 3407 is included in the tip and ring conductors of the through circuit.

Following the receipt of the last of the 10 numerical digits at the terminating office, relay 4808 is operated in the manner already explained and battery and ground is connected to the two sides of the incoming trunk circuit through the windings of relay 4806. By this operation a through circuit is prepared including battery and ground connections through the windings of relay 4806 at the terminating office, thence over the 15 trunk through the windings of relay 3407 20 at the second tandem office, thence over the trunk through the windings of relay 2301 at the first tandem office, thence over the trunk to the originating office, through the windings of polarized relay 233. This circuit is completed at substantially the same 25 time that the sender in the second tandem office is released, whereby the relays 3407 and 2301 are operated before the corresponding slow relays 3403 and 2303 have time to 30 release to remove ground from the sleeve conductors upon which the tandem district switches depend for their maintained operation. Thus a through connection has been established from the originating office 35 through two tandem offices into the sender of the terminating office. The apparatus is now in condition for completing the connection by operating the incoming switch 4600 and the group selector and connector 40 switches 5300 and 5400 to establish the conversational circuit between the calling and called subscribers' lines.

The operation of these latter switches takes place in substantially the same manner as that hereinbefore described and ringing current is applied to the called line if it is found idle.

The incoming and final marker and the incoming sender at the terminating office 50 after performing their functions are released at the proper times. When the called subscriber answers the supervisory relay 4513 energizes and serves to reverse the current over the tip and ring conductors of the 55 line whereby the polarized relay 233 in the trunk circuit at the originating office is energized to cause the operation of the message register in case the calling line is so equipped.

60 Release of the established connection.

Following conversation the calling and called parties hang up their receivers. This results in the deenergization of slow relays 65 204, 2303, 3403 and 4502. These relays remove

ground from the various holding conductors and thereupon the switches restore to normal and release the established connection.

Establishment of connection through two tandem offices involving full transmission of record to the first tandem office and a partial transmission of record to the second tandem office. 70

The next type of a call to be treated in this description is one where the connection extends from the originating office through two tandem offices to a final office and where the relative lengths of the different interconnecting trunks employed are such that it is desirable to transfer the complete record from the originating office to the first tandem office, then to transfer the office portion of the record from the first tandem office to the second tandem office and thereafter to transfer the numerical portion of the record from the first tandem office directly through the second tandem office to the final office. Referring to the diagram of Fig. 59 such a call may be illustrated by a connection from the calling line 5916 in the office 5902 to the first tandem office 5900, thence to a second tandem office 5901 and thence to a called subscriber's line 5914 in an outlying called office 5911. Considering the relative lengths of the different interconnecting trunks, the assumption here is that the originating office 5902 lies at a considerable distance from the first tandem office 5900 whereby the total distances from the originating office to the second tandem office 5901 is so great that the record must first be transferred in full from the originating office 5902 to the first tandem office 5900. It is also assumed that the distances from the first tandem office 5900 over the incoming trunk to the second tandem office 5901 and thence to the outlying office 5911 is sufficiently short to permit the safe transmission of the numerical part of the record from the first tandem office directly into the terminating office 5911. 100 105 110

With respect to the detail drawings the same office equipment and apparatus employed in a call of this type will be in general the same as that already fully described. It will, therefore, be necessary only to discuss in detail those features wherein a call of this particular class differs from those previously described. 115 120

Inasmuch as each different class of a call involves a different office code, it will be assumed that the name of the called office in this case has the abbreviation letters BER which are represented by series of 2, 3 and 7 impulses and, moreover, that the number of the called subscriber's line therein is the same as heretofore taken, namely 1 3 2 6. It is not considered necessary to explain any of the details of the operations 125 130

taking place in the originating office, since these will be substantially similar to those fully described hereinbefore. It is sufficient to observe that the office numerical records are set up on the registers of the sender in the originating office, following which, the district and office switches are positioned to extend the connection to the first tandem office, whereafter, the full record is transferred by code impulses over the interconnecting trunk and recorded on the registers of the sender at the first tandem office.

By inspecting the circuits it will be found that by operations analogous to those herefore considered, the code impulses representing the office designation cause the setting of register relays 2759, 2735, 2737, 2739 and 2741. The numerical code of impulses cause the setting of registers 2800, 2801, 2802 and 2900 the same as before explained.

At the first tandem office the marker is associated in the usual manner, the office code is transferred from the registers of the marker, the translator is positioned and selection takes place at the district switch 2400 to extend the connection to the second tandem office, following which, the marker is released and restored to the common use of other senders.

30 *Class indications.*

While the marker at the first tandem office is attached to the sender the necessary class records are produced in the sender by reasons of the particular settings of the translator device 3120 due to the office code. Where the register relay 2759 is operated in the present case, it may be found from inspection of the circuits that register relay 3140 alone of register 3101 is operated, whereas the registers 3102, and 3103 take the same settings as before. Due to this combination of settings of the registers 3101, 3102 and 3103, relays 3105, 3154 and 3119 are operated in the translator. This results in the extension of the circuit from the grounded conductor 3015, conductor 3136, through the contacts of relay 3154, horizontal conductor 3156, contact of relay 3105, winding of relay 3155 to battery. Relay 3155 operates and applies ground through the conductors 3138, 3152 and 3151 causing the operation of relays 2660, 2613 and 2917 in the manner already described.

55 Because of the assumption that the trunk from the originating office to the first tandem office is a long one this call is one of the class in which the ground connection at the connecting block 2540 should be omitted. Consequently, the relay 2662 in the marker is not operated as heretofore explained.

60 *Transfer of the office record from the first tandem to the second tandem office.*

65 When the connection is extended from the

first tandem to the second tandem office, an idle sender is associated in the second tandem office with the incoming trunk 2428 through a sender selector switch 3600 ready to receive the office record from the distant 70 or first tandem point. At the first tandem office the association of the marker with the sender causes the operation of relay 2665 as heretofore described. With relay 2660 operated and when relay 2665 subsequently, 75 operates, a circuit is closed from battery through the winding of relay 2604, right front contact of relay 2660, outer left contact of relay 2661, outer right front contact of relay 2665, conductor 2745 to ground at 80 the lower contact of relay 2743. Relay 2604 operates and when the connection is extended to the second tandem point, relay 2607 is included across the tip and ring conductors of the trunk and becomes operated to cause the operation of relay 2608. Later when the sender is attached at the second tandem point, relay 2607 releases and relay 2606 operates to start the impulse mechanisms in operation to transmit the 85 code impulses.

When relay 2620 attracts its armatures a circuit is closed from ground through the outer right contact of this relay, contact of relay 2621, right front contact of relay 2613, 90 conductor 2698, thence through the left back contact of relay 2710 to the winding of relay 2709. Relay 2709 operates and connects the first register 2700 with the impulse mechanisms. From this point on code impulses are generated and transmitted in accordance with the settings of registers 2700, 2701 and 2702 to the second tandem office where the relays 3705, 3706 and 3707 respond to these impulses to cause the operation, respectively, 100 of registers 3800, 3801 and 3802. Of these registers the relays 3804, 3805, 3806, 3807 and 3808 are operated and locked. Following the transmission of the third digit, relay 2620 energizes and a circuit heretofore traced is closed over conductor 2698, thence through the left front contacts of relays 2710, 2716 and 2723, conductor 2760, outer right back contact of relay 2657, outer right contact of slow-to-release relay 2610, left back contact of relay 2699, winding of relay 2655 to battery. Relay 2655 operates but relay 2699 being shunted remains deenergized for the time being. A circuit is now 110 closed from battery through the winding of relay 2610, right contact of relay 2699, outer right contact of relay 2655 to ground over conductor 2684. Relay 2610 operates and at its left contact opens the holding circuit of relays 2606 and 2608. 120 These relays release to disable the impulse mechanism from transmitting any further impulses. Relay 2610 at its outer right contact removes the shunt from around the winding of relay 2699 and this relay oper- 130

ates in series with relay 2655. Relay 2699 at its right contact opens the circuit of relay 2610 which, after an interval, becomes deenergized to reclose ground potential to the holding conductor 2633. Since the relay 2606 is released the impulse mechanism at the first tandem office will wait until it gets a signal from the distant terminating office notifying it that the numerical impulses 10 may be transmitted over the line.

Operation of the apparatus at the second tandem office.

Following the receipt of the office code at 15 the second tandem office, a marker is associated with the sender in the manner explained, the office record is transferred to the registers of the marker, the translator is positioned and selection takes place at 20 the tandem district switch 3500 all substantially as heretofore described.

Class indications.

It will be observed that this call is one of 25 the class in which the numerical portion of the designation is to be transmitted directly through the second tandem office from one of the preceding offices. Because nothing is known about the total length of the trunk 30 incoming to the second tandem office the connecting block 3613 is not strapped to the ground connection and the relay 3712 in the sender is not operated.

When the tandem marker is connected to 35 the sender at the second tandem office, the record on registers 3800, 3801, and 3802 is transferred to the registers 4201, 4202 and 4203 of the marker. This results in the operation of relays 4224, 4225, 4226, 4227 40 and 4228. The operation of these relays results in the operation of multicontact relays 4222 and 4229. With these relays operated, a circuit may be traced over the grounded conductor 4102 through contacts 45 of relay 4229, contacts of relay 4222, thence over conductor 4223 to contacts of relay 4401, conductor 4402, through the winding of relay 4005 to battery. Relay 4005 operates and locks to conductor 3702. For this 50 particular class of a call, it may be noted that the relays 3704 and 3713 are operated over a circuit leading to the back contact of the relay 3907 associated with the thousands register 3900 inasmuch as no thousands record is received. Relays 3704 and 55 3713 lock through the outer left contact of relay 3704 to the grounded conductor 3703. The relay 3704, in operating connects the tip and ring conductors of the incoming 60 trunk 2428 from the first tandem office to the corresponding tip and ring conductors of the trunk outgoing through the selector 3500 at the second tandem office to the distant terminating office. The polarized 65 counting relay 3728 is included in this cir-

cuit for the purpose of counting the number of digits transmitted through from the sender at the first tandem office in order to determine when it is proper for the sender in the second tandem office to release. The 70 relay 3713 which also operates at its upper contacts, disconnects the tip and ring conductors from the contacts of relay 3716.

Transfer of the numerical record from the 75 first tandem office to the terminating office.

When the connection is extended through to the terminating office battery and ground potential is connected through the windings of relay 4504, over the trunk to the second tandem office, thence through the winding of the polarized counting relay 3728 and thence over the trunk 2428 to the first tandem office through the winding of relay 80 2607. Relay 2607 operates and causes the operation of relay 2608. As soon as the sender is associated at the terminating office battery and ground potentials are disconnected from the trunk and relay 2607 at 85 the first tandem office releases to permit the operation of relay 2606.

It may be noted that the flow of current through the winding of relay 3728 is in proper direction to operate this relay. Relay 3728 operates relay 3731 and when current ceases to flow, relay 3728 releases and relay 3732 operates in series with relay 3731, thus making the first count in the sender at the second tandem office. With relay 90 2606 operated the impulse sending mechanism at the first tandem office is set in motion and the numerical digits are transmitted over the line as explained hereinbefore. The impulses representing these digits are 95 received at the terminating office and the registers 4900, 5000 and 5001 are positioned correspondingly. Following the transmission of the last units digit, the polarized counting relay 3728 operates for the last time 100 and in the manner fully explained hereinbefore, causes the operation of relay 4006. A circuit now may be traced from battery through the winding of relay 3726, lower front contact of relay 3713, conductor 3734, inner lower front contact of relay 4005 to ground at the lower contact of relay 4006. Relay 3726 operates and brings about the release of the sender and sender selector 105 switch in the second tandem office. 110

Also following the transmission of the units digit the sender at the first tandem office is released in the manner heretofore described. With the release of the tandem office senders a through connection is established as hereinbefore described from the terminating office where battery and ground potentials are supplied from the winding of relay 4806, over the trunk through both 125 tandem offices, through the originating of 130

fice including the winding of the polarized relay 233. The flow of current in this circuit is not in the proper direction to operate said polarized relay. It does, however, hold energized the relays 2301 and 3407 in the tandem office to maintain the district selector switches therein operated.

Following the receipt of the numerical record in the terminating office, the incoming and line markers are associated, respectively, and the incoming and group selector and connector switches are actuated to complete the connection through to the called subscriber's line. After conversation takes place the parties hang up their receivers and the connection is released.

Establishing a connection through two tandem offices involving the partial transmission of the record to each tandem office.

Lastly, the case will be considered in which a call involving two tandem offices is made of such a class that the office record is transferred from the originating office sender to the sender in the first tandem office, then from the sender in the first tandem office to the sender in the second tandem office, whereupon the numerical record is transferred from the sender in the originating office directly through both tandem points and established on the sender in the terminating office. With reference to Fig. 59 such a call is represented by a connection from the subscriber's line 5924 in the office 5925 to the tandem office 5900, thence to a second tandem office 5901, and thence to a subscriber's line 5926 in an outlying called office 5910. While as a general rule tandem offices lie at a considerable distance from one another, a case might exist where two of these tandem points were sufficiently near to permit the transmission of code impulses from an office satellite to one of the tandems to an office satellite to the other tandem. This would be true especially where the originating office is only a short distance from the first tandem point and where the terminating office is similarly situated with respect to the second tandem office.

Inasmuch as this is a different class of call from any of those previously discussed, the office code must be different and the assumption is that this code is represented by the abbreviation letters TER corresponding to a series of 8, 3 and 7 impulses. For simplicity the numerical part of the designation will be retained the same as in previous calls, namely, 1 3 2 6.

The operation of the apparatus in the originating office in response to the initiation of the call and the dialing of the impulses takes place substantially the same as hereinbefore described. Due to the effect of the office code on the translator of the

district marker, the class relays 613, 502 and 501 in the sender are operated, whereas the remaining class relays are left undisturbed.

At the first tandem point a register sender is associated as soon as the connection is extended and when the apparatus is in condition, the office code is transferred from the sender in the originating office and established on the registers 2700, 2701 and 2702 at the first tandem point. For this particular code, the impulses transmitted over the line cause the operation of relays 2758, 2759, 2761, 2735, 2737, 2739 and 2741.

Upon the receipt of the office code at the first tandem point, the marker is associated with the sender and the district switch is positioned as above explained to select a trunk leading to the second tandem office. During the time the marker is associated with the sender, the necessary class indications are reverted to the sender for controlling the further extension of the call. Since the relays 2758, 2759 and 2761 of the register 2700 are operated, corresponding relays 3139, 3140 and 3126 of the marker register 3101 are energized. Consequently, the multicontact relay 3108 of the translator 3120 is operated. With relay 3108 and relays 3105 and 3119 energized as heretofore explained, a circuit is completed over the grounded conductor 3015, contact of relay 3108, contact of relay 3105, winding of relay 3158 to battery. Relay 3158 operates and at its left-hand armatures connects ground to conductors 3138, 3152 and 3151 resulting in the energization of relays 2917, 2613 and 2660.

Moreover, due to the character of the trunk incoming from the originating office to the first tandem point, the connecting block 2540 individual to such trunk is strapped to ground and, consequently, class relay 2662 in the sender is operated and locked as heretofore explained, but because the connection is to be extended to a second tandem office, ground is not connected to its contact through the translator and relays 2673 and 2695 do not operate at this time. As soon as the tandem district switch 2400 at the first tandem point has operated and extended the connection to the second tandem office, a sender is attached to the trunk at said second office ready to receive the office portion of the designation. When the apparatus is in condition the relay 2604 is operated in a circuit from battery through its winding, right front contact of relay 2660, outer left contact of relay 2661, outer right front contact of relay 2665, conductor 2745 to ground at the lower contact of relay 2743. Relay 2604 operates and when the sender is eventually connected at the second tandem point, relay 2607 operates and releases as explained to start the impulse mechanism in operation. When relay 2620

energizes following the transmission of the third digit in accordance with the setting of the register 2702, it closes a circuit from ground through its outer right front contact, 5 contact of relay 2621, right front contact of relay 2613, thence as previously traced through the left front contacts of relays 2710, 2716 and 2723, conductor 2760, outer right back contact of relay 2657, outer right 10 contact of slow relay 2610, left back contact of relay 2699, winding of relay 2655 to battery. Relay 2655 operates, closes a circuit for relay 2610 which operates and opens the holding circuit of relays 2606 and 2608 thereby 15 disabling the impulse sending mechanism. Relay 2699 operates presently and opens the circuit of relay 2610 which becomes released after an interval. While relay 2610 is operated a circuit is also closed from ground 20 through its inner right contact, thence through the outer right contact of relay 2662, thence through the windings of relays 2673 and 2695 in parallel to battery. Relay 2695 at its upper armatures disconnects the 25 winding of relay 2607 from the tip and ring conductors of the impulse circuit. Relay 2673 in the manner heretofore explained connects the tip and ring conductors of the trunk incoming to the first tandem office to 30 the corresponding conductors of the trunk outgoing therefrom to the second tandem office and includes the polarized relay 2672 in this circuit.

At the second tandem point the office code 35 is received on the registers 3800, 3801 and 3802 resulting in the attachment of the marker, the operation of the district selector switch 3500 to extend the connection to the final completing office and the operation of 40 class relay 4005.

Because nothing is known about the total length of the trunk incoming to the second tandem office, the connecting block 3613 individual to this particular trunk is not 45 strapped to ground and, consequently, the class relay 3712 remains deenergized. Subsequently, the marker extends the connection through the switch 3500 and releases. Because no record was transferred to the 50 thousands register 3900 a circuit may be traced from battery, windings or relays 3704 and 3713 in parallel, through the outer left back contact of relay 3907, and thence to ground.

55 The relay 3704, in operating, connects the tip and ring conductors of the trunk incoming from the first tandem office, through the corresponding conductors of the trunk outgoing from the second tandem office to 60 the final office and includes the polarized counting relay 3728 in circuit therewith.

The relay 4504 at the terminating office is now connected across the tip and ring conductors of the circuit leading to the second 65 tandem office, thence through the first tan-

dem office to the originating office where the winding of relay 607 is included. Relay 4504 operates in this circuit and causes the attachment of an idle sender at the terminating office. The polarized relays 3728 70 and 2672 operate to make one count in the respective tandem office. Relay 607 at the originating office operates and subsequently releases to start the impulse mechanism at this office in motion to send the code impulses representing the numerical part of the designation to the final controlling sender.

75 After the units digit has finally been transmitted the sender at the originating office is released. At the first tandem office the polarized relay 2672 having caused the operation of relay 2920 as explained a circuit is closed as follows: from battery through the winding of relay 2668, conductor 80 2918, lower front contact of relay 2695, conductor 2624, inner lower front contact of relay 2917, lower contact of relay 2920 to ground. Relay 2668 operates and causes the release of the sender at the first tandem 85 office.

80 At the second tandem office polarized relay 3728 in a similar manner causes the operation of relay 3726 and the consequent release of the sender.

85 In the usual manner ringing current is applied to the called line from the terminating office and following the conversational periods the subscribers replace their receivers on the switchhooks causing the release of 90 the entire connection.

95 *Special features of the system.*

100 In the foregoing descriptions of the various classes of calls encountered in a system of this character deviations from the main line of thought have been avoided as far as possible by omitting to discuss the various secondary features and operations which are incidental in some cases and essential in 105 others to the establishment of the connection. Some of these more important features will now be considered under separate titles.

110 *Allotment of trunks at the line switch.*

115 A few words of explanation will now be given concerning the action of the allotter 143 of the line switch 100. As was pointed out hereinbefore, the allotter 143 serves to 120 continually keep an idle trunk allotted for use whenever a call is initiated. Each time a call is put through the allotter advances to find and allot a new idle trunk. Should, however, all trunks in the group leading 125 from the line switch be busy, it is desirable to take a record of this condition provided a subsequent call is initiated, and fails. Assuming that all trunks, except one, are busy and a call is initiated, the last trunk being 130

taken into use, relay 147, for example, is operated and a series circuit is completed through the left contacts of all similar relays, conductor 175, winding of relay 140 to battery. Should another call be initiated while all trunks are in a busy condition, relay 135, in operating, completes a circuit from ground over conductor 158, outer right back contact of relay 137, left front contact of relay 135, conductor 176, outer left contact of relay 140, left contact of relay 141, winding of relay 142 to battery. Relay 142 operates and prepares a circuit, from battery through its winding and the winding of relay 141 in series, contact of relay 142, to ground at the inner left contact of relay 140. Relay 141, however, is shunted so long as ground potential exists on the conductor 176. When ground is removed from conductor 176, relay 141 operates and closes a circuit for the register 177. Register 177 records that a call was initiated at a time when all trunks were busy.

Due to the existence of an all-trunk busy condition, the allotter switch 143 is prevented from operating since the circuit of magnet 138 is held opened at the right contact of relay 140.

30 Special features of the marker mechanisms.

The common markers are so arranged that in case one of them is associated with the recording sender and the operations fail to proceed within reasonable time, the marker 35 is automatically released and rendered free for association with other senders. Considering the district marker represented in Figs. 11, 12 and 13, it will be recalled that when the marker is attached to the recording sender, relay 1101 operates. A circuit may now be traced from ground through the contact of relay 1104, conductor 1116, inner right contact of relay 1101, conductor 1134, left back contact of relay 1114, winding of relay 1112 to battery. Relay 1112 operates and closes a circuit from battery through the winding of relay 1113, contact of relay 1112, to ground over conductor 1134. Relay 1113 actuates and closes a circuit from 40 battery through the winding of relay 1114, inner front contact of relay 1113, conductor 1134 to ground. Relay 1114 locks through its winding and left front contact to the grounded conductor 1134. Relay 1114 opens 45 the circuit of relay 1112, which, being slow, releases its armature after an interval. Relay 1112 opens the circuit of relay 1113, which also, being slow to release, requires an interval of time for retracting its armatures. 50 When relay 1113 releases a circuit is closed from ground over conductor 1134, inner back contact of relay 1113, inner right contact of relay 1114, conductor 1121, winding of relay 1100 to battery. The release relay 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 the uppermost contact. After reaching its full forward position the device 532 commences to restore under the control of a dash-pot, escapement or other suitable 5 method, and measures an appreciable interval of time during its release. The device is further arranged such that at the beginning of its restoration it opens its uppermost contact and closes its middle contact, 10 but does not close its lowermost contact until it measures the interval and reaches its fully restored position.

When the device 532 reaches its operative 15 position it opens its own circuit and also closes a circuit from battery through the winding of relay 533, uppermost contact of device 532, outer left back contact of relay 534, middle left contact of relay 529, to ground over conductor 531. Relay 533 operates and locks through its innermost lower contact, right back contact of relay 534, middle left contact of relay 529, to ground over conductor 531. Assuming the device 20 532 has time to restore to its normal position before the subscriber dials the first series of 25 impulses which would result in the operation of relay 529, then on reaching its restored position said device closes a circuit from battery through the winding of relay 30 535, right back contact of relay 529, lowermost contact of device 532, lowermost front contact of relay 533, middle contact of device 532 to the grounded conductor 531. Relay 35 535 operates and locks in a circuit from battery through its winding and innermost left contact, to ground over conductor 531. Relay 535 closes a circuit from ground through its inner right contact, right back contact of 40 relay 536, left back contact of relay 537, conductor 538, left contact of relay 409, lamp 446 to battery. The lamp 446, which is located at the monitoring operator's position illuminates to advise the operator that 45 a sender has been seized and that the first series of impulses has not been received within the allotted time. The monitoring operator may take such action as is necessary to ascertain the nature of the trouble.

The relay 535 also initiates the operation 50 of the sender connector 1400 to connect the district marker to the recording sender for the purpose of governing the operation of the district selector switch to extend the calling subscriber's line to a trouble operator's position. The circuit for operating 55 the sender connector may be traced from ground through the middle left contact of relay 535, conductor 540, outer right back contact of relay 513, conductor 514, winding 60 of relay 1409 to battery. Relay 1409, in the manner hereinbefore described, operates the sender connector to connect the district marker to the particular recording sender attached to the subscriber's line. When the 65 marker is associated with the sender a circuit

is completed from ground through the outermost left contact of relay 535, conductor 539, contact of relay 1401, conductor 1442, winding of relay 1109 to battery. Relay 1109 operates and locks in a circuit through 70 its winding and contact, conductor 1125, contact of relay 1105, inner left contact of relay 1106, to ground through the contact of relay 1104. Relay 1109 completes a circuit over the grounded conductor 1116, inner 75 right contact of relay 1106, inner left contact of relay 1109, conductor 1127, thence over conductor 1354 to a particular group relay similar to the relays 1306, 1307, 1308, etc. in the district marker, which is individual to the group of trunks of the district selector switch 1000 leading to the trouble operator's position. In the manner already thoroughly explained, this group relay causes the selection of the group of trunks 80 and the selection of an idle trunk therein, whereby the calling subscriber's line is extended through the district selector to the operator's position.

Relay 1109, moreover, closes a circuit from 90 ground through the outer right contact of relay 1106, outer left contact of relay 1109, conductor 1128, thence over conductor 1356, contact of relay 1401, conductor 1443, winding of relay 542 to battery. Thus the district marker, through the class conductors 95 1236 of the district translator 1200, establishes a circuit leading back to the recording sender whereby an indication is produced in the sender that the call undergoing extension is one of the class involving the selection of an operator's position. With this information the recording sender is enabled to govern its action to meet the requirements of that particular class of call. The relay 100 542, in operating, locks through its winding and inner right contact to the grounded conductors 531 and 507.

As soon as the district selector switch has 110 functioned, the district marker is prepared for restoration. Just before the district marker releases from the recording sender a circuit is closed, as hereinbefore traced, for the operation of relay 513. Relay 513 locks through its winding and inner right 115 contact to the grounded conductor 506. Relay 513 having operated, a circuit for the release relay 412 is established from battery through the winding of said relay 412, conductor 525, conductor 543, outer right front contact of relay 542, outer right back contacts of relays 503 and 502, outer left back contact of relay 504, outer right front contact of relay 513, conductor 540, to ground 120 at the middle left contact of relay 535. Relay 412 operates and in the manner hereinbefore explained brings about the restoration of the recording sender, inasmuch as the sender has been notified by the district marker that its service will no longer be 125 130

required in connection with this particular call. The trouble operator may communicate with the calling subscriber and complete the connection for him manually, if desired. At the end of conversation release of the operated equipment may take place in the usual manner.

Consider next that the calling subscriber, after initiating a call, transmits the first series of impulses regularly but that he fails to complete the transmission of all series of impulses within a prescribed interval following the transmission of the first series. This is known as an unfinished dialing condition in the sender and the presence thereof should be brought to the attention of the monitoring operator. When the first series of impulses are transmitted the relay 710 is operated, as hereinbefore explained. Relay 710 closes a circuit from ground through its inner left contact, conductor 753, winding of relay 529 to battery. Relay 529 operates and opens the circuit of relay 533, which is locked at this particular instant. Relay 533 releases and in so doing recloses the circuit of the time measuring device 532, which device at this time is in the act of restoring to its normal position. The reclosure of the circuit of device 532 immediately causes said device to move back to the end of its forward stroke. When relay 533 releases a circuit is closed from battery through the winding of relay 534, inner left contact of relay 529, uppermost back contact of relay 533 to ground over conductor 531. Relay 534 operates and locks through its inner left contact to ground over conductor 531. Therefore, when the device 532 is moved back to its fully operated position following the transmission of the first series of impulses, relay 533 is again operated in a circuit from battery through its winding, uppermost contact of device 532, outer left front contact of relay 534, outer left back contact of relay 544, outer left contact of relay 545, to ground over conductor 531. Relay 533 operates and locks through its winding and innermost lower contact, right front contact of relay 534, right back contact of relay 544, to ground over conductor 531.

Having again reached its full forward position, the device 532 opens its own circuit and commences to release measuring a new interval of time which starts with the instant the first series of impulses are transmitted over the line. Under the assumption the subscriber does not finish the dialing of all series within this required interval of time, therefore, the device 532 fully restores to normal before the units series of impulses are received and relay 927 is operated. This being the case a circuit is established from battery through the winding of relay 536, right back contact of relay 545, right front

contact of relay 529, lowermost contact of device 532, lowermost front contact of relay 533, middle contact of device 532, to ground over the conductor 531. Relay 536 operates and locks to the grounded conductor 531. Relay 536 establishes a circuit from ground through the resistance 546, right front contact of relay 536, left back contact of relay 537, conductor 538, left contact of relay 409, lamp 446, to battery. Due to the resistance 546 the lamp 446 burns dimly and this signal advises the monitoring operator that an unfinished dialing condition exists in the sender.

The next assumption is that the subscriber transmits the first series of impulses within the allotted time, transmits all series of impulses in the regular manner, but that the recording sender fails to complete its functions within a definite time following the receipt of the last series of impulses. A condition of this kind is known as a "stuck" sender, and the monitoring operator should be advised accordingly.

When the last or units series of impulses are received in regular operation, the relay 927 actuates before the device 532 has time to restore to normal. A circuit, therefore, is closed from ground through the inner left contact of relay 927, conductor 930, inner right contact of relay 517, conductor 518, winding of relay 545 to battery. Relay 545, at its outer left contact, opens the locking circuit of relay 533 and this relay immediately releases and recloses the energizing circuit of the device 532. The device 532 thereupon moves back to its forward position, opens its own circuit and commences to release gradually to measure a third interval of time which is calculated as sufficient for the sender to complete its function when acting normally. The relay 545, in operating, closes a circuit from battery through the winding of relay 544, inner left contact of relay 545, inner upper contact of relay 533, to ground over conductor 531. Relay 544 operates and when the device 532 moves back to its full forward position in readiness to commence the measurement of the third interval, the relay 533 is energized in the following circuit: battery, through the winding of relay 533, uppermost contact of device 532, outer left front contact of relay 534, outer left front contact of relay 544, conductors 509 and 507 to ground. Relay 533 locks through its innermost lower contact, right front contacts of relays 534 and 544, to ground over conductor 509.

Since the sender fails to function properly the device 532, in restoring to its normal position, closes a circuit from battery through the winding of relay 537, inner right contact of relay 510, outermost left contact of relay 517, right front contact of relay 545, right front contact of relay 529,

lowermost contact of device 532, lowermost front contact of relay 533, middle contact of device 532 to ground over conductor 531. Relay 537 operates and locks to the ground-conductor 531. Relay 537 completes a circuit from ground through the interrupter 547, left front contact of relay 537, conductor 538, left contact of relay 409, lamp 446 to battery. Due to the interrupter 547, the lamp 446 flashes to instruct the monitoring operator that a "stuck" sender condition exists. The monitoring operator may insert the plug of her cord circuit in the jack 447 and communicate with the calling subscriber advising him to repeat the attempted connection and may take such other action as is necessary.

Should the sender complete its functions before the device 532 has time to restore, release then takes place, as above explained, before the monitoring operator can be given a signal.

Extension of connection to an operator's position.

In some cases the subscriber may wish to obtain connection directly with an operator who may give him such information as he requires, or may complete the connection through to another operator or to the called subscriber's line. For this purpose the subscriber dials a single digit 0. Digit 0 is represented by a series of ten impulses which, from inspection, will be found to result in the operation of counting relays 413, 416, 417 and 418. With these relays operated and relay 709 actuated, a circuit may be traced from ground over the conductor 432, outer left front contact of relay 413, outer right front contact of relay 418, conductor 448, uppermost contact of relay 709, windings of relays 707 and 708 in series to battery. Relays 708 and 707 operate and lock in a circuit through the right contact of relay 707, to ground over conductor 736. Relay 707 completes a circuit from the grounded conductor 736 through its left contact, conductor 740, winding of relay 505 to battery. Relay 505 operates and closes the circuit for relay 1409, whereby the sender connector 1400 operates to associate the recording sender with the district marker.

Providing relay 1105 in the district marker is released, and since the register 1201 remains in normal position, no code digit having been dialed, a circuit is closed from battery through the winding of relay 1110, conductor 1131 to the inner right back contacts of relays 1227, 1226, 1225 and 1224, conductor 1243, conductor 1125, contact of relay 1105, inner left contact of relay 1106, to ground through the contact of relay 1104. Relay 1110 operates and locks through its right contact to the grounded conductor 1125. Relay 1110 closes a circuit from ground over conductor 1116, inner right contact of relay 1106, inner left contact of relay 1110, conductor 1130, thence over the conductor 1262 to one of the group relays 1306, 1307 and 1308 in the district marker 70 individual to the group of trunks leading from the district switch to the desired operator's position. In response to the operation of this group relay, selection of the group of trunks and the operation of the 75 district switch takes place in the manner already described and the calling subscriber's line is extended through to the operator's position.

Relay 1110 also closes a circuit from ground through the outer right contact of relay 1106, outer left contact of relay 1110, thence over the conductor 1128 in the manner traced, to relay 542 in the recording sender. Relay 542 operates and governs the 85 behavior of the sender in the manner explained.

On an operator's call it is not necessary to utilize the repeating coil 227 in the trunk circuit for talking purposes inasmuch as the 90 operator's cord circuit is ordinarily provided with means for supplying conversational current. The adjustment of the trunk circuit 114 to eliminate the repeating coil for this particular class of call is taken care of 95 by the common link circuit 1031 of the district selector switch 1000. It will be noted that the link 1031 is connected in circuit whenever one of the selector vertical magnets 1015, 1016, 1017, etc. is operated. 100 Therefore, when the relay 1110 operates on a call of this character it also closes a circuit from ground over the conductor 1128 as traced, conductor 1263, contacts of horizontal link 1031 in the vertical row 1008, conductor 1045, winding of relay 202 to battery. Relay 202 operates and locks in a circuit from battery through its winding and inner lower front contact to the grounded sleeve conductor 150. Relay 202 110 completes a circuit from battery through the winding of relay 208, inner upper contact of relay 202, to the grounded conductor 150. Relays 202 and 208 being operated, the subscriber's line is extended for conversation 115 over the tip and ring conductors 148 and 149 of the trunk 114 through the normal contacts of relay 201, which relay releases when the sender is discharged, front contacts of relay 202, through the outer right 120 front contacts of relay 205, which is also operated at this time in the manner above explained, front contacts of relay 208, and thence over the tip and ring conductors of the trunk through the district selector switch 125 1000 to the operator's position.

When the particular vertical operating magnet 1015, or 1016, employed in establishing connection, is released, the circuit of the horizontal magnet 1027 is opened and 130

this magnet restores to disconnect the common class horizontal link 1031.

All trunks busy condition.

- 5 The switches and controlling apparatus in the various offices may be arranged to take into account the fact that all trunks in the desired group are busy at the time the test is made. Referring, particularly, to the 70 equipment described in connection with the calling exchange, a description of this phase of the system will now be given.
- For instance, should all trunks in the desired group outgoing from the district selector switch 1000 be busy when the test is made, indication of this fact is recorded in the sender while the marker is still attached and a characteristic tone is transmitted from the sender back over the calling subscriber's line. If all trunks in the group containing the trunks 1028 and 1029 are busy, the corresponding test relays 1336, 1339, 1374, etc. will be energized. Consequently, when relay 1349 operates, the circuit hereinbefore traced is completed from ground over conductor 1364, conductor 1372, thence through contacts of relay 1315, right front contacts of relays 1336, 1339, 1374, through the right front contact of the last 80 of these relays, thence over conductor 1376, through contacts of the relay 1315, uppermost contact of relay 1309, winding of relay 1373 to battery. Relay 1373 operates and closes a circuit from ground through its 85 upper contact, conductor 1377, contacts of relay 1401, conductor 1468, winding of relay 510 to battery. Relay 510 operates and locks to the grounded conductor 509. Relay 510 completes a circuit from ground through 90 the secondary winding of the tone coil 560, outer right contact of relay 510, outer right back contact of relay 517, conductor 528, upper left contact of relay 710, conductor 95 733, condenser 424, lower winding of the coil 422 to the grounded conductor 425. The current induced in this circuit, in turn, 100 induces a current in the upper winding of coil 422 which flows over the subscriber's line and produces a characteristic tone in his receiver. This tone notifies him that one of 105 the switches has found all of the trunks busy and the connection cannot be obtained for the time being. Relay 510 at its inner left contact opens the previously traced circuit 110 for relay 412 to prevent the operation of this relay and the consequent release of the register sender. Relay 510 at its outer left contact applies ground to the conductor 561 which may, in the well-known manner, cause 115 the operation of a peg count meter. The calling subscriber realizing that the connection cannot be secured hangs up his receiver and permits the release of relay 400. Thereupon the connection is disestablished 120 in the manner fully explained.

Abandoned calls.

Should the calling subscriber after having initiated a call change his mind and abandon the same the partially established connection and all apparatus incident thereto should be released immediately.

At the originating office the abandonment of a call at any time prior to the release of the sender merely results in the release of the relay 400 together with the holding relay 402. This causes the removal of ground from the several holding conductors and the entire release of the apparatus as previously explained.

85 In the tandem offices where a release abandonment takes place on the part of the calling subscriber, either the relay 2301 or 3407, as the case may be deenergizes and causes the removal of ground potential from the holding conductors resulting in the release of the respective tandem district selector.

90 Should the connection proceed to the final or called office and the subscriber abandon the call after the sender has been attached, the result is the release of the relay 4806. Relay 4806 releasing at this time opens the holding circuit of relay 4800. Relay 4800 retracts its armatures and a circuit is closed 95 from ground through the right back contact of said relay, left contact of relay 4804, outer left contact of relay 4808, winding of relay 4802 to battery. Relay 4802 operates, locks temporarily and closes a circuit for relay 4804. Relay 4804 at its outer right contact opens the holding circuit of relay 4801. Relay 4801 removes ground from the holding conductors and permits the release of the sender and the sender selector switch 100 together with such other apparatus as may have been operated at this time.

105 Although the showing in this application has been limited to an exchange system employing only two tandem offices in connection with any particular call, it is obvious that as many tandem offices may be involved in a single connection as is necessary or desirable. In accordance with the principles already laid down for the explanation and control of connections through succeeding 115 offices, records may be transferred fully or partially through as many tandem points as may be necessary.

110 In the originating office illustrated in this disclosure the equipment shown in detail is particularly adapted for the purpose of extending calls outward to distant offices. It will, of course, be understood that each such office is also equipped with apparatus for receiving and completing calls to lines therein originating either locally within the same office or in distant offices. The same explanation applies with respect to the terminating office illustrated in this case where particu- 120 125 130 135

lar attention has been paid to the apparatus employed for the purpose of completing incoming calls.

For a better understanding of the manner in which other types of connections are handled, which are not specifically described herein, and also for further information regarding systems of this character, a general reference is made to the patent to S. B. 10 Williams, No. 1,517,331, granted December 2, 1924.

What is claimed is:

1. The combination in a telephone system having offices and means for extending a 15 connection involving a number of said offices, of means for storing in one of said offices a record pertaining to said connection, means for transferring said record directly through one of said offices to another of said 20 offices, and means in said last office for receiving said record to control the extension of said connection.

2. The combination in a telephone system having offices and selective switches in each 25 of said offices for extending a connection through a number of the offices, of means for storing in one of said offices a record pertaining to said connection, means for transferring said record directly through 30 one of said offices to another of said offices, means in said last office for receiving and storing said record, and means controlled in accordance with said record for operating the switches of said last office in the 35 extension of said connection.

3. The combination in a telephone system having a plurality of offices, of means for setting up the record of a designation in one 40 of said offices, means for extending a connection from said first mentioned office and involving a number of succeeding offices, means for transferring the record from said first mentioned office directly through a succeeding office to an office beyond involved 45 in said connection, and means governed according to such record for controlling the extension of said connection.

4. The combination in a telephone system having a number of offices and means for 50 extending a connection involving a plurality of said offices, of a calling subscriber's line terminating in one of said offices, means controlled by the calling subscriber for setting up the record of a designation in said 55 last mentioned office, means for transferring said record from the office in which it is established directly through a succeeding office to a still further office, and means in said last mentioned office operated in accordance with the transferred designation for still further extending the connection.

5. The combination in a telephone system having offices and means for extending a connection involving a plurality of said offices in tandem, of means for storing a record

pertaining to said connection at one of said offices, means for sending impulses in accordance with said record from said one of said offices directly through another of said offices to an office beyond, registering means in said last office responsive to said impulses for establishing the record of a designation, and means governed in accordance with said record for extending the connection. 70

6. The combination in a telephone system having a number of offices and arranged to extend a connection through a plurality of said offices, of means for storing a record pertaining to said connection at one of said offices, means for sending current impulses varying in character in accordance with said record directly through one office to an office beyond, registering means in such last mentioned office responsive to said impulses for establishing the record of the call, and means governed according to said record for completing the extension of the connection. 75

7. The combination in a telephone system of an originating office, a tandem office and a terminating office, means for extending a connection from the originating office through the tandem office to the terminating office, means at said originating office for storing a record pertaining to said connection, means for sending said record from the originating office directly through the tandem office to the terminating office, and a register mechanism in said terminating office for receiving and storing said record to control the further extension of the connection. 85

8. The combination in a telephone system of a number of offices, means for extending a connection from the first office to a second office, means for thereupon extending the connection from the second office to a third office, means for thereupon sending the record of a designation from said first office to said third office directly through said second office, a register mechanism in the third office for storing said record, and means controlled by said register mechanism for further extending the connection. 90

9. The combination in a telephone system of a plurality of offices, switching means for extending a connection from a first office to a second office, switching means for thereupon extending a connection from the second office to a third office, a subscriber's line terminating in said third office, means effective following the extension of the connection to the third office for sending a record designating said line from said first office directly to said third office, a register mechanism in the third office for receiving and storing said record, and switching means controlled in accordance with said record for further extending the connection to said subscriber's line. 115

10. The combination in a telephone sys-

tem of a central office, a calling line therein, a second office and a third office, switches in each of said offices, a controlling mechanism in the first office governed by the calling subscriber for establishing the record of a designation, means governed by said controlling mechanism for operating the switches in the first office to extend a connection to the second office, means for operating a switch in said second office to extend the connection to a third office, means for then transferring said record from the first office through the second office to said third office, and means controlled in accordance with said record in the third office for further extending the connection.

11. The combination in a telephone system having a number of offices and arranged for the establishment of a connection from a first office through a second office to a third office, of means for recording a designation record at said first office, means for sending a portion of the record from the first to the second office and for sending another portion of said record from said first to said third office directly through said second office, and means controlled in accordance with said record for establishing the connection.

12. The combination in a telephone system having a number of offices and arranged for the establishment of a connection from a first office through a second office to a third office, of means for registering a record at said first office, means for transmitting code impulses representing a portion of said record from the first to the second office and for transmitting code impulses representing the remainder of said record from the first to said third office directly through said second office, and means controlled in accordance with said record for establishing the connection.

13. In a telephone system, a plurality of offices having automatic switches therein, means for recording a record in one office, means for operating switches therein according to said record to extend a connection to a second office, means for transferring a part of the record to and establishing the same in said second office, means for operating a switch in the second office according to the record to extend the connection to a third office, means for transferring another part of the record through the second office to the third office, and for establishing the same in said third office, and means for operating the switch in the third office according to the record transferred for further extending the connection.

14. In a telephone system, a central office, a line incoming thereto, a line outgoing therefrom, means for connecting the incoming line to the outgoing line, means for sending a designation record over the incoming line, and means effective dependent

upon the character of the incoming line and upon the character of the outgoing line for determining whether said record shall be recorded at said office or shall be sent directly through said office over the outgoing line.

15. In a telephone system, a central office, a line incoming thereto, a line outgoing therefrom, switching means for connecting the incoming line to the outgoing line at said central office, means for sending the record to designate a call over the incoming line, and means effective dependent upon the length of the incoming line and upon the length of the outgoing line for determining whether said record shall be recorded at said central office or shall be sent directly through said office over the outgoing line.

16. In a telephone system, an office, an incoming trunk and an outgoing trunk, an automatic switch in said office for extending the incoming trunk to the outgoing trunk, a register mechanism in said office, means for extending the record of a designation over the incoming trunk, and means effective dependent jointly upon the length of the incoming trunk and the length of the outgoing trunk for determining whether said record shall be recorded on the register mechanism at said office or be sent directly through said office over the outgoing trunk.

17. In a telephone system, first, second and third offices, a trunk interconnecting the first and second offices, a trunk interconnecting the second and third offices, means for sending a designation record from the first office over said first trunk toward a second office, means effective dependent jointly upon the character of said first trunk and the character of said second trunk for determining whether said record is to be recorded in the second office or sent directly through the second office to the third office, and means controlled in accordance with said record for further extending the connection.

18. In a telephone system, first, second and third offices, a trunk interconnecting the first and second offices, a trunk interconnecting the second and third offices, a recording mechanism at the second office, means for sending the record of a call from the first office over said first trunk toward the second office, means at the second office controlled in accordance with the length of said first trunk and the length of said second trunk jointly for determining whether said record is to be recorded on the mechanism of said second office or sent directly through the second office to the third office, and means controlled in accordance with said record for extending the connection.

19. In a telephone system, a first office, a second office and a third office, a trunk

- line interconnecting the first and second offices, a trunk line interconnecting the second and third offices, selective switches for interconnecting said trunks, means for sending part of a registration from the first office to the second office, means effective dependent upon the character of the first trunk and upon the registration transferred for determining whether the remainder of said record shall be received at the second office and recorded or transferred directly from the first office through the second office to the third office, and means controlled in accordance with the last portion of said record for further extending the connection. 20. In a telephone system, first, second and third offices, a trunk interconnecting the first and second offices, a trunk interconnecting the second and third offices, means for registering a record in the first office, a selective switch in the second office for interconnecting said trunks, means for sending part of the record from the first office to the second office and for sending the last 25 of the record through the second office to the third office, means for sending all of the record from the first office to the second office and for sending a part of such record from the second office to the third office, and means governed according to the part of the record transferred to the third office for further extending the connection. 21. In a telephone system, a first, a second and a third office, a trunk interconnecting the first and second offices, a trunk interconnecting the second and third offices, means in the first office for registering a designation record, means effective dependent upon the character of the trunk incoming to and 30 upon the character of the trunk outgoing from the second office for determining either that a part of the record registered shall be sent from the first office through the second office to the third office or that such part of the record shall be sent to and recorded in the second office and then sent to the third office, and means governed in accordance with the transferred record for further extending the connection at the third office. 22. In a telephone system, first, second and third offices, a trunk interconnecting the first and second offices, a trunk interconnecting the second and third offices, means for establishing a record in the first office, means 35 dependent upon said record for determining whether part or all of said record shall be sent to the second office, means at the second office dependent upon a part of the record received for determining whether another part of said record shall be sent to the third office from the second office or directly from the first office, and means at the third office controlled in accordance with the record for extending a connection. 23. The combination in a telephone sys- 40 tem having a number of offices and arranged for establishment of a connection through a plurality of said offices to a terminating office, of means in said offices for registering a designation record, means dependent on the character of the connection for either transferring said record from one office to another in succession and registering the same in each such office or for transferring said record directly from one office through all intermediate offices to said terminating office, and means controlled according to said record for governing the establishment of said connection. 24. The combination in a telephone system having a plurality of offices and arranged for the establishment of a connection involving a number of said offices to a final office, of means in said offices for registering a designation record, means effective dependent on the distances between said offices for transferring said record either from one office to another office in succession and registering the same in each successive office or from the first office through all intermediate offices to the final office, and automatic selective switches controlled in accordance with said record for further extending the connection. 25. The combination in a telephone system having a number of offices and arranged for the establishment of a connection through a series of said offices, of means for registering a record in the first office, means for either sending all of the record to each succeeding office and there recording and resending it or for sending part of the record to each office in succession and the sending the remainder of the record from the first office directly through intermediate offices to the final office, and means controlled in accordance with said record for extending the connection. 26. In a telephone system, a first, a second and a third office, selective switches in said offices, a register sender and a controlling mechanism in the first office, means for transferring part of a record from the sender to the controlling mechanism to operate switches in the first office to extend a connection to the second office, means for operating a switch in the second office to extend the connection to the third office, means for sending another part of the record from the sender directly through the second office to the third office, and means controlled in accordance with the transferred record for operating switches in the third office to further extend the connection. 27. In a telephone system, a first, a second and a third office, selective switches in said offices, a register sender and a marker mechanism in the first office, means for setting said marker in accordance with a part of the record in said sender to control the switches

- in the first office to extend a connection to the second office, means for transferring said part of the record from the sender in the first office to the second office for controlling 5 a switch in said second office to further extend a connection to the third office, means for sending another part of the record from the sender directly through the second office to the third office, and means in said last 10 office for controlling the switches in accordance with the transferred record to further extend the connection.
28. In a telephone system, a first, a second and a third office, selective switches in said 15 offices, a number of senders and a marker mechanism common to said senders located in the first office, means for transferring part of a record from a sender to a common marker to operate switches in the first office for extending a connection to the second office, means for operating a switch in the second office to extend the connection to the third office, means for sending another part of the record from the sender in the first office 20 directly through the second office to the third office, and means controlled by the transfer of the record from the third office to operate switches therein for further extending the connection.
29. In a telephone system, a first, a second and a third office, a trunk outgoing from the first office and incoming to the second office, a trunk outgoing from the second office and incoming to the third office, coordinate switches having link circuits for 25 interconnecting the incoming and outgoing trunks, and means for sending designation records pertaining to the connection being established directly from said office through 30 the second office to the third office.
30. The combination in a telephone system having a number of offices, of coordinate selective switches in said offices arranged to establish a connection from a first through a second to a third office, means for recording a designation record at said first office, means for sending a portion of the designation record from the first to the second office and for sending another portion of said record from the first to said third office, and means controlled in accordance with said record for governing the coordinate switches in the establishment of said connection. 45
31. In a telephone system a first, a second and a third office, selective switches in said offices, a register sender and a marker mechanism in the first office, means for setting said marker in accordance with a part of the record in said sender to control the switches in the first office to extend a connection to the second office, a register sender and marker mechanism in said second office, means for transferring part of the record from the sender in the first office to the sender in the second office, means controlled by the marker in said second office for operating a switch in such office to further extend the connection to the third office, and means for sending another part of the record from the sender in the first office directly 50 through the second office to the third office, and a marker mechanism in said third office for controlling the switches in accordance with the transferred record to further extend the connection. 60
